TRUST COMPANY OF ILLINOIS, EXECUTORS OF SAID HERBERT M. FRIENDLY,
DECEASED

TELEPHONE SYSTEM

Application filed March 5, 1923. Serial No. 622,733.

The present invention refers particularly to toll (or long distance) telephone systems, though the devices thereof have adaptations in other arts as well. For example, the telegraph art.

Broadly, the present invention is directed toward providing a comprehensive toll system in which usual manual operative methods of interconnecting the toll lines and for 10 extending connections to local lines therefrom is supplemented by apparatus which may be remotely controlled by an operator.

It is not new to provide a toll line for dual operation, that is, manual and automatic, 15 where calls can be progressed manually, or be so progressed directly by a calling operator. However, the present invention comprehends extending these facilities so that the remotely controlled progression of 20 calls will be more rapid and positive, and that the calling operator will be enabled to perform switching functions at remote linking points corresponding generally to those usually accomplished manually at such 25 switching points.

To this end I provide an impulse control system corresponding generally to the duplex telegraph impulse control for conveying the control impulses over each section of a toll line, each said control system being complete and integral to each toll line so equipped. The said control apparatus operating upon the said duplex principle admits of adjusting to line conditions as are individual to each 30 line, so when an adjustment is attained the operation will be positive, almost without regard to abnormal line conditions which may exist. Directively controlled automatic switching mechanism, such as selectors, 35 are associated with the ends of the toll lines and this mechanism is interlinked with the said impulse control system, so that impulses applied by an operator at a calling end of a line will manifest directive operation of the 40 mechanism at the remote end of the line.

The said switching mechanism is arranged for extending not only a talking path from its line to a cooperative line under the directive control of the operator but it will 45 incidently interlink the impulse control sys-

tem of the calling line with that of the line to which connection has been made. This latter interlinking is accomplished without disturbing the individual line adjustments referred to. Impulses now applied to the 55 first line will be repeated over the impulse control means belonging to the second said line, effective to a directly controlled automatic switching mechanism at its far end generally similar to that on the far end of the 60 first said line. At the point of connection between two lines a repeating condition is set-up whereby control and other impulses received from the first said line are re-transmitted to the second said line, the adjustments 65 as regards the individual lines not being mutually affected. The mechanism at the far end of the second said line thus becomes responsive to the impulses transmitted by the calling operator as if the calling operator were transmitting the impulses from the 70 near end of the said second line, so that a third line can be linked from the end of the second said line in the manner that the first said line became linked to the said second 75 line, etc.

The ease of adjusting the impulse control system for mutual interlinkings whereby other lines do not have to be taken into account, together with the positiveness and 80 fastness, lends itself, to this application, since operators or others in charge of the individual lines will only be required to see that such lines are in themselves in proper order as regards to the impulse control mechanism 85 thereof.

The impulses will preferably be conveyed over a single conductor (or a simplex circuit) of a two-wire talking path, as if said impulses constituted telegraph signals, though it, of course, is manifest that the impulse path need not be a physical part of the talking path of the line it is designed to interlink or otherwise control. The talking path may obviously be a phantom circuit wherein the impulse path is derived from one or more of the side conductors, or from some other line or lines not in talking relation.

The impulse control system provides for sending directive and other impulses from 100

either end effective to mechanism at the other end so the toll lines may be interlinked to a cooperative line at either of its ends, controlled from the remote end. Of course, it is not essential that the equipments be located at the physical ends of the toll line as, in fact, the effective end in the use herein may be some miles distant of either or both physical ends, respectively.

10 The impulse control system also provides for transmitting impulses from opposite ends to corresponding opposite ends simultaneously without confusion. That is, while the operator is transmitting directive impulses over a plurality (or one) of toll lines which have been interlinked directly, perhaps, other impulses may be coincidentally sent towards, and to the calling station, effective to mechanism. The sending of impulses in 15 opposite directions simultaneously over a single physical conductor is not new in the telegraph art wherein intelligence is conveyed.

It thus appears that while the same physical conductor and prime impulse system is 20 employed for transmitting directive linking switch control impulses employing either end as the calling one, I also provide for sending impulses in both directions over the inter-linked path simultaneously during a calling 25 operation directed from one or the other end of the toll line, or toll line train. The object of this latter said arrangement is to enable the calling operator to receive manifestations, as by the indications on an indicator or indicators auxiliary to the impulse 30 transmitting means (calling device of the dial form, for example), whereby the progress of the call, responsive to the sent impulse, is evidenced coincidently with the sending 35 of the directive impulses. That is to say, while the various interlinking switches are operating responsive to the directive impulses sent, corresponding reverting impulses 40 are being sent back from an auxiliary contact set on the primary (vertical) magnet of the switch operating, effective to an indicator in view of the calling operator to confirm that the switch is responding correspondingly to 45 the directive impulses being sent. If, due to defectiveness of the line or adjustments, for example, the remotest switch is not responding or is not responding as directed from the calling device, this will be discerned by 50 a comparison of the impulse series sent with the indication, if any, displayed by the indicator. The said reverted impulses occur coincidentally, responsive to the directive ones sent. The indication of the indicator is 55 maintained until effaced incidental to setting the calling device for the sending of the next series of directive impulses whereupon the indicator will again indicate the directive performance of the now remotest switch of 60 the toll line train.

The linking switches of the exemplified system chosen to elucidate the invention, with the exception of a local connector shown, and which will be discussed presently, have an automatic secondary selective movement, self-initiated forthwith following the primary directive operation. The latter causes the first idle line of the group selected by the directive series to be seized. The latter assumes a plurality of lines in a selected group, through obviously one line only may constitute it, whereupon if this line (or lines) is found busy the switch will be caused to rotate to the last rotary position to operate a set of cam springs effective to applying a tone indicative of the condition, audible to the calling operator.

The rotary magnets of the various switches effective to causing the said automatic secondary movement thereof are provided with contact devices which will cause reverting impulses to be applied back to a second indicator auxiliary to the first said indicator. The latter said indicator becomes connected in place of the first said indicator, upon the calling device restoring upon transmitting the impulse series, so the second said indicator now responds to the secondary operations whereby an idle line is being selectively tested for and seized, or the wipers caused to rotate off the last set of bank contacts. Thus, if each said switch has access to ten sets of bank contacts per level, and the indicator indicates the wipers have been advanced to the eleventh position and causes a prompting lamp to glow, the calling operator will know the switch failed to seize an idle line. This will be confirmed by listening-in to discern the "11th rotary" tone. The first said indicator may be called the directive indicator, and the second said indicator the selective indicator. The selective indicator will maintain its indication until effaced incidental to next setting the calling device. Therefore, upon the operator sending a directive series, the directive indicator will operate as the calling device transmits and then the selective indicator will operate to indicate what trunk of the group has been seized, or if the switch failed to seize, and therefore rotated to the eleventh position. The operator can now deliberately observe the two indications before setting the calling device for the next digit, whereby the indications become effaced. The selective indicator apprising the calling operator what trunk has been seized by the last switch operating has in view that all trunks of a group may not possess the same transmission capability and therefore all may not be suitable for certain circuit trains.

Reference has been made to the prompting lamp associated with the selective indicator, which is to attract the operator's attention if the switch failed to find an idle line. A preferred arrangement is also shown (Fig. 11)

which provides for locking the calling device against being subsequently set without a special unlocking operation on the part of the operator in case the directive indication 5 does not correspond to the impulse series sent or if the selective indicator has indicated that the selector has not hunted, or has hunted and rotated past the last line position. This arrangement therefore provides a check 10 against careless operation wherein calling may be proceeded with after a faulty condition has been introduced into the call.

It will appear, presently, that under certain conditions special switches employed 15 will not selectively test a group of lines if all said lines are in a busy condition, a tone being applied audible to the calling operator indicative of the said condition. The said tone will also index the order in which the. 20 group has been encountered busy by other switches still locked against testing the lines of the group. That is, the tone will index how many calls (and their order of calling) are awaiting an idle condition to ensue to 25 one of the lines of the group ahead of the present call. This tone will change, to index the ensuing condition as other waiting switches which were operated previously selectively operate and seize or have been 30 caused to restore without doing so. Thus, if a switch having an order-of-access restores, any switch or switches having a subsequent order-of-access will have its (or their) order-of-access changed or advanced accordingly. Under 35 this condition of a switch being locked against selectively functioning, wherein the said preferred arrangement for locking the calling device is employed, it will operate to lock the calling device, because the remotest 40 switch failed to selectively function. The operator upon noting the condition of the indicators may listen-in to ascertain the order-of-access attained, for example, after which the operator may decide to await the idleness 45 of one of the lines of the group; destroy the established connection in whole, or destroy the established connection in part only, in a manner as will appear, presently, and thereafter re-route the call to the wanted line or an 50 alternative wanted line. Where the sending device employed is of the pre-set machine type the magnet for locking to dial sending device would be a magnet for locking the said machine sending device or perhaps a 55 relay whose office is to disable operative circuits thereof.

In further reference to the last foregoing, means is provided whereby the calling operator can multiply operate code-switches at all 60 interlinking centers concerned in a call. These code-switches are selectively effective to predetermined series of impulses to cause any of a plurality of functions to ensue at the certain, intended switching center. For 65 example, by sending a certain index series

all code-switches will prepare for introducing a speech amplifier. Then, when a digit train of impulse series is annexed corresponding to the numerical designation of the switching center at which the said introduction is to take place is transmitted, the pertinent code-switch functions to introduce the speech amplifier. The introduced amplifier can be ejected from the interposed relation by sending the same index series and annexed 75 digit train as employed for introducing it.

Provision is made for introducing a repeating coil into the talking path at any switching center. This introduction, like that referred to with respect to the amplifier, 80 can be effectuated as the call is progressed, or after a call has been built up complete to a point beyond.

Ringing current can be caused to be applied at any remote section of a built-up line 85 from the calling station through the agency of the code-switch thereat.

Through the agency of the code-switches, a built-up line train can be destroyed to any switching center, or only the local switches 90 extending from the line terminating switch at a switching center to a called local exchange substation line can be destroyed at will. Thus, any remote sections of a toll line train can be directly destroyed or just the 95 connection leading to a local substation at the remote end may be destroyed. This therefore provides for building a new toll line train while retaining any pertinent portion of a previously built-up train, and it also 100 provides for calling a plurality of substation lines in a local exchange without destroying the toll line train leading thereto. Were it necessary to destroy any portion or all of a train of line (or trunk) links which could be 105 employed in a call to be forthwith established, loss of line and operator time would be manifestly occasioned. This loss, and perhaps delay due to other seizure, may represent charges sufficient to carry an investment 110 and incidental costs many times the cost of equipments contemplated in the present invention to forestall the necessity of re-building-up each call in its entirety, regardless of the fact a portion of an existing call would 115 be re-employed in the new call to be linked forthwith.

Another capability of the code-switch is to enable the calling operator to signal the wire-chief (or other attendant or operator) at any 120 switching center concerned in a call being progressed, or in a call completed to a point beyond.

A preferred modification of the code-switches (Figs. 19-20-30) disclose means 125 whereby the series of impulses determining the function to be performed is sent last, a first train of series being sent to capacitate the code-switch at the concerned switching center. Where telegraph signals are to be 130

exchanged, for example, after a connection has been completed this arrangement provides against idly operating the code-switches.

5 Mention has been made of the duplex method of impulse control in the foregoing general statements. It will appear that some of the toll lines use the so-called simplex impulsing plan. Such as the latter would be 10 employed on short isolated lines where they would not become links intermediate of a long train of duplex links. The duplex method affords a faster and more reliable impulse path wherein impulses are to be repeated a number of times and where long 15 distances or troublesome line conditions are concerned. The said duplex also lends itself better than the simplex to conditions of indiscriminate inter-switching between lines of 20 all classes as to length and electrical condition.

Another function attained is supervision from the called substation line or from a responding operator to the calling operator. The return "side" of the duplex impulse control path is employed for this, in addition to 25 its use for conveying the reverting check impulses from the operating switches.

The operation of the system in view of the various functions enumerated, and other 30 functions not specifically mentioned, will appear from descriptions to follow, having due reference to the drawings.

Attention is called that in local exchange systems the costs attaching to outside wire 35 and plant construction does not greatly exceed the costs of the corresponding central office switching equipments under the most elaborate conditions of wire distribution. However, in toll line operation the outside 40 wire and plant construction may involve an investment many times that of switching equipment therefor. It thus becomes a problem in engineering and in economics to determine to what degree equipment functions may be consistently introduced into toll 45 systems, looking towards reducing the total investment required in the undertaking. This, of course, must be compatible with attaining a given traffic capacity with relation 50 to costs and practicability, and for maintaining a given service capability. It must also comprehend the earning capacity of the system with relation to auxiliary service supplementary to talking service, and also operating and carrying charges.

The selective switches employed belong to the class of U. S. patent to Keith, Erickson and Erickson, No. 815,321, granted March 13, 1906. The connector switch G15 belongs 60 to the class of U. S. patent to Keith, Erickson and Erickson, No. 815,176, granted March 13, 1906. The said selectors and connector are modified, however, so as to operate in accordance with the so-called two-wire principle and to operatively incorporate the ob-

jects of the present invention. The telephones may be of the well known two-wire automatic type. The calling devices employed by the operators are of the well known type dial calling device adapted to send 70 closed impulses. The latter function, however, is not essential, as intermediate translating means may be employed wherein open impulses are primarily sent. The calling devices are modified to function in accordance 75 with the present invention.

Fig. 22 shows a diagrammatic arrangement of a possible call contemplated under the invention.

Fig. 23 shows a diagrammatic plan of connections, contemplated in Figs. 24 to 28, (inclusive).

Figs. 24 to 28 shows how the drawings may be assembled to display some of the possible circuit arrangements involved in a comprehensive system of the present invention.

Fig. 29 shows means of connecting opposite ends of lines into bank levels in order to vary the preference of selection between calls in opposite direction.

Fig. 30 shows a preferred modification of Fig. 9 in which, either or both, a repeating coil and speech amplifying repeater can be directly introduced or excluded at will.

Fig. 24 specifically shows the assembly of sheets to display an organization of circuits in the system as are concerned in a call from a springjack J2 (in Fig. 2) on a toll switchboard to a called substation T'5 in a distant local exchange, the calling number of which is "7-8-4-1-1-1". In this organization of circuits, a single toll line link L2 is involved. Other organizations or circuit linkings from springjack J2 will be detailed presently, which involve a plurality of toll line links.

Attention is called to the fact that while a selective switch is not shown associated with the end of the toll line L2 to which springjack J2 is connected, it is to be understood that equipments such as is shown connected to the other end, to which springjack J'2 is connected, may be so introduced

at the end to which springjack J2 is connected, and moreover, such an organization (involving a selector at both ends of the line) would be the usual one in the commercial embodiment of the present system. The omission of the referred-to selective equipments have been occasioned in order to limit a comprehensive disclosure of the system to as little unnecessary circuit detail as possible; such limitations being followed in other illustrations as well.

Each end of the toll line L2 has composite coils, such as are well known in the art, to enable impulses to be sent over a single conductor (which for convenience will be called the "impulse conductor") of the line, without appreciable disturbance to talking service over it. A salient feature of the invention is the employment of circuits and apparatus in connection with the impulse conductor which approximate so-called duplex telegraph organizations in respects, but of course, modified and adapted to the present invention. For example, P2 denotes a polarized relay with the winding center point (of its two windings) connected through the armature of the impulse relay p2 to plus battery (having its minus pole grounded). One winding terminal of relay P2 is connected to an artificial (adjustable) line to ground, and the other (physical) winding terminal thereof is connected to the sleeve conductor of switching plug S2. In connection with the latter said plug, the talking conductors are omitted (looking towards simplicity of disclosure), though it will be understood the tip and ring conductors of the said plug S2 correspond to well known switching cord and plug circuits wherein two conductors only are employed, or in fact, may be similar to that shown in the cord-pair, Fig. 10.

Connected to each end of the impulse conductor (209) of line L2 are polarized relays P'2 and P2', related in a duplex circuit disposition, their center winding points normally connected to minus battery, respectively. The sleeve of springjack J2 is connected to the physical winding terminal of polarized relay P'2. The duplex sets involving P'2 and P2', respectively, are permanently interlinked so as to mutually form a duplex repeater of the so-called indirect type, the latter distinction being occasioned by reason of employing the secondary control relays p'2 and p'2'. Normally, the armatures of relays in Fig. 2 (and other figures) are resting as drawn. In this connection it will be noted that if plug S2 is inserted into springjack J2, the armatures of relays P2 and P'2 will not be disturbed, though the armatures of relays P'2 and P2' will be. Also, since relays P'2 and P2' are normally balanced and have the same polarity applied to the winding centers thereof, should the impulse conductor 209 become opened no 130

operative effect will occur to the armatures of said relays P'2 and P2'. However, if the polarity is changed at the center point of the winding of either relay P'2 or P2' the relay at the opposite end of the said impulse conductor will operate its armature from the position shown in the drawings. The latter function is independent of any said change of polarity applied to the center point of the winding of the opposite relay which may be in the act of operating, or which it may be desired to operate from or to the position shown in the drawings. It is thought this will make clear the normal adjustments of all polarized relays shown in the drawings regardless of the fact all armatures thereof are shown resting against the left-hand stop. The latter depends upon the polarity of the permanent polarizing magnets and the direction of the electro-polarizing windings.

The circle M2 encloses equipments, the purpose of which is to index to the calling operator what action, if any, is resulting from control impulses directly sent. This, as has been referred-to, enables the calling operator to also know what trunk of a group is selected, having in mind that the trunks of a group may not all be of the same transmission efficiency, and therefore not all suitable for calls over certain distances. Again, were no means afforded to enable the calling operator to be definitely informed as to the progress of the call, and a faulty link is encountered, the operator will continue to transmit the control impulses idly. If no response is obtained the reason thereof cannot be definitely attributed. The more links there are concerned in a call the more indefinite the status becomes. In commercial operation defective links are frequently encountered, and where no means is provided to check the condition of the interlinkings the localization of trouble is delayed, aside from the line and operator time taken in idly holding operative links in such a futile call.

The equipments denoted by M2 are companion to the operator's calling device D2 and are common to all cord-pair calling device keys (as K2) of an operator's position, so that when the calling device D2 is introduced, equipments denoted by M2 are also introduced. At this time it will be understood that the slow-releasing relay 201 is in series between conductor 202 and the stepping magnet MM2. A pointer 203 is driven from a shaft by magnet MM2 when the conductor 202 is grounded momentarily, so that the pointer (operating generally like a wiper of a connector of well known type) will indicate on the scale how many such impulses have been applied to conductor 202. The off-normal springs ON2 will operate consequent to the first off-normal movement of the pointer 203. So, when the sent and reverted impulse series ceases, and the calling device D2

restores, and relay 201 deactuates thereafter (it sustaining over a series), a closed circuit from the ground on the off-normal spring 204 in the calling device D2 will exist through off-normal springs ON2, armature of relay 201 to the release magnet Re2 to restore the pointer. That is, as the series of impulses are applied over conductor 202 the pointer 203 will correspondingly progress over the scale. The spring 205 will normally be disengaged from its cooperating spring 204, so when the sending device D2 restores, consequent to the termination of the last impulse sent therefrom, the springs 204 and 205 will become disengaged. This latter condition prevents the described path to the release magnet Re2 from being closed, though relay 201 deactuates. Under the condition, the pointer 203 will remain where advanced. However, upon setting the calling device for sending the successive digit series, the springs 204 and 205 engage and cause the magnet Re2 to restore the pointer 203, in readiness to be driven forward from its zero position consequent to the next series of reverted impulses being sent from the device D2, upon the operator releasing it. This enables the operator to leisurely observe the pointer before directly restoring it incidental to setting the calling device for the successive digit. The operation of the indicating device designated M2 will be discussed in further detail, presently, with reference to generally similar device M10.

The winding of the signal drop D'2 is normally in a bridge between the talking conductors of the line L2. The device M'2 is generally similar to M2, only that after the pointer shown thereon has progressed to a prearranged point the lamp 206 will glow as a signal. Upon the cessation of the impulse series wherein relay 201' (corresponding to 201) will deactuate (assuming push button PB normal) and close a path from ground, off-normal springs ON2' (corresponding to ON2), to the release magnet Re2' (corresponding to Re2) will restore the pointer 203' and disengage the springs ON2'. MM2' corresponds to MM2.

The device M'2 will function only if a switching plug is in springjack J2, as will appear, presently, and its purpose is to indicate if a predetermined number of impulses have been applied to it under conditions as will appear.

It is clear that a duplex combination, as is shown (assuming plug S2 in springjack J2), enables impulses to be applied from the calling device D2 effective to relay P2', and at the same time permits impulses to be applied effective to relay P2 from relay 207 or relay 208, over the impulse conductor 209 of the line L2 without mutual interference. That is to say, it is possible to send directive impulses from the calling device D2 over the conductor 209 and receive counterpart or

other impulses in return over said conductor 209. This permits a single control conductor to serve as an impulse path in both directions simultaneously and independently. In view 5 of it being contemplated to provide opposite ends of line L2 with directive apparatus the duplex impulse circuit will function reciprocally depending upon which end of the line is the calling end.

10 In view of the foregoing, it will be clear that applying a plug (as S10 shown in Fig. 10, for example), into springjack J2 or J'2, and thereafter applying ringing current in bridge of the talking conductors of the 15 springjack, will cause the opposite calling signal drop D'2 or D2', as the case may be, to operate. This method would be employed if normal manual service is desired, the responding being as has been a practice in 20 strictly manual systems. However, in the present case, assuming plug S2 is inserted into springjack J2, a circuit path will be closed from the physical winding terminal of relay P2, winding of slow-releasing relay 210, 25 contact 211, sleeve of plug S2, sleeve of springjack J2 to the physical winding terminal of relay P'2. Relay 210 will actuate and apply ground to the armature of relay P2. In this connection it will be understood 30 that while the relay 210 is shown as slugged, to render it slow-releasing over short current impulse lapses, it will be of such mechanical construction as to not destroy its slow-releasing characteristic, consequent to a current reversal. That is, the armature of relay 210 35 will have inertia to prevent it retracting at the time of change of polarity wherein the effect of the slug will be in a measure momentarily destroyed.

40 Under the condition of plug S2 being inserted into springjack J2 (key K2 being normal, for the present), the unbalance between relays P2 and P'2 will be such that the armature of said relay P'2 will actuate 45 from the normal position shown. In commercial installations all cord relays corresponding to P2 will be adjusted to a standard, as will also line relays corresponding to P'2. Thus, any cord relay corresponding 50 to P2 may be connected with any line relay corresponding to P'2, and an operative condition will ensue. In the drawings, adjustable resistances and condensers are shown comprising the artificial lines of said relays P2 55 and P'2. In commercial installations, due to no changeable "line" condition occurring or being possible between relays corresponding to possible pairs, as relays P2 and P'2, the artificial line may have a permanent value, 60 and in fact, not necessarily involve condensers. Due to the armature of relay P'2 attracting to the right, the armature of relay P2 not being disturbed, ground will be applied from the armature of relay P'2 to the 65 winding of relay P'2, causing the polarity of

the center point of the winding of relay P'2 to be changed to plus. The relays P'2 and P2' are normally balanced, but are now unbalanced so that the armature of relay P2' will change its position, the armature of relay P'2 not being disturbed. Ground from the armature of relay P2' will be applied to conductor 212 and through armature 213 to the winding of slow-releasing relay 214. Relay 214, like other slow-releasing relays shown 70 in the drawings subjected to current impulse lapses, will sustain over short lapses as employed in directive calling. The attraction of armature 215 disables relay 216 and causes conductor 217 to become grounded for the 75 purpose of guarding the line L2 against seizure from a switch; for causing guard lamp 219 to glow, and for other objects as will appear, presently.

Ground from conductor 212 is applied 80 through armature 220, conductor 221 to the winding of control relay 301, the latter said relay actuating. Grounded armature 302 attracting, operatively energizes slow-releasing relay 304 and causes armature 305 to apply 85 ground to conductor 306 and to the winding of cut-off relay 222 to disassociate the signal drop D2'. Due to the attraction of armature 307, ground-seeking tone source T3 is applied over line conductor 225, audible to 90 the calling operator through the listening key of the concerned cord-pair. This indexes to the operator that the terminal equipment at the far end of the line has normally responded to the seizure and that the line is 95 probably in operative order, ready to receive the first directive impulse series.

In this connection (assuming that the cord-pair shown in Fig. 10 is substituted for the one having plug S2) attention is directed 100 to the fact that should it be desired to signal the operator at the far end of the line L2 by applying ringing current through switching plug S10 from the cord ringing key R10, in lieu of extending the call directly 105 through the agency of the calling device D10, the conductor leading from the physical terminal of relay P10 will be incidentally opened at the contact 211" (corresponding to 211) when applying the ringing current. 110 The object of this is to cause relay P'2 to de-actuate resultant to relay P'2 restoring to normal, and in turn cause relay P2' to restore and remove the ground from conductor 115 212. The latter condition will cause relays 301 and 304 to deactivate, followed by relay 222, to re-associate the signal drop D2'. Slow-releasing relay d'2 is connected in a local circuit of the signal drop D2' and is for 120 the purpose of applying a guarding ground to conductor 217 while armature 215 is retracted. It will be manifest that the winding shown on relay d'2 may be transferred to the core of relay 214 with like results, 125 thereby displacing relay d'2. 130

Going back to the condition wherein relays 301 and 304 actuated, it will now be assumed that it is desired to extend the call directively. The key K10 will be manipulated to prepare the sending circuit from calling device D10. The latter said device is arranged to close a circuit from ground through spring 223" (corresponding to 223) to the winding of relay p10, corresponding to the digit sent. Thus, in the present instance wherein the first digit is "7", will cause relay p10 to actuate and deactivate seven times successively, as a digit series. This will change the polarity normally existing at the center point of the windings of relay P10, so that relay P'2 will become correspondingly balanced, whereby its armature will, in turn correspondingly vibrate effective to relay p'2. The polarity existing at the center point of the winding of relay P'2, due to the attracted condition of the armature of relay p'2, will be changed seven times responsive to the vibration of the armature on relay p10 so that the armature on relay P2' will correspondingly vibrate with the armature on relay p'2. Each time the armature of relay P2' retracts (from its right-hand contact) ground is removed from conductor 212, causing relay 301 to correspondingly vibrate, so that the latter said relay thus vibrates responsive to the grounds applied from the calling device D10. Each time armature 302 retracts, its ground is applied through armatures 308 and 309, winding of slow-releasing series relay 310 to the vertical magnet V3, effective to step the shaft carrying the set of wipers 312 to 318 (inclusive) into alignment with the seventh level of bank contacts.

Remembering that the tone source T3 was initially applied audible to the calling operator consequent to the actuation of relay 304, it will be noted that consequent to the shaft stepping off-normal the spring set ON3 operates and incidentally disconnects the tone source T3.

It will be noted here that the fourth and seventh levels of bank contacts accessible to selector C3 correspond to selector D4, but it will appear, presently, that the selector D4 (and also the selector C3) will function differently depending upon which said level accessible to selector C3 is seized. It will also appear that when a call is destined to a local substation, as is the present call, the seventh level will be called, and if the call is destined to a toll line, the fourth level will be called. Of course, a plurality of pairs of levels would be connected to selectors corresponding to D4, which latter selector may be termed a combination local and toll selector in view of its dual functioning depending upon how seized by selectors corresponding to C3. Each level would ordinarily have ten sets of bank contacts, one only (the first) being shown, so if selector D4 is busy the

selector C3 will automatically function to test for and seize the first idle selector of the group containing D4, as will appear.

At the time relay 310 energizes (and sustains over the current lapses) ground from armature 305 is applied through conductor 320, conductor 321, off-normal springs to the winding of shunted relay 322, the latter said relay actuating and locking from conductor 321, armature 323 on the rotary magnet R3 to grounded armature 325. It will thus appear that relay 322 can unlock only under the condition of armature 323 attracting or the off-normal spring set ON3 restoring.

Upon relay 310 deactuating following the transmission of the "7" digit series, a circuit path is closed from armature 320, armature 327 to the rotary magnet R3, causing the armature 323 to attract and open the energizing path for relay 322. Consequent to the rotary magnet R3 actuating as set forth, the wipers 312 to 318 will rotate into engagement with the first set of bank contacts 328 to 334, respectively. Assuming for the present that bank contact 329 engaged by wiper 313 constitutes ground, due to selector D4 being busy, as will appear, this ground will be communicated through armatures 336 and 323, conductor 321, off-normal springs to the winding of relay 322, causing it to again actuate and lock as before, whereupon the rotary magnet R3 will be again energized by way of advancing the wipers an additional step into engagement with the second set of bank contacts (not shown), the wiper 313 again testing the condition. If the wiper 313 now finds ground, the wipers will be again advanced; the cycle continuing until wiper 313 fails to receive ground, whereupon the selector C3 will function as will be now described, assuming that the bank contact 329 did not constitute ground when primarily engaged by wiper 313. At the time relay 322 first actuated, the upper winding terminal of relay 337 is applied to ground by armature 325, the lower winding terminal of said relay 337 being grounded through armature 305. The ground is thus maintained on the upper winding terminal of relay 337 through wiper 313 while the selector C3 is hunting, so the winding of relay 337 is, in effect, short-circuited. However, upon wiper 313 failing to receive ground, the ground ceases to exist on the upper winding terminal of relay 337 and a series energizing circuit for relays 337 and 322 can then be traced therefrom through armature 323, conductor 321, off-normal springs to the winding of relay 322, the relay 337 actuating; the relay 322 remaining deactuated, due to its marginal adjustment. The selector C3 has thus seized selector D4.

Line conductor 209 is now continued over conductor 225, armatures 338 and 339, wiper 316, bank contact 332, conductors 340 and 130

341 to armature 401 of selector D4. Line conductor 228 is now continued over conductor 229, armatures 343 and 344, wiper 315, bank contact 331, conductor 345, conductor 346 to armature 402 of selector D4. A path can also be traced at this time from conductor 212, armature 220, conductor 221, armature 347, wiper 317, bank contact 333, conductor 348 to armature 403 of selector D4. A path also exists from the winding of relay 207, winding of solenoid 230, conductor 231, armature 349, wiper 318, bank contact 334, conductor 350 to armature 404 of selector D4. The relay 301 is still energized from grounded conductor 221, dependent upon the armature of relay P'2. Armature 336 being attracted, ground from armature 305 is applied to wiper 313 and to the seized bank contact 329 (and its multiples) as a busy guard for selector D4 against its seizure through multipled bank contact sets. Ground can be traced from attracted armature 351, armature 352, wiper 314, bank contact 330, conductors 354 and 355, armature 405 to the winding of control relay 406 of selector D4. At the time the vertical magnet V3 operated, its armature applied its ground to conductor 231 at each operation, and these ground impulses are applied through the winding of solenoid 230 (non-effective to said 230, as will appear, presently) to the winding of relay 207 thus causing said relay 207 to vibrate its armatures seven times, thereby changing the polarity existing at the center point of the windings of relay P'2, correspondingly. The latter function will cause relay P'2 to correspondingly vibrate its armature seven times. At each vibration of the armature of relay P'2, a circuit path is closed through the winding of series relay 235 to the winding of relay p'2. The polarity of the center point of the windings of relay P'2 will thus be changed seven times, causing relay P10 to vibrate seven times. That is to say, upon the calling device D10 sending seven impulses over conductor 209 effective to operating the vertical magnet V3 seven times there will be seven reverting impulses applied back over conductor 209 (in effect), effective to relay P10. Since the combination of relays P'2 and p'2 with relays P'2 and p'2, disregarding the relay 235, form an "indirect duplex repeater", impulses may be transmitted through the said repeater combination in both directions without mutual interference. The object of relay 235 will be discussed, presently. Relay 210" (corresponding to relay 210) being actuated, ground from its armature is applied through the armature of relay P10, key spring 10", dial spring 8", conductor 202", winding of relay 201" to the magnet MM2", operative to drive the pointer 203" over the scale, in the manner as has been referred to hereinbefore with respect to M2.

In this connection it will be noted that at the time plug S10 was inserted into spring-jack J2, wherein the armature of relay P'2 operated to the right hand stop, the armature of relay P10 does not operate, due to the balance adjustments, it being also noted that the center points of the windings of relays P10 and P'2 normally have different polarity on their said center points. Under the stated condition, supervisory lamp 238" will glow. The latter said lamp will be caused to flicker while the reverting impulses are causing the armature of relay P10 to vibrate, however, to no prime purpose at this juncture. The contact springs 204" and 205" (corresponding to springs 204 and 205) being disengaged, disables the release magnet Re2", as has been set forth with reference to M2. The pointer 203" thus indexes the number of times the vertical magnet V3 operated, which, of course, should correspond to the number of impulses sent by the calling device D10, if the selector C3 operated as directed by the operator. The pointer 203" will remain where last set until the calling device is again set by way of incidentally closing off-normal springs 204" and 205" thereof, causing the magnet Re2" to operate. The operator can thus retain the indication of pointer 203" as long as desired.

After the selector C3 seizes, as set forth, the operator will set the calling device D10 for sending the second digit. The latter said digit will depend upon whether it is desired to start the ringing of the called subscriber automatically self-initiated upon his line becoming seized by the connector, or if the ringing is to be thereafter directly initiated by the calling operator. If the second digit is "8", the ringing will be automatically self-initiated, and if the second digit is "7" it will only be initiated under directive control of the calling operator, the same local selector E13 being attained in either case. It will appear, presently, that other levels, the first and the second, for example, are reserved for connections to toll lines through toll selectors, as Q5 in Fig. 5.

Assume that the operator now sets the calling device to send digit "8". The pointer 203" will be caused to restore as set forth. The eight impulses will be transmitted over conductor 221 to relay 301, in the manner as before. Upon each retraction of armature 351 the circuit path energizing relay 406 will be deenergized, so relay 406 will cause its armature 407 to vibrate eight times therefrom. At the time relay 406 first energized, its armature 407 applied its ground to operate energize slow-releasing relay 408. This causes armature 409 to apply a supplemental ground to conductor 410, it having been previously grounded from wiper 313. It will be thus manifest that conductor 410 may be dispensed with so far as it attaching

to bank contact 329 is concerned, which might be desirable if selectors C3 and D4 are located at a distance from each other. Armature 412 prepares a path for the vertical magnet, so upon each retraction of armature 407 ground is applied through armatures 413 and 412, series winding of slow-releasing relay 414 to the vertical magnet V4, effective to stepping the shaft carrying wipers 415 to 421 into alignment with the eighth level of bank contacts. The relationship of relays 422, 414 and 423, together with the rotary magnet R4 and private wiper 416 correspond to the relationship of relays 322, 310, 337, rotary magnet R3 and wiper 318, respectively, so it is not thought necessary to fully describe the selective functioning of selector D4 in order that its operation may be fully comprehended, and that it will therefore forthwith start hunting on the eighth level, having in mind that corresponding bank positions of the seventh and eighth levels (combined) lead to selectors similar to E13. Of course, it is not essential that there be a numerical correspondence between the latter said levels with respect to the accessible selectors, but it is preferred.

It will be assumed further that the selector E13 is idle and that the wipers 415 to 421 seize the bank contact set 424 to 430, bank contact 429 being dead. Relay 423 being now actuated, wiper 416 receives ground from conductor 410 by way of armature 431; conductor 355 becomes disassociated from relay 406 at armature 405 and is applied to wiper 417; conductor 346 is extended through armatures 402 and 432 to wiper 418; conductor 341 is extended through armatures 401 and 433 to wiper 419 and conductors 348 and 350 are extended through armatures 403 and 404 to wipers 420 and 421, respectively. Armature 409 retracts but ground is maintained on conductor 410 from armature 305 in selector C3. It also receives ground from selector E13, as will appear, presently.

At the time the vertical magnet V4 operated, its armature applied eight ground impulses to conductor 434, armature 404, conductor 350, bank contact 334, wiper 318, armature 349, conductor 231, winding of solenoid 230 (non-effective to said 230) to the winding of relay 207, causing the latter said relay to transmit eight impulses effective to relay P10 and the pointer 203", in the manner as before described, the release magnet Re2" being disabled from restoring the pointer until the calling device D10 is again set, the pointer thus always indicating the last digit sent effective to the remotest selector.

Before taking up the circuit condition now existing in selector E13, attention is directed to functions of the code switch C'3 auxiliary to selector C3. Relay 337 being actuated at the time of starting the second digit series, each time armature 302 retracts a ground is

applied from it, armature 308, conductor 345, series winding of slow-releasing relay 346 to the stepping magnet M3, causing the wipers 347—348 to be advanced eight successive steps over cooperating pairs of bank contacts, the relay 346 actuating and sustaining until after the eighth impulse is sent. The off-normal spring set ON3' will operate incidental to the first off-normal movement of the wipers 347—348, so when armature 349 retracts it closes a path from ground, off-normal springs to the release magnet Re3', operative to restore the said wipers 347—348 to normal. In view of the relationship of relays 337 and 301 not being changed until the selector C3 is restored, it will be clear, in view of descriptions to follow, that the code-switch C'3 will function as described in accordance with each digit of the called number as well as other digits subsequently sent. However, it will also appear that it has other functions, directly controlled by the calling operator.

Going back to the condition wherein the connection has been extended to bank contacts 424 to 430. Bank contact 425 leads over conductor 436 to attracted grounded armature 301' in selector E13. Bank contact 426 leads over conductor 439 through the series winding of slow-releasing marginal relay 302', series winding of marginal relay 303', armature 304' to the winding of low-resistance control relay 305', the relays 302', 303' and 305' actuating. The armature 306' being attracted, operatively energizes slow-releasing relay 307'. Bank contacts 427 and 428 lead over conductors 443 and 444, armatures 309' and 310', armatures 312' and 313' to wipers 315' and 316', respectively. Bank contact 430 leads over conductor 451, attracted armature 317' to free conductor 319'.

When the third digit "4" is sent, the equipments in Figs. 2 and 3 will function in the manner as when digit "8" was sent, but in view of armature 405 being attracted, the impulses applied over conductor 355 are now effective to relay 305' in selector E13, the included relay 302' sustaining over the impulse lapses, but the included relay 303' responding thereto. Each time armature 306' retracts, a ground impulse is applied thereto through armature 320', series winding of slow-releasing relay 321', armature 322' to the vertical magnet V13, operative to step the shaft carrying wipers 325', 326', 315' and 316' into alignment with the fourth level of bank contacts. At the time the vertical magnet V13' operates, its armature applies ground through attracted armature 317', conductor 451, bank contact 430, wiper 421, armature 404, conductor 350, effective to relay P10 as when the vertical magnet V4 applied ground impulses. In the present case, however, the pointer 203" is rotated over four scale divisions. At the time relay 321' ac-

tuated consequent to the first impulse applied to the magnet V13, its armature applied ground from conductor 436 through the winding of interrupter relay 335', armature on rotary magnet R13 to grounded battery, the said relay 335' actuating; its armature closing a locking path for its winding from conductor 436 by way of upper off-normal springs of set ON13 (which operated incidental to the first off-normal movement of the shaft), to the upper winding terminal of said relay 335'. Upon the armature of relay 321' retracting, following the last impulse, the winding of the rotary magnet R13 is applied to the grounded locking circuit, causing it (R13) to actuate and disconnect the battery from the winding of relay 335', causing the locking circuit to open. The wipers are now in testing engagement with the first set of bank contacts 331' to 334'. It will be noted here that the upper winding terminal of relay 336' is grounded on conductor 436, and that while the armature of relay 321' is attracted, the lower winding terminal of said relay 336' is applied to grounded conductor 436 by way of off-normal springs and armature of relay 321'. That is to say, the winding of relay 336' is then short-circuited. The rotary magnet R13 is energized through the make-before-break spring 338', and attracts its armature to disconnect the battery applied therethrough and rotates the wipers into engagement with the first set of bank contacts before the armature on relay 335' retracts by way of removing the ground applied therethrough to the lower winding terminal of the relay 336', so that if private wiper 325' encounters ground on bank contact 331' because of selector F14 in Fig. 14 being busy, the ground will be maintained on the lower winding terminal of relay 336' by way of its armature 339'. When the armature on the rotary magnet R13 retracts, relay 335' will be reenergized from battery at armature of rotary magnet R13, by way of spring 338', off-normal springs, armature 339' and wiper 325' to grounded bank contact 331', the rotary magnet again actuating to advance the wipers an additional step; this cycle of operations continuing as long as wiper 325' receives ground from a tested bank contact. When an idle, ungrounded bank contact is encountered by wiper 325', the rotary magnet will not be reenergized and ground will therefore cease to exist on the lower winding terminal of relay 336'. Under the latter condition there will be an energizing path from battery, armature of the rotary magnet, spring 338', off-normal springs, winding of relay 336' to grounded conductor 436. Due to marginal adjustments, relay 336' will actuate but its seriesed relay 335' will not, the selector E13 thus having seized.

It will be clear that if the wiper 325' fails to receive ground when it engages bank contacts 331' the selector E13 will seize thereat. The said seizure causes conductors 443 and 444 to be continued to wipers 315' and 316', respectively; conductor 439 to wiper 326' and conductor 436 to wiper 325'. The armature 301' retracts, so ground is maintained on conductor 436 from armature 305 in selector C3. The condition of conductor 451 has not changed because relay 302' is maintained actuated under the condition, as will appear.

The ground from armature 351 in selector C3, applied over the traced path to wiper 326' is continued through bank contact 332', conductor 342', armature 401' to the winding of low-resistance control relay 402'. The armature 404' applies its ground to operatively energize slow-releasing high resistance relay 406'. Armature 407' applies a supplemental ground to conductor 408' leading to bank contact 331'. The bank contact 333' is connected over conductor 345', upper winding section of repeating coil C14 in selector F14, to armature 410', and from contact 411', lower winding section of repeating coil, conductor 413' to bank contact 334', the last described path being open at retracted armature 410'. However, an operative path exists from conductor 345', condenser, winding of relay 415', armature 416', armature 417' to conductor 413'.

Returning to selector E13, at the time relay 336' actuated its upper armature applies ground to conductor 348', attracted armature 349' on relay 302', armature 350' to the winding of slow-releasing ringing relay 352', the latter said relay actuating to apply the ringing current source G13 over the talking conductors operative to relay 415' in selector F14, the armature 420' thereof attracting, but to no operative purpose at this juncture, as will appear.

When the fourth digit "1" is sent, the control relay 402' in selector F14 will deactivate and reactivate one time responsive thereto. The relay 406' will sustain over the lapse, and armature 422' will apply a ground impulse through armatures 424' and 425', series winding of slow-releasing relay 426' to the vertical magnet V14, operative to step the shaft carrying wipers 427' to 431' into alignment with the first level of bank contacts: 115 the off-normal spring set ON14 operating at the time relay 426' actuates, its armature 435' will apply ground from conductor 408' to conductor 438' through the upper off-normal springs to the winding of interrupter relay 442', causing the latter said relay to activate and establish a locking circuit for itself from armature 445', armature on the rotary magnet R14 to conductor 438'. Upon the armature 435' retracting at the termination of the impulse, ground will be applied therefrom, armature 446' to the rotary magnet, the rotary magnet operating to rotate the wipers 427' to 431' into engagement with the first set of bank contacts 451' to 455', re-

spectively. Assuming that private bank contact 453' is not grounded, indexing that connector G15 in Fig. 15 is idle. The latter said connector is (in general) well known in the art as a "combination local and toll exchange connector", and it therefore will not be necessary to detail its operation as to functions which do not bear upon its cooperative operation (in view of the present invention), with other elements of the system of the present invention. The selector F14 as relates to the equipment elements to the right of the repeating coil C14 are generally disposed as in well known toll, local exchange selectors, used as immediately antecedent to the connector, as in the present exampled instance. However, the selector F14 has novel objects, so far as I am aware. These novel objects relate (partly) to the application of ringing current to the called line.

When the armature 445' attracts, both winding terminals of relay 458' are then grounded, and the free winding terminal of relay 442' is short-circuited to ground, but 25 when the armature of the rotary magnet attracts wherein wiper 429' does not encounter a grounded bank contact, ground is removed from the upper winding terminal of relay 458' and the winding of relay 442' becomes in 30 series with it. The relay 442' is marginally adjusted so it will not operate under the stated series condition, but relay 458' will operate, thereby effecting the seizure of selector F14. However, had the wiper 429' encountered ground on bank contact 453', indexing the connector G15 is busy, this ground would be communicated to the upper winding terminal of relay 458' before armature 445' retracts, and upon the retraction of 40 the armature on the rotary magnet this ground will be applied over conductor 438' and off-normal springs to the winding of relay 442', to cause it (442') to reactuate, and in turn, cause the rotary magnet to advance 45 the wipers an additional step, the cycles of functioning continuing until the wiper 429' fails to receive ground, it being understood that there are a plurality of connectors similar to G15 normally accessible through the 50 first level bank contact sets, respectively.

Incidental to the seizure of connector G15 a circuit path can be traced from attracted armature 422', armature 460', wiper 427', bank contact 451', conductor 462', spring 55 501' to the upper winding of control relay 502'. Armature 503' will attract and apply its ground to operatively energize slow-releasing relay 504'. Armature 505' will apply its ground to conductor 506' to guard the connector G15 against intrusion by a local selector (none of which are shown), the ground from the latter said armature being applied through the winding of series relay 60 65 508', conductor 509', bank contact 453', wiper

429', armatures 463' and 465' to grounded battery, the relay 508' actuating to convert the connector. Circuit paths can now be traced from wipers 430' and 431', bank contacts 454' and 455', conductors 468' and 469', 70 armatures 510' and 511', armatures 512' and 513' to armatures 514' and 515', respectively. A circuit path can also be traced from retracted armature 472', wiper 428', bank contact 452', conductor 473', to the winding of 75 relay 516'. Due to the inside armatures of relay 458' in selector F14 being attracted, the upper and lower windings of relay 476' are applied through the upper and lower sections of repeating coil C14 to armatures 514' 80 and 515', respectively, so a closed circuit condition between armatures 514' and 515' will cause relay 476' to actuate. This will occur, as will appear presently, if relay 517' actuates while wipers 518' to 520' are in engagement with bank contacts 521' to 523', respectively, (for example) and the receiver at substation T15 is removed by way of a response thereto.

Going back to the condition ensuing upon 90 relay 458' actuating, ground can be traced from conductor 408', upper armature of relay 458', armature 477', armature 420' to the winding of relay 478' when relay 415' is energized from source G13 in Fig. 13, as has 95 been described. The relay 478' will actuate and lock through its lower inside armature, armature 477', upper armature of relay 458' to conductor 408', so that regardless of the duration of the application of source G13 at 100 selector E13, the relay 478' will remain actuated, incidentally disconnecting relay 415' at armature 416'. The interrupter device D14 will now apply ground impulses through the upper armature of relay 478' to the winding 105 of slow-releasing relay 480', causing it to periodically actuate in accordance with any desired ringing code. The actuation of relay 480' will cause relay 516' to actuate, followed by the deactuation of relay 508. The object 110 of the said relays 516' and 508' will appear, presently.

At the time the vertical magnet V14 operated, the one time, its armature applied ground to the upper winding terminal of 115 relay 476', the relay 458' not having yet actuated. This will cause relay 476' to actuate to disconnect the low-resistance winding of relay 402' and substitute the high resistance winding of relay 406' therefore. Due to the marginal adjustment of relay 303' the winding of which is now in series with the winding of relay 406' (also 302'), the said relay 303' will deactuate, relay 302' sustaining over the lapse. Thus, ground from conductor 348' 120 will be applied through the upper armature of relay 303', conductor 451, bank contact 430, wiper 421, armature 404, conductor 350, operative to relay P10 and the pointer 203' 125 in the manner before described. 130

The connector G15 being now in readiness to receive the last two directive impulse series (being one impulse for each series in the present call), its vertical magnet V15 will first operate to step its shaft, carrying wipers 518' to 520', into alignment with the first bank level responsive to the first digit impulse. Then, in response to the second digit impulse, the rotary magnet R15 will cause the 10 wipers to be set upon the bank contacts 521' to 523', respectively, whereupon the relay 517' will actuate to effect the seizing function of the connector. At each actuation of relay 516', followed by the deactuation of 15 relay 508', ringing current from source G'15 will be applied to the signal device at substation T15.

Incidental to the operation of the vertical magnet V15, and also the rotary magnet R15, 20 armatures thereon will cause two ground impulses (one for each digit "1") to be applied to talking conductor 468', operative to relay 476'. The brief operation of the latter said relay will cause relay P10 and the pointer 25 203'' to operate responsive thereto as before described. The calling operator thus has received confirmation indications through the agency of the pointer 203'' that the selectors C3, D4, E13 and F14 attained vertical levels 30 corresponding to the setting of the calling device (or not, as indicated), and that the connector G15 likewise set its wipers in accordance with the last two settings of the 35 calling device. Device M10 is disconnected at spring 8''.

Due to the continued functioning of relay 480' in selector F14, the ringing current source G'15 will be periodically applied, controlled by interrupter device D14. However, 40 upon the called party responding at substation T15 while relay 508' is actuated at an off-ringing period, the windings of relay 476' will become operatively energized, displacing the low-resistance winding of relay 45 402' by the high resistance winding of relay 406' for a prolonged period. The upper inside armature of relay 476' causes ground to be applied operative to slow-releasing relay 50 481'. The locking ground for relay 478' is thus disconnected, causing it to deactuate. Due to armature 417 being attracted, relay 415' is disconnected.

At the time the called party responded, causing relay 476' to actuate, followed by 55 the deactuation of relays 302' and 303', due to the slow-releasing characteristic of relay 352', a circuit may be traced from grounded conductor 348', armature 349', lower armature of relay 352' to the winding of relay 353'. The relay 353' will actuate and lock 60 to conductor 436, disabling the relay 352' from again applying ringing current. In this connection it will be noted that while the ringing current source G13 was applied 65 to relay 415', before the selector F14 seized, it

was to no operative purpose, due to the fact the upper armature of relay 458' is at that time retracted. It will also be noted, in this connection, that the described alternative functioning of relays 516' and 508' will be 70 to no operative effect until the relay 517' actuates, whereupon the called line will be rung upon.

Consequent to the prolonged attenuation of the current traversing marginal relays 302' and 303', after the response of the called party, both said relays 302' and 303' will deactuate, and under this condition a prolonged ground will be applied from conductor 348', upper armature of relay 303' to 75 conductor 451, operative to relay P10 as before described. Under the present condition the supervisory lamp 238'' is extinguished and the key K10 is in a restored position. The pointer 203'' indicates the last re- 80 verted confirming impulse corresponding to the last digit. This will be effaced consequent upon the next setting of the calling device, or may be done directly by moving the said calling device off-normal, simply. 85 The calling operator now manipulates the listening key L10, if same has not been in its operated position, as preferred, whereupon the conversation between the said operator and the called party may proceed, and the 90 connection further extended through the plug S'10, companion to plug S10, to a third party.

The solenoid 230 will operate, due to the prolonged application of current through it, 100 but to no operative purpose in the present call, since relay 241 has not actuated. The relay 235 remains actuated while the called party holds the receiver.

Should the called party flash the hook 105 wherein relay 476' will correspondingly deactuate with each flash to re-connect the winding of relay 402' for that of relay 406', the relays 302' and 303' will in turn respond by actuating to disconnect ground from conductor 451 to cause relays P10 and 235 to de- 110 actuate. The relay P10 will cause lamp 238'' to flash and the relay 235 will cause the device M'2 to operate in accordance with the impulses, having in mind that the latter said device will restore if a prolonged opening of 115 the path closed by the armature on relay 235 occurs. The device M'2 has other objects, as will appear.

If the called party permanently replaces 120 the receiver, the lamp 238'' will correspondingly glow as a disconnect signal. However, if under the latter assumed condition, it is desired to re-call the called party, it will be accomplished as follows: Attention is directed to calling device D10, which has sixteen finger-holes, each said hole corresponding to a setting. That is, setting the finger-holes with reference to the finger-stop will 125 cause different impulse series to be sent cor- 130

responding to the finger-hole so set and released. Thus, if the fifteenth finger-hole is rotated to the stop, in the manner well known, and released fifteen closed (or open) impulses will be effectuated by the impulse springs thereof. Calling devices of the general type, well known in the art, are provided with off-normal contact springs which are operated at all off-normal positions of the finger-hole plate. The calling device D10 belonging to the present invention has such off-normal springs, used for a novel purpose, as will appear, presently.

The re-ringing of the called line will now be proceeded with. The calling operator will set the calling device key K10 and then draw the fourteenth finger-hole to the stop and release. Fourteen closed impulses will thus be applied through spring 223" to the winding 10 of relay p10, effective to relay P"2 and other dependent relays including relay 301 in selector C3. Of course, relay 402' (in selector F14) and relay 502' (in connector G15), will operate fourteen times, responsive to the 20 calling device D10 but to no operative purpose, due to the condition of the circuits locally related to the latter said relays.

It will be remembered here that the code-switch C'3 operates responsive to the vibrations of relay 301; this time advancing its wipers 347-348 into engagement with the fourteenth set of bank contacts. Following the last impulse, the armature 349 retracts and applies its ground to conductor 356. In 30 this connection attention is directed to the off-normal sets ON3' and ON3''. The former set operates by a cam shown in Fig. 3A consequent to the first off-normal movement of the wipers 347-348. The latter set 40 operates by a cam shown in Fig. 3B consequent to the wipers 347-348 attaining the eleventh rotary position. That is to say, the set ON3' is in an operated state at all off-normal positions of the wipers, while the set 45 ON3'' is in an operated state at all off-normal positions beyond the tenth. The armature on the release magnet Re3' is adjusted to disconnect the contact at the extreme operated position of the said armature. The latter 50 provision is to insure that ground will be maintained on conductor 357 until just before the release pawl releases the wipers for restoration, and so that the wipers will be free of ground while retracting, so as to not affect passed-over bank contacts. The release magnet Re3' energizes through the spring set 55 ON3', conductor 356 to grounded armature 349. The general mechanical arrangement of the code-switch C'3 is as shown in the 60 patent to Stevens, No. 957,909, granted May 17, 1910. However, the release magnet in the present disclosure is effective upon its energization in lieu of upon its deenergization as shown in the said cited patent.

65 The ground is applied from armature 349,

conductor 356, armature on release magnet Re3', conductor 357, make-before-break spring 358, wiper 347, fourteenth cooperative bank contact to the winding of the slow-releasing ringing relay 359, the latter said relay operating to apply ringing current from source G3 to armatures 339 and 344, wipers 316 and 315, and over the before traced path to conductors 313' and 345' in bridge, operative to relay 415'. Relay 481' being normal, ground from conductor 408' is applied through upper armature of relay 458', armatures 477' and 420' to the winding of relay 478', causing the latter said relay to actuate and lock as before described, wherein the interrupter device D14 will apply ground impulses effective to relay 480', which in turn will cause the called line to be re-rung. Upon the called party again responding, the relay 481' will actuate as before, to unlock 70 relay 478' to stop the application of ringing current. The relay 359 will deactivate consistent with its releasing period, due to the wiper 347 retracting forthwith after applying ground to its cooperating fourteenth bank contact. However, a very brief application of ringing current to the relay 415' is sufficient to re-initiate the application of continuous ringing to the called line. The off-normal set ON3'' will cause conductor 360 to 75 become grounded because of the wipers 347-348 rotating past the tenth rotary position, the object of which grounding will appear, presently. The ringing of the called line can be re-initiated as often as desired, following a response, by sending a series of 80 fourteen impulses.

It will now be assumed that it is desired to restore the selector C3, and incidentally destroy the connection linked through selectors D4, E13, F14 and connector G15, without withdrawing the plug S10 or releasing the line L2. The calling device D10 will be set to send a series of eleven impulses, effective to rotating the wipers 347-348 into engagement with the eleventh set of bank contacts, wiper 347 applying ground to wiper 312 in the manner as before described with reference to applying ground to the winding of relay 359. Wiper 312 being in engagement with bank contact 328, the said ground will be conducted to the winding of slow-releasing relay 361, the latter said relay actuating to apply ground to conductor 362, off-normal springs to the release magnet Re3, operative 90 to restore the shaft of selector C3.

Consequent to the said restoration of selector C3, ground is removed from conductors 355 and 410 leading-in to selector D4. This will cause the deactivation of relays 502' and 504' in connector G15. The said deactivation of relay 504' will remove the ground applied to the leading-out extension of conductor 410. Therefore, relays 423, 302', 303', 336', 402' and 458' will deactivate. In case 95

the said series of eleven impulses had been sent while the called party is holding the receiver, relays 478' and 406' will deactuate, in addition, the latter said relay in lieu of 402'. At this juncture the connector G15 will be restored to normal due to a circuit path being closed from the release magnet Re15, armature 525', off-normal springs of set ON15 to grounded armature 505'. The selector F14 will be restored to normal due to a circuit path being closed from the release magnet Re14, off-normal springs, armatures 425', 424' to grounded armature 422'. The selector E13 will be restored to normal due to a circuit path being closed from the release magnet Re13, off-normal springs, armature 322', winding of relay 321', armature 320' to grounded armature 306'. The selector D4 will be restored to normal due to a circuit path being closed from the release magnet Re4, off-normal springs, armatures 412, 413 to grounded armature 407. It will be manifest that while the restoration of selectors C3, D4, E13 and F14 will be positive upon the said sending of eleven impulses the restoration of the connector G15 will be dependent upon the called party having the receiver restored, as otherwise armature 525' will be attracted, preventing the establishing of the operative circuit to the release magnet Re15.

Withdrawing plug S10 from springjack J2 will cause relay P2' to restore to normal, followed by relays 301, 304 and 337, in sequence. A circuit path can now be traced from the release magnet Re3, off-normal springs, armatures 309, 308 to grounded armature 302, operative to restore the shaft of selector C3. It will be manifest that withdrawing plug S10 while the connection to the called line was still established would have the same effect on selector C3, and in addition cause the succeeding linked switches to restore as when the shaft of selector C3 was caused to restore resultant to sending a series of eleven impulses.

Referring to Fig. 10, it will be noted that the calling device D10 has two reverting indicators M10 and M'10 associated therewith. The indicator M'10 is associated with spring 10" of calling device key K10, the off-normal spring 7" being serially included in the latter connection when the calling device D10 is normal. The indicator M10 is substituted for said M'10 at off-normal positions of D10, serially including off-normal spring 8". Having in mind that the indicators M10 and M'10 are similar to M2, though M'10 has an added off-normal spring set N'10 for an auxiliary use, it will appear that if the armature of relay P10 vibrates while the calling device D10 is sending impulses through spring 10" of Key K10, the indicator M10 will operate its pointer 203". In the same manner, if the armature of relay P10 vibrates while the calling device D10 is normal and

the key 10 is set, the indicator M'10 will operate its pointer 12". In both the latter said functionings the pointers will be disabled from restoring until the device D10 is moved off-normal. That is to say, if the indicator M10 operates while the calling device D10 is restoring and the indicator M'10 then operates after the calling device D10 restores, the respective pointers 203" and 12" will remain as set until the device D10 is next operated whereby the off-normal spring 205" grounds conductor 13" to close a circuit to the release magnets of the respective said indicators. The indicator M10 may be termed the "directive indicator" since it operates responsive to directive impulses from the device D10. The indicator M'10 may be termed the "selective indicator" since, as will appear, presently, it operates responsive to the automatic selective functioning of a switch (as a selector) after a primary directive functioning of the concerned switch. The calling operator thus has an indication of the operative effect of each directive series sent as well as an indication of the position automatically selectively taken by the last switch primarily directly operated. The latter thus indicates what trunk of a group or level has been seized in the case of a selector and that the switch is ready to receive the last digit series, in the case of a local connector. Of course, if the indicator M10 does not indicate in correspondence to the setting of the device D10, the operator will know the directive series sent was not properly effective, due possibly to a defective condition. The same will hold true with respect to the indications of the device M'10.

It has been explained how the directive impulses are reverted by the closure of a contact set on the vertical magnets of the respective switches when establishing the call to substation T15. With this in mind, it will be assumed that under the said calling condition the switch-arms 363 (in selector C3), 110 452 (in selector D4), 355' (in selector E13) and 482' (in selector F14), are moved into operative relation. It will now be clear that following the operation of the respective vertical magnets of the selectors, wherein the corresponding rotary magnets operate, the auxiliary armatures on the respective rotary magnets will apply ground impulses to the same control circuit as the auxiliary armature of the companion vertical magnets. The rotary magnet does not initiate its operation until the directive impulses to the companion vertical magnet has ceased and the calling device D10 is therefore at normal, whereat the indicating device M'10 is substituted for the device M10 with relation to key spring 10".

In commercial systems each selector level may, for example, have ten rotary bank positions corresponding to switches of the next numerical order. Assuming that the selectors

shown have this number of rotary bank positions, in case all tested positions are passed over as busy the rotary magnet of the concerned switch will have operated eleven times and caused the designated eleventh rotary cam springs to operate to apply an indicated tone source to the talking path, audible to the calling operator, thus apprising the condition. In such case the pointer on the selective indicator M'10 will be driven to the eleventh position, incidentally causing the off-normal spring set N'10 thereon to energize the signal lamp 14", so further idle calling will not be carried on.

15 The side-switch-arm 530' (grounded on conductor 506') and which is mechanically linked with the side-switch arms 531' and 532' passes over contact 533', momentarily grounding conductor 468' as the side-switch assumes the second position. This latter function thus causes the pointer 12" to indicate one impulse has been reverted after the calling device D10 restores. It confirms that the connector is ready to receive the final digit series. It will appear, presently, that it has another object.

In the described call, the line leading to substation T15 was caused to be automatically rung upon forthwith upon the seizure by the connector. This was occasioned because the third digit sent was "8", wherein selector D4 seized selector E13 at the eighth level. Should digit "7" be sent in lieu of "8", thereby causing selector D4 to seize selector E13 at the seventh level, the said automatic initiation of application of ringing current by the connector will not ensue, and will only ensue by a directive operation by the calling operator, as when re-ringing a called line, as described, since relay 352' will not energize. The only circuit changes in seizing selector E13 from the seventh level are that slow-releasing marginal relay 356' will become included in the impulse path including conductor 357' and relay 303', in lieu of conductor 439 and relay 302', and that leading-in conductor 358' will be concerned in lieu of conductor 451. That is, when the armature of relay 356' retracts upon the called party responding, conductor 458' will become grounded in lieu of conductor 451, (now free) as when armature 317' on relay 302' retracts. One of the conductors 451 or 358' will become grounded upon the retraction of relay 303', depending upon which of relays 302' or 356' is attractively energized, and conductor 451 is free when relay 356' is concerned, while conductor 358' is free when relay 302' is concerned. It is thus manifest that the calling operator can, at will, cause the ringing upon the called line to be self-initiated or directly initiated, depending upon what level the selector E13 is caused to be seized from.

15 The equipments shown in Figs. 2, 3 and 4

have other functions, some of which will be described, presently.

Assembling the figures as indicated by Fig. 25, it will be noted that Fig. 8 has been introduced to the right of Fig. 3 (as shown in Fig. 24), and Fig. 9 has been introduced to the left of Fig. 4 thereof. This examples the disposition of equipments wherein a second toll line is enabled to be linked to the toll line L2 at the switching center at which selector D4 is located. The selector D4 is employed at a switching center wherein there are more groups of toll lines than the line terminating selector C3 can reach from the sending of a single digit series. That is, the selector D4 may be considered as a second selector to the line-terminating selector C3, considered as a first selector. Selector D4 has access to selectors of the toll exchange and to selectors of the local exchange at the concerned switching center whereat selector H9, shown in Fig. 9, is the in-coming or first selector at the switching center for toll line L8.

It has been stated that the fourth and seventh levels (for example) of selector C3, and other selectors of its group, are connected to a group of combination local and toll selectors as selector D4. The ninth level of the selector C3 (for example), is connected to a group of toll lines, of which line L8 is assumed to occupy the first bank position therein, so that if the line L8 is found busy, the other lines of the group will be selectively tested and the first idle line seized. It will appear, presently, how the system of the present invention may be alternatively organized (as shown in Fig. 23), or in fact multiply disposed, so the leading-out conductors of the said ninth level of selector C3, for example, will be also accessible through the selector D4. Where the latter method is employed in linking a call, it will obviously require more directive operations from the calling station to effect a connection from line L2 to line L8. However, it will appear, that if more than one toll line link antecedes the line L8 it will ordinarily be advantageous to effect the connection through a selector as D4, and also a following selector, as Q5, shown in Fig. 5. The latter selector has the function of permitting a connection to be made to a line of a busy called line group, only in the order in which calling lines have encountered the group as busy, as well as other functions.

It will now be assumed that the plug S10 has been inserted into springjack J2, key K10 manipulated, and that relays 301 and 304 have actuated in the manner described, the selector C3 being in readiness to directly respond to the first series of impulses (constituting nine) to be transmitted from the calling device D10. Upon drawing the ninth finger-hole to the finger-stop (incidentally disconnecting spring 7" and connecting spring 8" over conductor 14" to spring 10"), and re-

130

leasing, the wipers of selector C3 will step into alignment with the ninth level in the manner as before described wherein the first digit transmitted was "7" in lieu of "9". The vertical magnet V3 will incidentally cause its contact armature to apply nine ground impulses to conductor 231, effective to stepping the pointer 203" over nine scale divisions. The selector C3 will forthwith self-initiate its rotary selective movement and rotate until an idle toll line is found and seized, which line in this instance will be assumed to lead from the first bank contact set. That is to say, the rotary magnet R3, 10 operates one time, incidentally applying a ground impulse through switch-arm 363 to conductor 231, effective to stepping the pointer 12" once. The indicators M10 and M'10 will thus index "9" and "1", respectively, indicative that the selector C3 stepped its wipers to the ninth level and there rotated them to the first set of bank contacts. Wipers 312 to 318 are now in engagement with bank contacts 364 to 370, respectively.

15 Circuits can now be traced as follows:— From winding of relay 800, make-before-break spring 801, armature 802, conductor 803, bank contact 365, wiper 313, armature 336 to grounded armature 305, relay 800 actuating. Armature 804 applies ground over conductor 805, armature 806, conductor 807 to line cut-off relay 808 to disassociate the signal drop D'8. The winding of slow-releasing relay 809 is legged from conductor 805 and actuates, disconnecting relay P'8 from the sleeve of springjack J8. Armature 810 applies ground to energize guard lamp 812. The slow-releasing relay 813 is disabled, due to the attraction of armature 814. Control relay 901 in selector H9 is disconnected due to the attraction of armature 815. Bank contact 366 is dead, so impulses from relay 301 will not be applied ahead. The talking conductors of line L2 will be continued from wipers 315 and 316 to bank contacts 367 and 368, conductors 371 and 372, conductors 818 and 819, line conductors 820 and 821, respectively, of toll line L8, to springjack J'8. The duplex impulse control conductors will be continued from wipers 317 and 318 to bank contacts 369 and 370, conductors 373 and 374, respectively. Conductor 373 leads to the winding of relay p'8, and open branches. Conductor 374 leads to an open contact of relay P'8 and to an inoperative, open branch 823. Due to the wiper 317 leading over conductor 221, armature 220, conductor 212 to the grounded attracted armature on relay P2', the relay p'8 is operatively energized, 50 which latter condition, in view of previous descriptions with reference to Fig. 2, will cause relay P8' to attract its armature to the right-hand contact, thus applying ground to the winding of relay p8'', the latter said relay actuating, but to no operative purpose at

this juncture further than to close a circuit path from spring 824 on springjack J'8, armature 825 to signal lamp 826. The operator at the switchboard containing springjack J'8 may recognize the glowing of lamp 826 as a 70 calling signal, or the calling operator may send a series of fourteen impulses from device D10, as before described, to apply the source G3 in bridge of line conductors 820 and 821, operative to the signal drop D8' as 75 a calling signal. In this connection it will be understood that well known devices, such as so-called "composite ringing equipment", may be interposed between the toll lines (as in L2 and L8, for example), and the signal 80 devices, springjacks and connections thereon. Under such condition the current traversing the signal devices is a relayed current which has been translated twice, the signaling current traversing the toll line being of a character non-effective to the superposed impulse paths, as well as not subject to being absorbed below an effective value by the choke coils employed in deriving the impulse path 85 from the toll line.

90 The called operator may respond by inserting the plug S8 into springjack J'8. In view of the fact plus battery is on the center point of the windings of relay P8, and that the center point of the winding of relay P8'' 95 has plus battery connected thereto (relay p8'' being operated), the armatures of said relays P8 and P8'' will move to their respective right-hand contacts. Slow-releasing relay 829 energizes in the path between the 100 windings of relays P8 and P8'' under conditions as set forth in relation to relay 210. The plug S8 and associated equipments is like plug S2 and associated equipments, and therefore may be considered as representing 105 a cord-pair like Fig. 10.

110 Upon relay P8'' operating, the relay p8' becomes operatively energized to change the polarity of the center point of the windings of relay P8', which in turn, causes the armature of relay P'8 to move to its right-hand contact to ground conductor 374, leading to bank contact 370, wiper 318, armature 349, conductor 231, winding of solenoid 230 to the winding of relay 207. Relay 207 thus actuates, to in turn cause relay P10 to actuate, extinguishing lamp 238'', in the manner before described, to index to the calling operator that the called operator responded, and has the plug S8 in the answering springjack. 115 The withdrawal of plug S8 will cause relays P8'' and P10 to restore, to reenergize lamp 238''.

120 Due to relay p8'' being actuated at the time plug S8 is inserted into springjack J'8, the center point of the windings of relay P8'' will have plus battery connected thereto, while the corresponding point of relay P8 is connected to plus battery, however, the condition of relay p8 as regards to the ap- 125

plication of either plus or minus battery to the center point of the windings of relay P8 will not be to any operative effect as regards relay P8. The relay P8 thus attracts its armature against the right-hand contact, responsive to relay $P8''$ solely, to disconnect the supervisory lamp 828. Should the calling operator remove the plug S10 first, the relay P8' will attract its armature to the left-hand contact (as drawn), deenergizing relay $P8''$ and thereby causing relay P8 to attract its armature to the left-hand contact (as drawn) to energize the lamp 828 as a clearing signal. It is thus clear that both the calling and answering operators have supervisory signal means controlled by the other independently, and that the control is over the single switch directive control conductor. The destroying of the established connection is under the control of the calling operator wherein selector C3 may be restored in the manner as has been described, and also in a manner as will appear, presently.

From the foregoing descriptions it is manifest that if after the connection is established from the springjack J2 to springjack J'8, the calling device D10 is further operated, the armatures of the polarized relays $P''2$, $P2'$ and $P8'$ (and other relays) will vibrate coincidentally; that of relay $P2'$ in a secondary circuit of relay $P''2$, and that of $P8'$ in a secondary circuit of relay $P2'$. That is to say, relay $P2'$ at the far end of toll line L2 and relay $P8'$ at the far end of toll line L8 will operate responsive to the impulses transmitted by the device D10, the latter said two relays occupying the same circuit relation with respect to the two said toll lines.

It will now be clear that if equipments to the right of section line A8 be removed from Fig. 8, and equipments like shown at the right of section line A2 in Fig. 2 (in view of Fig. 16), including equipments shown in cooperation therewith in Fig. 3, be substituted for the said displaced equipments in Fig. 8, it will be possible to annex a digit series after attaining connection with line L8 as described, whereby a selector like C3 will function to extend the connection from the far end of line L8, in the manner as described with relation to Figs. 24 and 25, for example. Similarly, both ends of toll line L8 may be equipped like the left-hand end thereof, including cooperative equipments in Fig. 9. In fact, a comprehensive automatic toll system will involve toll lines similarly equipped at both ends as shown at the right-hand end of line L2 (in view of Fig. 16) or the left-hand end of line L8, interchangeably. It would thus be possible to serially interlink as many toll line sections as desired; perhaps ten or more sections. After the second toll line is seized (as was L8) and the second digit series started from the calling

device D10, the reverting impulses from the vertical and the rotary magnets involved in the selector at the far end of the line L8 will be repeated by the various relays in a manner as set forth in connection with extinguishing and glowing lamp 238'', responsive to causing relay $P8'$ to actuate, and in view of the descriptions relating to the call to substation T15 wherein the selector C3 caused reverting impulses to be applied to the devices M10 and M'10.

Attention is directed to the fact that when plug S10 is inserted into the springjack J2, a duplex combination (generally similar to an indirect polar duplex repeater known in the telegraph art) exists between relays $P''2$ and $P'2$. Also, a duplex line combination (generally similar to a polar line duplex known in the telegraph art) exists between relays $P'2$ and $P2'$. Then, when selector C3 interlinks lines L2 and L8, as described, a duplex repeater (indirect type) combination is formed between the relay $P2'$ individual to toll line L2 and the relay $P'8$ individual to toll line L8. The said duplex combinations between the relays $P''2$ and $P2'$, and between relays $P'2$ and $P2'$ is permanent. The same as the latter holds with reference to relays $P8''$ and $P8'$ and between relays $P8'$ and $P'8$. However, the said repeater combination between relays $P2'$ and $P'8$ is temporarily formed out of relays forming the adjacent permanent duplex line combinations belonging to the two lines interlinked as a talking path. It will thus appear that the linking selector not only links a talking path between two successive talking line sections, but it also forms a duplex repeater combination intermediate of the duplex repeater combinations belonging permanently to the respective two talking line sections interlinked as a talking path by the said selector.

While the impulse paths have been shown as formed from corresponding talking lines it is manifest any other arrangement wherein there is a corresponding impulse path for a talking line section will suffice and be equivalent in operation.

It is clear from the foregoing that when lines L2 and L8 were described as interlinked as drawn, if the calling operator operated the calling device D10 after line L2 is seized, the armature of relay $P8'$ will vibrate responsive thereto. Also, upon plug S8 being inserted into springjack J'8 the said operation of the calling device D10 will cause relay P8 to also vibrate its armature. Likewise, operating calling device D8 (with key K8 operated) will cause relays $P'2$ and P10 to vibrate their armatures, the said reciprocal operation being independent of either operation. If it is assumed that a circuit closing telegrapher's key is introduced at TK10 and at TK8, either of the relays $P'2$ and P10 at

one end and P8' and P8 at the other may be used as sounders for telegraphing, after the lines have become directly linked through the agency of the calling device D10. Of course, the said telegraphers' keys may be introduced at alternative points so the key TK10 will cause relay p'2 to vibrate its armature and key TK8 will cause relay p8' to vibrate its armature. That is, the keys are introduced where indicated by TK2 and TK8' as auxiliary to or as displacing the other said keys. It will thus be clear that the system may be employed for linking telegraph lines directly wherein talking paths shown are not involved, or where they are involved. The commercial adaptation of the directive linking of telegraph lines through the agency of a calling device will be where messages are to be routed to points from a traffic center or where an idle telegrapher is sought in a traffic center, the selector at the switching terminal of the line serving to effect the connection as if a talking connection were to be established.

Fig. 21 shows a schematic layout of the ends of toll lines L2 and L8, illustrating the reciprocal linking possibilities wherein the selector H9 has a bank level into which toll line L2 is connected to the first set of bank contacts. That is to say, the relationship of selector H9 to line L2 (and other lines of its group) corresponding to the relationship specifically described with relation to selector C3 and line L8. In this connection it will be understood that the left-hand end of line L2 will have equipment like that shown connected to the left-hand end of line L8, and vice versa. Also, the equipments (though differing in circuit detail and functional object), at the adjacent ends of lines L2 and L8 may be interchangeably employed, the different circuits being shown as illustrative of possible modifications of the invention in meeting varied operative conditions at the different switching centers of a comprehensive system.

With further reference to Fig. 21, it will be understood that a plurality of paired links, the adjacent ends only of which are shown, may be linked, each linking responsive to a series of directive impulses from the calling operator's calling device, which impulses in turn cause indicative impulses to be reverted from the remotest selector through the intermediate line and all the repeater duplex combinations to the directive and selective indicators associated with the said calling device, to index the effective progression of the call. Having in mind the code-switches as C'3 and H'9 are associated with selectors C3 and H9, respectively, it will appear, presently, how any portion of the far end links of a train of links may be definitely directly disconnected by the calling operator, and moreover, the linking can be thereafter proceeded

with from the end of the remotest link retained, under directive control of the calling operator.

A fortunate property of duplex combinations, as have been referred to, is that where a duplex line combination is adjusted, or in the parlance of the telegraph art, is balanced to the line condition, such balanced combinations can be interchangeably interlinked to repeat from one duplex combination or section to another, without further adjustment with reference to the new combination formed. So, should a line section become faulty, to a degree, which may, however, be overcome by adjustment of its permanently associated duplex equipments, the said condition of the line will not affect adjustments of cooperating duplex combinations which may be temporarily cooperated. This property lends itself to faster impulse transmission between circuit links and to simplified adjustments, since it is only necessary to see that permanently related duplex combinations are in proper balance, without reference to other combinations which may cooperate. The employment of duplex impulse links admits of linking a larger number of sections into a circuit train and still conserve rapid control, than is possible under commercial operative conditions wherein the so-called simplex or "Morse" method is employed. Again, a salient advantage gained through the duplex method is the facility thereof which admits of returning supervisory and other signals, without interfering with out-going impulsing conveyed over the same, single conductor path.

In this connection it will be understood that while the toll lines are shown as terminating in an individual springjack, in order to simplify the disclosure, it is manifest that a plurality of springjacks may be multiply related as are the individual ones shown, but where equivalent auxiliary springs are operated by relays controlled in local circuits of the groups of multiplied springjacks. Thus, inserting a switching plug into any springjack of a said group causes the equivalent circuit change with reference to all springjacks as contemplated in the individual springjacks shown.

Before detailing a call from springjack J'8 to substation T15, the calling number of which is "784111", attention is directed to the fact that selector H9 has certain of its bank contacts in correspondence with the bank contacts accessible to selector C3. That is to say, the selectors C3 and H9 belong to a general group having common access to the same leading-out lines or trunks. The circuits in selectors C3 and H9 and code-switches C'3 and H'9 differ, and also have different functions to a degree. This is occasioned because of special conditions as-

sumed to exist with respect to lines L2 and L8.

It will be assumed that a plug as S10 is inserted into springjack J'8, the calling operator having caused selector C3 to disconnect from line L8 by withdrawing the switching plug. The armature of relay P8'' will attract to the right-hand contact, causing relay P8' to actuate and the armature of relay P'8 to attract against the right-hand contact, as when plug S8 was inserted in springjack J'8 in responding to a call. A circuit can now be traced from grounded armature on relay P'8, armature 830, winding of slow-releasing relay 813, armature 814 to grounded battery, the relay 813 actuating to apply ground from its upper armature, conductor 831, armature 810 to guard lamp 812. Conductor 823 also leads through armatures 832 and 815, conductor 833 to the winding of relay 901, the latter said relay actuating. The lower armature of relay 813 applied to make-before-break spring 801, disconnects the winding of relay 800 and applies ground through armature 802 to conductor 803, bank contact 365 to guard the line L8 against intrusion by selector C3 and other accessible selectors of its general group. Relay 902 will acuate in a local circuit of relay 901, its armature 903 applying ground to conductor 904.

Upon the calling operator sending impulses corresponding to digit "7", the shaft carrying wipers 905 to 911 will be stepped up so the said wipers will be in alignment with the seventh level of bank contacts and there rotate-in and seize the first idle set of bank contacts which will be assumed to be the first set, 913 to 919, corresponding to selector D4. The detailed functioning of selector H9 in the said seizure will be omitted since the elements thereof concerned correspond to those of selector C3 (and will therefore be clear), the bank contacts 329 to 334 being in multiple with bank contacts 914 to 919, respectively. Suffice it to state, the talking conductors 820 and 821 lead over conductors 818 and 819 through armatures 921 and 922, 923 and 924, wipers 908 and 909, bank contacts 916 and 917, conductors 340 and 341 to armatures 402 and 401 in selector D4, respectively. The further extension of the call through selectors D4, E13, F14 and connector G15 to the called line leading to substation T15 will be as before described with relation to the call from springjack J2 to said T15, having in mind the alternative bank levels, seven and eight, of selector D4, leading to selector E13.

The code-switch H'9, so far as the first six relays thereof, counting from the left, and the wipers and cooperating bank contacts are concerned, correspond generally with similarly located equipments as drawn in code-switch C'3, and likewise, have similar objects.

However, the code-switch H'9 has additional functions involved in the two right-hand relays thereof which will be discussed, presently.

Each line switching center at which toll lines terminate in linking switches will be known by a numerical designation, as for example, the line switching center into which lines L2 and L8 terminate in selectors C3 and H9, respectively, and at which toll line L terminates in selector A, as will appear, presently, is designated as number "357". All co-operating switches as selectors D4 and J5 (which will be further discussed, presently), E13, F14 and connector G15 are located contiguous to the said switching center "357". The far ends of the toll lines L2 and L8, for example, lead to similar line switching centers from which lead still other toll lines (not shown, though indicated in Fig. 22), which terminate at line switching centers referred to with respect to the discussion with reference to Fig. 21. Each of these switching centers will, of course, have a specific numerical designation. Further, the code-switches companion to the line selectors will be connected in a specific manner to correspond to the line switching center numerical designation. For example, the lower windings of relays 925, 926 and 927 correspond, respectively, to the third, fifth and seventh set of bank contacts cooperative with wipers 929 and 930 of code-switch H'9.

It will thus be manifest that where a call has been directly progressed through a plurality of line switching centers, as referred to in connection with the discussion of Fig. 21 (in view of Fig. 22), wherein the latter said figure is representative of the equipments at each of said switching centers in the train, the respective code-switches, companion to the in-coming line selector, will be specifically effectively responsive in accordance with the numerical designation of the concerned switching center. For example, the code-switch companion to the in-coming selector (like C3 or H9) at the far end of line L8, in a call progressed from springjack J2 through selector C3 to line L8, will be effectively responsive to a different digit combination than "3-5-7". The latter said code-switch may be assumed to be effectively responsive to digits "3-5-8", in lieu of "3-5-7", or any other combination of digits, or a single digit, or in fact, variously spaced or durated impulses. The code-switches will be differently responsive depending upon an index series prefixed to the digits comprising the line switching center numerical designation, the index series determining the operative function to be effectuated by the suffixed digit train pertinent to the switching center at which the effectuation is to take place.

It has been described how the code-

switches become operative to all directive impulses sent by the calling operator after the selector companion thereto seizes, though it is not essential that the said seizure take place. By attaching conductor 934 directly to armature 933, in lieu of through a contact engaged only upon the attraction of the latter said armature, the code-switch H'9 will function responsive to the initial deactivation of relay 901 when the vertical magnet V9 is operated. Under certain conditions, the latter may be the preferred method of connection.

It being clear that all code-switches, companion to all line terminating selectors in a connection coincidentally function in accordance with all series of impulses transmitted, it will appear that if impulses pertinent to any specific switching center be transmitted, code-switches at other switching centers will not be functionally effective therefrom.

Before detailing certain operative features, relating to the code-switches, it will be stated that a series of eleven impulses (referred to herein as an index series) will cause the remotest line-terminating selector to restore, if it is in seized relation with a local selector adapted to complete a connection to an exchange substation line, or where such substation line is actually linked. The seventh level of selector C3 meets this condition in descriptions which have been set forth. Obviously, this would not occur at intermediate toll line switching centers, because the said seventh level is reserved for local exchange switching. The uses of the various levels would preferably correspond at all switching centers for the sake of uniformity in operation, as otherwise all the various details of each switching center must be known by operators.

An index series of twelve impulses will cause all line-terminating code-switches companion to the selectors of an extended call to prepare or set-up a condition in each of the said code-switches looking towards restoring its companion selector. If the latter said series of twelve impulses is followed by a digit series corresponding to the first digit of the numerical designation of any switching center concerned, (regardless of what level the companion selector is in relation with), the said selector will be further prepared to restore. Should the series of twelve impulses be followed by a digit series which does not correspond to the first digit in the numerical designation of the concerned switching center, the set-up preparatory condition referred to will be effaced. Thus, all concerned code-switches will coincidentally function to set-up a like condition, responsive to the index series of twelve impulses. However, upon sending the second (the first digit) series, all concerned code-switches will

function to efface the latter said set-up condition, excepting the code-switch or switches located at the switching center or centers wherein the latter said (digit) series is the first of its numerical designation. Of course, if the latter said (digit) series is not pertinent to any concerned switching center, all the concerned code-switches will operate to efface the said first set-up condition. The latter would occur, for example, if after transmitting the index series of twelve impulses, the operator decides to institute some other directive function at any concerned switching center, or perhaps to further extend the call.

It will be understood that where the first digit series sent is pertinent to any code-switch or switches concerned there will be a further set-up condition effectuated in the latter said switch or switches looking further toward restoring its companion selector or selectors. When the second digit (following the index series) is sent pertinent to any code-switch or switches, there will be a still further set-up condition effectuated in the latter said switch or switches looking toward the said restoration of the so-far pertinent selector or selectors. Any code-switch to which the last said digit series is not pertinent will be caused to efface the condition set-up. The same will apply when the third digit is sent, wherein all code-switches excepting the one pertinent to the switching center numerically designated by digits corresponding to the three sent will have been caused to efface any set-up condition enduring after the second digit following the index series. The said pertinent code-switch will cause the release magnet of the selector companion thereto to operate by way of restoring the selector and incidentally effacing the set-up condition of the code-switch. It will appear, presently, that though the code-switches concerned will all operate responsive to every digit sent, the functional effectiveness therefrom will depend solely upon predetermined successive operation, which latter refer to the index series and also the numerical designations of switching centers.

A series of thirteen impulses will cause all code-switches concerned (as H'9) to prepare or set-up a condition therein looking towards signaling the wirechief (or other attendant or operator) at the switching center "357". The said wirechief will be signaled only when the impulses constituting the latter said three digits in the given order have been sent following the sending of the index series. If any digit or series is sent other than the given digit order, any set-up condition ensuing will be thereby effaced. Other code-switches (as C'3 and A') show the thirteenth bank position as dead in order to not unduly involve the drawings and descrip-

tions, though it will be manifest the present described function relating to the calling of the wirechief may be readily introduced therein, employing the circuit devices shown in H'9.

5 A series of fourteen impulses will cause the codeswitch or switches concerned (as C'3, H'9 and A') to forthwith apply ringing current to the next successive section linked. In 10 commercial operation, this function will ordinarily be employed when but one code-switch is concerned and where it is desired to apply signaling current to a connected line, as for example, when selector H9 was described as having seized line L8. Under this 15 condition ringing current from source G9 will be applied by slow-releasing relay 932 (corresponding to relay 359 in code-switch C'3), effective to the signal drop D8', in the 20 manner as described wherein the source G3 was applied through the wipers 315—316 of selector C3, responsive to the sending of a series of fourteen impulses, simply.

A series of fifteen impulses will cause all 25 code-switches concerned (as H'9) to prepare or set-up a condition therein looking towards applying ringing current to the next successive section linked. The said application of ringing current will not be effectuated unless 30 digits corresponding to the numerical designation of the switching center ("357", where said H'9 is located) are annexed in the given order. Any series sent, not conforming to the said given order, will operate to efface the 35 set-up condition, in the manner as has been set forth with relation to the directive control wherein twelve impulses constituted the index series.

A series of sixteen impulses will cause all 40 code-switches (as A') to prepare or set-up condition therein looking towards introducing a speech repeating equipment (or alternative repeating coil, for example), into the talking path. The said introduction will not 45 be effectuated unless digits corresponding to the numerical designation of the switching center ("357", where said A' is located) are annexed in the given order. Any series sent not conforming to the said given order will 50 operate to efface the set-up condition, in the manner as has been set forth with relation to the directive control wherein twelve impulses constituted the index series. After the said 55 amplifying (or alternative) equipment has been directly introduced, it may be directly excluded, by the same directive operations as were used to introduce it. That is, it will be introduced at the switching center "357" responsive to sending the index series of 60 sixteen impulses, followed by impulses corresponding to digits "3—5—7", and it will be excluded upon like directive operations being again effectuated. It will thus appear, presently, that an operator is enabled to interlink a plurality of line sections and there

after directly introduce a speech amplifying repeater equipment at any intermediate switching center desired, which of course, may be near one end, in the middle, or other suitable point, depending upon the transmission properties of the various sections. Further, one or more additional speech amplifiers may be thereafter introduced where desired, and any or all may be excluded at will. It will also appear that the said contemplated 75 introductions and exclusions of the speech amplifying equipments may be made as the call is progressed, if desired.

In the drawings, code switches have been shown associated with toll line terminating 80 selectors only, but it will be manifest that any local selectors shown or contemplated may have a code-switch introduced auxiliary thereto, and employed in the manner disclosed with relation to the toll lines, by way 85 of example.

The general operative objects of the code-switches having been set forth, it will now be assumed that the circuits are as when the call was described as extended from springjack 90 J'8 through the selector H9 to the local line leading to substation T15, and that the calling operator now desires to gain the attention of the wirechief at switching center 95 "357" without destroying the connection set-up. The thirteenth finger-hole of the calling device D10 will be drawn to the stop and released, causing a corresponding series of impulses to be sent effective to relay 901 whereby the armature 975 will correspondingly apply ground impulses through armature 933, conductor 934, series winding of slow-releasing relay 935 to the stepping magnet M9, operative to rotating the wipers 929—930 into engagement with the thirteenth set of 100 bank contacts. The armature 936 on relay 935 will sustain over the impulse lapses, but will retract following the last one sent, whereupon a circuit path can be traced from the latter said armature, conductor 937, armature 938 on release magnet Re9', make-before-break spring 939 on relay 940, wiper 929, its engaged bank contact to the winding of relay 941, the latter said relay actuating and locking through its armature 942; common conductor 943, armature 944 on slow-releasing relay 945, off-normal springs of set ON9 (which operated incidental to the off-normal movement of the shaft of selector 110 H9), to grounded conductor 904. The off-normal spring set ON9' is adjusted to operate upon the first off-normal movement of the wipers 929—930, so ground from armature 936 is applied to release magnet Re9', operative to restore the wipers 929—930, the armature 938 disconnecting grounded armature 936 from spring 939 before the wipers retract, so as to not affect passed-over bank contacts. The armature 938 does not attract 115 from its resting contact until just before the 120 125 130

wipers retract, to insure proper energization of relay 941. At the time armature 942 attracted it applied ground from conductor 943 to the winding of relay 940, causing the latter said relay to actuate and lock to conductor 943 for the purpose of substituting wiper 930 for 929 in relation to spring 939, wiper 929 being now free in lieu of wiper 930. The object of the latter function will 5 appear, presently. The selector H9 being at switching center "357", the digit "3" will be next sent, causing the wipers 929-930 to rotate into engagement with the third set of bank contacts, following which ground will 10 be applied to wiper 930, and the release magnet Re9' will operate to again restore the wipers. The ground applied through spring 939 and wiper 930 will be applied over conductor 946 to the lower winding of relay 925, 15 causing it to actuate and its upper winding to lock through its upper armature to conductor 943. Conductor 947, which attaches to the fifth bank contact engageable to wiper 930 is now continued through make-before-break 20 spring 948, armature 949 to the lower winding of relay 926. The wipers 929-930 will be restored as before. If the next digit sent is "5" the conductor 947 will be caused 25 to become grounded as described with relation to conductor 946, relay 926 actuating and its upper winding locking to conductor 943. Conductor 950, which attaches to the seventh bank contact engageable to wiper 930 is now 30 continued through make-before-break spring 951, armature 952 to the lower winding of slow-releasing relay 927. The wipers 929-930 will be restored as before. 35

The three digits "3-5-7" pertinent to the switching center at which code-switch H'9 is located having been sent, and relays 40 941, 940, 925, 926 and 927 caused to actuate and lock in the given order, a circuit can now be traced from grounded armature 953 on relay 927, armatures 954, 955, conductor 45 956 to the winding of relay 957, the latter said relay actuating. Ground from armature 953, armatures 954, 955, conductor 956 will be applied through lower armature of relay 927, conductor 958 to the winding of relay 50 945, operative to disconnect the ground from conductor 943 to unlock the said locked relays and thereby efface the set-up condition in the code-switch. Returning to actuated relay 957, a locking ground for same exists 55 through its armature 960, auxiliary contact 961 of springjack J9 to grounded conductor 904, the calling lamp 962 will be energized through lower armature of relay 957. The wirechief will respond by inserting an 60 answering plug, such as a in Fig. 1, into springjack J9, incidentally unlocking relay 957 and extinguishing lamp 962. Of course, the lamp 962 may be installed in view of the operator's supervisory springjack J8 so that 65 the said operator may recognize the glowing

of said lamp 962 as a special calling signal auxiliary to line drop D'8, which latter drop is responsive to ringing current applied in bridge of line conductors 820-821 from ringing key R10. Under the latter condition, the 70 calling operator can selectively call-in the operator at springjack J8, located at switching center "357" after gaining the response of the party at substation T15, or at any other stage of the call. However, the usual procedure (in view of the connection from selector H9 being a local one), would be to send an index series of eleven impulses, causing wiper 929 to apply ground through the eleventh cooperative bank contact, wiper 80 905, bank contact 913 to the winding of slow-releasing relay 966, effective to apply ground from armature 967, off-normal springs to the release magnet Re9, thus disconnecting the extension through selector D4, and enabling the calling operator to signal the operator at springjack J8 by operating signal drop D'8 as before described, as if no directive calling 85 through selector H9 had taken place.

Going back to the condition wherein the 90 index series of thirteen impulses was sent, causing relays 941 and 940 to actuate and lock, it will appear that the only bank contact position the wipers 929-930 can stop upon, whereat wiper 930 will not apply 95 ground to conductor 958 effective to relay 945, wherein armature 944 will attract to open the described locking ground for locked relays 941 and 940, will be the third set of bank contacts, whereat relay 925 will be caused to 100 actuate and lock as set forth.

In this connection attention is directed to the preferred method of assigning switching center designation numbers, wherein the numerical values of the digits of the successive numerical orders progress. That is, say there are three digits in the switching center designation number, as in the present exemplified system. A digit will not occur more than once in the number and the second digit 105 will, preferably have a higher value than the first and the third a higher value than the second. This will insure that the wipers will not stop twice on the same set of bank contacts when the three digits are sent, following the index series. 110

Referring to the condition of the circuits following the sending of digit "3" last described, it will be noted that should digit "3" be again sent before relay 925 has been unlocked, it will be to no effect so far as further setting-up or effacing an existing set-up condition in the code-switch H'9. Any digit other than "3" and "5" sent now will destroy 115 the set-up condition ensuing, and the said digit "5" will cause a further set-up condition, as set forth. After digits "3" and "5" have been sent, following the sending of the index series, any digit other than "3", "5" and "7" sent will destroy the set-up condition ensuing, 120 125 130

and the said digit "5" will cause a further set-up condition as set forth.

Should the digit "5" have been sent first, following the said index series, ground will be applied from wiper 930, conductor 947, spring 948, conductor 958 to the winding of relay 945, the armature 944 opening the locking ground for relays 941 and 940 to efface the set-up condition.

10. It is preferred to omit the assignment of some one digit in switching center designations, digit "9" for example. Then, should a calling operator who has sent an index series, and perhaps one or two of the digits 15 of a switching center designation, decide to efface the set-up condition, the said digit "9" will be sent which will cause relay 945 to actuate in the manner described, unlocking any relays locked to conductor 943. Of course, any other digit not pertinent to the next numerical order digit of any partly set-up code-switch concerned in the call may be sent in lieu of "9".

It has been set forth how the selector H9 can be restored by sending a series of eleven impulses simply, due to wiper 905 being in engagement with bank contact 913. However, due to the wiper 930 becoming disconnected, and wiper 929 connected in lieu thereof consequent to a series of twelve impulses being sent, should a series of eleven impulses be sent while relay 940 is actuated it will efface the set-up condition in code-switch H'9 in lieu of causing the application of ground to wiper 905 to cause the restoration of selector H9.

- To apply ringing current from source G9 through the agency of relay 932 as referred to, by sending fourteen impulses, ground 40 from armature 936 is applied through wiper 929 to the winding of relay 932, the wiper 929 retracting forthwith. The application of signaling current from source G9 wherein the selector H9 is the remotest line selector in a train of line sections as contemplated with reference to Figs. 21 and 22 is as follows, having in mind that companion to each said line selector there is a code-switch: Upon the calling operator sending 45 the index series of fifteen impulses, all code-switches including H'9 will cause their respective pairs of wipers, corresponding to 929-930 to rotate and engage the fifteenth set of bank contacts, whereat all the wipers 50 corresponding to 929 will apply ground to the respectively engaged bank contacts (leading to the winding of the relay corresponding to 968) upon the respective relays corresponding to 935 deactuating at the termination 55 of the said series.

It will be assumed, for example, there are five toll line sections of which the calling section is similar to line L8, including selector H9 and code-switch H'9. However, 60 to promote convenience of description, the

calling end will be assumed as the portion of line L8 to the right of section line A8, while the said equipments to the left of section line A8 are assumed to be identically similar to that shown in the drawings as 70 said H9 and H'9. All other of the five line links are assumed to have equipments at each end thereof identically similar to that shown to the left of section line A8, including said H9 and H'9. However, the remotest said line link is to be assumed to terminate in the portion of line L8 to the left of section line A8, including said H9 and H'9. The selector H9 is further assumed to be in seized relation with the first set of bank 75 contacts of the seventh level, from whence the connection is extended through selectors D4, E13 and F14 and connector G15 to substation T15, in the manner as has been described, the party at substation T15 having 80 replaced the receiver. Fig. 22 shows a diagrammatic layout of the latter said assumed connection, the calling line being designated "Sec. 1" and the fifth line link being designated "Sec. 5", etc. The selectors and their 85 respective companion code-switches are correspondingly designated. The latter selectors and code-switches having a prime added to the designating numerals, represent the idle equipments on the near end of a seized 90 line section. Assumed switching center numerical designations corresponding to the various code-switches are placed below the said code-switch designations, it being noted that the line L8, is now shown as terminating 95 at switching center "678" and that selector H9 and its companion code-switch H'9 is now shown as at switching center "357" 100 as heretofore.

Before proceeding with the descriptions, it 105 will be manifest that by sending fourteen impulses in lieu of fifteen, each code-switch shown in Fig. 22 will cause ringing current to be applied to its successive line section. Due to there being a plurality of line sections, this is not desirable in the present instance, though it will produce the same effect so far as the applying of source G9 to 110 wipers 908-909 is concerned.

Assuming that a series of fifteen impulses 115 has been sent over the train indicated in Fig. 22, a set-up condition exists in code-switches H'2, H'3, H'4, H'5 and H'9 whereby relays therein corresponding to relays 968 and 940 will be actuated and locked to conductors corresponding to conductor 943, and also, the wipers corresponding to 929-930 will have been caused to restore in the manner as has been described. Upon sending the first digit "3", the said code-switches will coincidently 120 function to advance their wipers to the third set of bank contacts and cause ground to be applied through wipers corresponding to wiper 930, the wipers corresponding to wiper 929 having been freed consequent to the actua- 125 130

tion of the relays corresponding to relay 968. The following takes place in the code switches: In code-switch H'2 the relay corresponding to relay 945 is caused to actuate to unlock the stated locked relays and restore the said code-switch to normal condition. The same occurs in code-switches H'3 and H'4. However, in code-switch H'5 the conductor corresponding to conductor 946 is 5 grounded, so the relay corresponding to relay 925 is actuated and locked, preparing the relay corresponding to relay 926 to be responsive to the next digit, provided it is "5". The same as the latter holds for selector H'9, be- 10 cause in both instances "3-5" are the first two digits of their respective switching center designations. Upon the sending of the second digit "5", code-switches H'2, H'3 and H'4 will each rotate their wipers to the fifth 15 set of bank contacts, where their wipers corresponding to wiper 929 (now live) will apply ground to actuate the respective relays corresponding to relay 945, but to no operative object, since the relays therein corresponding to relays 968 and 940 were unlocked consequent to the first digit "3". In code-switch H'9 the wiper 930 applies ground over conductor 947, armature 949 to the winding of relay 926, causing it to actuate and lock in 20 the manner described, and wherein the relay 927 is prepared to be responsive to the next digit, provided it is "7". The same as the latter holds in the functioning of code-switch H'5, only the next digit to be effective to its 25 (H'5) relay corresponding to relay 927 must be "6". Upon the sending of the third digit "7", code-switches H'2, H'3 and H'4 will each rotate their wipers to the seventh set of bank contacts, where their wipers corresponding to 30 40 wiper 929 will apply ground effective to the relays corresponding to relay 945, as when digit "5" was sent. However, when the wiper corresponding to wiper 930 in code-switch H'5 applies ground to its engaged bank contact it will be communicated to the relay corresponding to relay 945, effective to unlock the relays corresponding to relays 968, 941, 925 and 926, because the conductor corresponding to conductor 950 attaches to the 45 bank contact engageable to the wiper corresponding to wiper 930 at the sixth bank position, it being understood that the conductors corresponding to conductors 946, 947 and 950 correspond to the first, second and third digits 50 55 of the numerical designation of the concerned switching center, and that they are attached to bank contacts engageable to the wiper corresponding to wiper 930 at numerically corresponding bank positions with reference to 60 each said switching center. For example, in code-switch H'5 the conductor corresponding to conductor 950 is attached to the sixth bank contact engageable to wiper corresponding to wiper 930, and the seventh bank contact engageable to wiper corresponding to wiper 930

is attached to conductor corresponding to conductor 958. That is, the conductors corresponding to conductors 946, 947 and 950 are disposed with respect to the three digits (in numerical order) of the designation by attaching them to corresponding (in numerical position) bank contacts engageable to the wiper corresponding to wiper 930; all other bank contacts engageable to the latter referred-to wiper between the first and tenth, inclusive, being attached to the conductor corresponding to conductor 958. The conductor 950 in code-switch H'9 attaching to the bank contact of the seventh bank position engageable to wiper 930 causes relay 927 to actuate and lock in the manner described, its armature 953 applying ground through armature 954 to the winding of relay 932, effective to applying source G9 to wipers 908-909 for causing ringing current to be again applied to the line leading to substation T15. Incidental to the attraction of the lower armature of relay 932, ground is applied over conductor 958 to the winding of relay 945, effective to remove locking ground from the relays 968, 940, 925, 926 and 927, whereupon the code-switch H'9 is at normal.

With reference to the last foregoing descriptions, if it is assumed the operator, after sending the index series of fifteen impulses, decides to efface the so-far set-up condition, it may be done by sending digit "9" or any other series not pertinent to further setting-up an existing partly set-up condition in any code-switch concerned. This will cause the relays corresponding to relay 945 to actuate to restore any locked relays, whereupon the code-switches are at normal.

In this connection, it will be noted that if it is desired to change the numerical designation of the switching center, where code-switch H'9 is located, to "375", for example, the connections of conductors 947 and 950 will be transposed at the bank contacts accessible to wipers 929-930.

From the foregoing, it will be clear that had the calling operator desired to call-in the wirechief, in lieu of applying ringing current, the index series consisting of thirteen impulses would have been sent, in lieu of fifteen, followed by digits "3-5-7". Of course, in the latter instance should digits "2-3-6" have been sent the wirechief at the corresponding switching center would have been called-in, the code-switch H'9, and all other code-switches, having restored to normal incidental to the first digit "2" being sent.

It will be assumed the lines are linked from springjack J'8 to substation T15 as shown in Fig. 22, and it is desired to restore selector H9 so a new call can be linked therefrom. The index series of twelve impulses will be sent, whereupon the relays, corresponding to relay 940 in all code-switches, will ac-

100

105

110

115

120

125

130

tuate and lock as before set forth. The sending of digits "3-5-7" will cause relays 925, 926 and 927 to actuate (the other code-switches functioning as when said three digits 5 were described sent, following the index series of fifteen impulses), armature 953 applying ground through armatures 954, 955, off-normal springs to the release magnet Re9, the locking ground on conductor 943 becoming 10 opened when the shaft restores and operates the off-normal springs. The call can now be progressed, through selector H9 as if it had not been operated before. This latter function thus enables a plurality of calls to 15 be successively made in a local exchange contiguous to a switching center without destroying the connection intermediate of the operator and the terminating toll line selector. Of course, the connection can be extended to other than local exchange lines 20 from selector H9, if desired, when directive-ly released as last set forth.

Assume attention of the operator at switching center "357" is desired, after restoring 25 selector H9. The calling operator will send the index series of fourteen impulses, followed by digits "3-5-7", thereby causing code-switch H'5 to apply ringing current over line section "5" effective to signal drop 30 D'8 in the manner described. Relay 835 is disconnected, due to relay 813 becoming energized when armature of relay P'8 moved to its right-hand contact consequent to the calling plug being in spring-jack J'8. Con- 35 ductor 807 being now grounded, relay 808 will be actuated, so signal drop D'8 is disconnected. Signal drop D'8 will be disconnected consequent to selector H9 seizing, when calls are directive-ly extended, due to 40 armature 970 applying ground from conductor 904 to conductor 807. That is, if no plug is in springjack J8 the signal device D'8 is in bridge of line conductors of line section 5 (Fig. 22) until selector H9 seizes. 45 When the operator responds by inserting a switching plug as S10 into springjack J8, relay P'8 will attract its armature to the right-hand contact to energize relay p'8, and armature of relay P'8 will attract to the 50 right-hand contact to energize relay P'8'', causing relay P10 to attract its armature to the right-hand contact to extinguish lamp 238''. Relay 809 will not actuate responsive to inserting a plug into springjack J8 55 unless selector H9 has its wiper shaft off-normal to close the lower set of contacts (of set ON9) shown in Fig. 8. Relay 809 disables relay P'8. An established connection cannot have signals or directive impulses affected by the insertion of a switching plug into springjack J8, as armature of relay 809 will have line winding of relay P'8 disconnected.

In view of the foregoing, it will be mani- 60 fest that if the index series of twelve im-

pulses is sent by the calling operator at any time after the code switches are restored to normal, all code-switches (as indicated in Fig. 22) will have the same set-up condition introduced therein, preparatory to receiving the succeeding digit series. Also, if for example, digits "2-3-6" are next sent, the code-switch H'4 will cause the selector H4 to restore to disconnect the successive links and restore the code-switches H'3 and H'2 to 70 normal, so the built-up train extends only to selector H4. Any impulses sent now will be directive-ly operative to said selector H4, so the call can be re-progressed from section "3"; the operator at switching center "236" 75 can be called, or any other directive function initiated as described in connection with selector H9. In general, the calling operator is enabled to destroy any portion of a pro- 80 gress call by directive means, the portion of the train not so destroyed being as when the train remaining was initially established.

Assume that after restoring selector H9 as last described, the calling operator then desires to restore selector H4, as last de- 85 scribed. Due to selector H9 not being in seized relation with a successive link, the armature 933 will be retracted so that the code-switch H'9 will not be operative. However, when the said index series of twelve 90 impulses is sent, preparatory to restoring selector H4, the vertical magnet V9 will operate twelve times. This will cause the designated eleventh vertical off-normal springs to be operated by the shaft of selector H9, the 95 shaft being limited at the eleventh vertical position. After the twelfth impulse, has been sent the wipers will rotate-in on the eleventh level which is engageable to wiper 905 only, the said eleventh vertical off-normal springs 100 remaining operated. In view of wiper 906 not encountering ground, since it does not engage a bank contact, the selector H9 will seize, armature 933 being now attracted to 105 capacitate the code-switch H'9. Tone source T9 will be applied through spring 974 to talking conductor 819, audible to the calling operator, indicating that the selector H9 has been run into a "blind" level, thus insuring that it cannot falsely progress the train, should 110 digits be now sent to restore the selector H4 as described, for example. Should selector H4 be now restored, relay 901 will deenergize, causing a circuit to be closed from armature 975, armatures 975, 933, 976, off-normal 115 springs to the release magnet Re9, operative to restoring the shaft of selector H9.

In this connection, attention is directed to tone sources T9, T9' and T9'' which are distinctive to index the switching center numerical designation, or otherwise. The purpose of source T9'' has been referred to generally. The source T9' applied through off-normal 120 springs of set ON9 is audible to the calling 125

operator when the line section (5) leading to selector H9 is seized. It will thus appear that the calling operator will at all times know what switching center is reached and also

5 know when the last terminating toll line selector is at normal; has rotated over all bank contacts of a level found busy, and when a said last selector has rotated-in on the "blind" level¹, so further directive operations may be

10 governed accordingly.

In case selector H9 has been run into the "blind" level and it is then decided to restore the said selector to normal so it can be employed to progress the call, a series of eleven

15 impulses will be sent which will cause wiper 929 to apply ground to wiper 905, bank contact 978 to the winding of relay 966, causing armature 967 to apply ground through off-normal springs to the release magnet Re9 to

20 restore the selector H9 to normal, the tone source T'9 being incidentally applied through the upper armature of relay 966 to conductor 819, audible to the calling operator, to confirm the functioning, whereupon tone from

25 source T9' will become audible. The latter tone source can only be applied when armature 979 is attracted, so under the condition of line section "5" being idle, no tone exists on conductor 819.

30 Withdrawing plug S10 will cause all relays corresponding to relay P'8 to restore to normal. This will cause relays corresponding to relays 901 and 902 to deactuate and restore the respective containing selectors.

35 It will be clear from previous descriptions relating to reverting impulses, that the latter said impulses sent from the vertical and rotary magnets of the selectors and the connector represented in Fig. 22 will be effective

40 to the indicators M10 and M'10 as calls are progressed through the said selectors, the said reverted impulses being repeated towards the calling end at each switching center; this also applying to supervisory control impulses.

45 By introducing Fig. 12 where indicated, it will be clear that under the condition of relay 809 being actuated for the objects set forth, the springjack J8 will have its tip and ring springs also disconnected.

In this connection it will be noted that if a switching plug as S10 is inserted into springjack J8 in the circuit disposition shown in Figs. 8 and 9, the signal drop D'8 will be disconnected, and relay 835 operatively energized. This will disconnect the windings of relays 809 and 800, and armature 802 will apply ground to bank contact 365 (and multiples) to guard the line L8 against seizure. If signaling current is applied from source G10 by key R10, effective to signal drop D8', and a response is obtained at springjack J8, relay P8'' will actuate as described. The relay P'8 will actuate result-

65 ant to the actuation of relay P8''. Ground

will be applied from the armature of relay P'8, armature 830 to the winding of relay 840. The polarity at the center point of the windings of relay P''8 being thus changed, relay P10 will operate to extinguish lamp 238''. Under the present condition relay P''8 will have its armature against its live contact, causing relay P'8 to be actuated, effective to causing relays P8', P8'' and P8 to be actuated. Withdrawing plug S10 first

70 will cause lamp 828 to glow, due to relay P8 restoring, and withdrawing plug S8 first will cause lamp 238'' to glow due to relay P10 restoring. That is, each operator has a supervisory lamp controlled by the other operator, and moreover, the said control is effected over a single intervening circuit path.

75 Attention is directed to auxiliary spring 824 on springjack J'8, a purpose of which is to apply ground to the artificial line of relay P8'', in order that no battery will be consumed normally by relay P8''. Contact point 842 indicates a contact controlled by a plug-switch so when the plug S8 is in the normal position the contact 842 will be open, thus disconnecting battery from the windings

80 of relay P8.

85 Referring to Figs. 23 and 26, an organization is shown wherein a toll line leading-out of the switching center at which selector C3 is located is reached through the interposed selector Q5. That is, the calling operator at springjack J2 is enabled to reach the toll line L8 directly from the ninth level of selector C3, or alternatively through the fourth level of said C3, the second level of selector D4 and the fourth level of selector Q5. From the last foregoing, it will appear that the calling operator at springjack J2 can send digit "9" simply, or can send digits "4-2-4" and in both cases attain connection with the line L8, if it is idle. As referred to before, the former method, employing one digit only, would be ordinarily chosen by the said calling operator if there are no intermediate toll

90 line sections between the far end of line L2 and line L8, as indicated in the drawings. The latter said method, wherein selector Q5 is introduced, would be ordinarily employed, should there be a plurality of toll links leading up to line L8 in the manner disclosed, with reference to Fig. 22. In the case of establishing the call through selector C3 directly, if the line L8 (or all lines of its group) is busy the wipers of said C3 will be caused to rotate to the eleventh rotary position. This will make it necessary to destroy the established set-up condition before the line L8 can be reached through the selector C3.

100 The latter can be done by withdrawing the calling switching plug from springjack J2 or by sending the index series of twelve impulses, followed by digits "3-5-7", as has been explained, will cause selector C3 to restore. However, it will appear, that the call-

105

110

115

120

125

130

ing operator under the condition has no way of knowing when the line L2 has become idle so as to time the re-calling operation in proper accord therewith, nor has the calling operator any facility for being apprised if any, or how many, other operators are similarly awaiting the idleness of line L8. Moreover, there is no assurance that a last calling operator may not forthwith re-call and gain connection ahead of other waiting operators. Where one toll line only is concerned, these recited operative limitations may not be of great consequence, particularly at certain hours when traffic is very light. Where there are a plurality of toll line links concerned leading-up to selectors as C3, at a heavy traffic period, perhaps, indeterminate delays may occur which will mean holding toll lines out of remunerative service, and will charge operators with more watchfulness.

The selector Q5 (and others of its group, of course) have the function of pre-testing a line or group of lines consequent upon the group or level being selected. If there is an idle line in the group it will (self initiated) selectively hunt for and seize (the first one) it. If there is no idle line the selector will not test, but will attain a set-up condition causing a specific tone to be projected audible to the calling operator to index the said condition, and also in what order the selector will be enabled to thereafter selectively function (self initiated) with respect to other selectors similarly waiting. The said order will correspond to the order in which the respective calling operators operated their selectors of the group containing Q5 in an attempt to reach the line L8, or a line of the group containing it. This specific tone will change in accordance with a changed condition, as by selectors with a preferred order-of-access having selectively operated and seized, or by another operator destroying a preferred waiting call and thereby vacate a corresponding order-of-access position, or as will appear, presently, by an intermediate operator destroying or re-arranging the relative order-of-access of a concerned calling line or lines.

It will appear that notwithstanding the group of selectors containing Q5, which terminate waiting calling lines, are disabled against selectively functioning out of their first order-of-access, it will be possible for selectors having similar first orders-of-access at opposite ends of a toll line or group in difference switching centers to co-incidentally hunt for the same idle line. Ordinarily, the line connections to the bank contacts will be lapped, reciprocated, or at least not occupy the same numerical position in the opposite terminal bank levels, so calls in one direction may thus have preference because the first selector to seize will bar the one still hunting when the latter arrives at the concerned set

of bank contacts at a further position. This is assuming both toll line terminals have selectors with the same hunting speed. It will, of course, appear that under certain operative conditions it will be desirable to give calls in a given direction preference. The latter may only refer to certain lines of a group, due to transmission efficiency, perhaps. Again, certain lines of a group may be given preference from opposite switching centers, as shown in the level arrangement in Fig. 29, wherein line *a* is the first choice from switching center X and the sixth choice from switching center Y; line *b* is the second choice from Y and the fifth from X; line *c* is the third choice from both ends; line *d* is the fourth choice from both ends; line *e* is the fifth choice from X and the second choice from Y; line *f* is the sixth choice from X and the first choice from Y.

With particular reference to selector Q5, it will appear, presently, that there is a preliminary or pre-testing position attained at the first rotary step of the wipers 501 to 512 whereat a condition is caused to be set-up in the selector, dependent upon what bank contacts are found to constitute ground potential. For example, private wiper 507 receives ground at the first position under all conditions. This would cause the selector to automatically rotate-off in the manner described in relation to selector C3, seeking an idle bank position whereat it will not encounter ground potential. However, under the condition of there not being an idle trunk in the bank level attained, the bank contact (and its multiples) engaged by wiper 505 will also constitute ground from a chained condition which ensues if all trunks of the corresponding level are busy, as will appear, presently. A circuit can, under the condition of all trunks of the level being busy, be traced from the grounded wiper 505, series windings of slow-releasing relays 513, 514, 515, make-before-break spring 516, winding of relay 518 to grounded battery, the said relays actuating. A restraining spring prevents armature 546 from flexing spring 516 from its resting contact unless relay 518 is energized directly to ground, not having relay windings serially included. Due to relay 513 being actuated, ground is applied through armature 519 to wiper 506 and to its engaged bank contact, and multiples thereof. Due to relay 518 being actuated, the rotary magnet R5 is disabled against causing the wipers to hunt in the manner referred to and as will appear, presently.

The common tone source T5 is applied through common interrupters AT4, BT5 and CT5, respectively, to tone supply conductors. The three latter tone sources will thus impress current which may convey certain intelligence. For example, the said tones may be applied in periods of one, two and three short

5 durations, followed by a relatively long silence. Under the condition of the relays being as last assumed, tone source AT5 is applied through armature 520 to talking conductor 525 of the leading-in conductors 521 to 527, audible to the calling operator, as will appear, to index that upon a line in the concerned level becoming idle, the selector Q5, terminating the call extension, will forthwith hunt. This latter is because ground will then be removed from the bank contact engaged by wiper 505, causing relays 513 to 515 and 518 to deactivate to disconnect the tone source AT5, and to capacitate the rotary magnet R5.

10 Having in mind the wiper 506 becomes grounded if wiper 505 receives ground, if it is now assumed a selector like Q5 of the same group is caused to operate as Q5 did in seeking a line of the same level group, its wipers corresponding to 505, 506 (and 507) will receive ground from the first set of bank contacts. The present selector, not shown, but which for convenience will be referred to as U, will thus receive ground

15 through its wipers U505, U506 (and U507), the prefixed letter being introduced by way of simplifying the descriptions as relates to the selectors not shown. This method will be followed in designating elements of selectors V and W, also like Q5, and belonging to its group. That is, the group contains selectors Q5, U, V and W, and possibly others, which are assumed to be alike. These

20 selectors are toll trunking selectors for linking connections from toll line terminating selectors to toll lines. Of course, selectors, such as Q5 may be employed as toll line terminating selectors where its levels will reach all desired groups employed.

25 Having in mind the relay U513 is normal, when selector U rotates its wipers into engagement with the first set of bank contacts wherein both wipers U505 and U506 (also U507), receive ground, the relay U513 will be short-circuited by way of its upper armature, and therefore, only relays U514, U515, and U518 will actuate. The tone source AT5 will remain normally disconnected, so far as selector U is concerned, due to armature U520 being retracted. However, tone source BT5 will be applied through armatures U528, U529, U520 to conductor U525, audible to the calling operator, indexing that a selector has an order-of-access anticipating that of selector U, which latter selector terminates the last call. Due to armature U519 being retracted, and armature U530 being attracted, ground from make-before-break spring 531 will be applied through armatures U530, U532, U533, wiper U509 to its engaged bank contact, and multiples thereof. Due to relay U518 being actuated, the rotary magnet of selector U will be disabled as in Q5.

30 Assuming that selectors Q5 and U are in the waiting conditions last described, if it is now assumed that selector V is next caused to operate like Q5, the wipers V505, V506, (also V507), and V509 will encounter ground potential, short-circuiting relays V513 and V514, the relays V515 and V518 only, actuating. Under the condition, armatures V520 and V529 are retracted, and armature V534 is attracted. The tone sources AT5 and BT5 will be disconnected, so far as selector V is concerned, due to armatures V528 and V529 being retracted. However, tone source CT5 will be applied through armatures V535, V536, V534, V529, V520 to conductor U525, audible to the calling operator, indexing that two selectors have orders-of-access anticipating that of selector V. Due to armature V537 being attracted, and armatures V538 and V539 being retracted, ground from its make contact, will be applied through armatures V537, V538, V539, V540, V541, wiper V510 to its engaged bank contact, and multiples thereof. Due to relay V518 being actuated, the rotary magnet of selector V will be disabled, as in Q5.

35 Assume that selectors Q5, U and V are in the waiting conditions last described. If it is then assumed that selector W is next caused to operate like Q5, the wipers W505, W506, (also W507), W509 and W510 will encounter ground potential, short-circuiting relays W513, W514 and W515, the relay W518 only actuating. Under the condition, armature W542 is retracted and armature W543 is attracted, so that tone from source T5 is applied to conductor W525 as a final busy signal, indexing that three selectors have orders-of-access anticipating that of selector W; in fact, the latter said tone indicates that no order-of-access occurs to said W, there being as many waiting selectors as the exemplified system permits. Conductor W544 is grounded during the time selector W is seized, as will appear, presently, and this ground will be applied through armatures W545, W546, spring W516 to the winding of relay W518, locking the latter said relay until ground is removed from conductor W544. This is to maintain the tone from source T5 until the selector W5 is restored, regardless of the condition thereafter occurring to any of the bank contacts engaged by its wipers. Under the condition of relay W518 being fully energized, the make-before-break spring W516 disengages its resting contact, so that ground from conductor W544 cannot be communicated to any of wipers W505, W506, W509 and W510, which in the event the operator maintained the connection to selector W, would cause subsequently operating selectors (at the concerned bank level) to falsely receive ground on its wipers corresponding to wipers 505, 506, 509 and 510, (causing the final busy tone to be applied),

regardless of the fact regularly set-up order-of-access conditions did not then exist in calling selectors.

It is clear that while a final busy tone is applied through armature W543 the latter said tone is locked against disconnection, should a change of the state of the test wipers subsequently occur. This does not occur with respect to the order-of-access tone. For example, if when selector V is projecting tone from source CT5 wherein relays V515 and V518 are actuated and wipers V505, A506, (also V 507) V509 and V510 are grounded, the calling operator holding selector Q5 destroys the connection, the following change in selector U and V will take place. The bank contacts grounded by wiper 506 will not now receive ground, due to the restoration of selector Q5. Under the last condition the wiper U506 will not receive ground so the ground short-circuit will be removed from the upper terminal of the winding of relay U513, the ground having been maintained on the bank contacts engaged by the wipers 505, U505 and V505, applied by the chained condition to be discussed, presently. Relay U513 will actuate and apply ground to wiper U506 in lieu of U509 from spring 531. Ground being now removed from the bank contact engaged by wiper U509 (and multiples of the latter said bank contact), the ground short-circuit will be removed from the upper terminal of the winding of relay V514, so that the latter said relay will actuate, the relay V513 not actuating because wiper V506 will receive ground applied from wiper U506. It will be noted in this connection that due to the armature 519 engaging spring U531, before the resting contact of the latter said spring is disengaged, wiper U506 becomes grounded before wiper U509 becomes ungrounded. This is to prevent the short-circuit from being removed from relay V513 at the time the short-circuit is removed from relay V514 consequent to the ground being transferred from wiper U509 to wiper U506. Due to the actuation of relay V514, ground will be applied to wiper V509 from spring V531, armatures V530, V532 and V533. If the relay W518 is still locked on final busy, no change in said selector W will take place. Under the present condition relays U513, U514, U515 and U518 in selector U are actuated, so tone source AT5 is being applied through armature U520 to conductor U525 in lieu of tone source BT5 as existed before selector Q5 restored. In selector V, relays V514, V515 and V518 are actuated, so tone source BT5 is being applied through armatures V528, V527, V520 to conductor V525, in lieu of tone source CT5 as existed before selector Q5 restored. It is thus clear that the operator who heard tone from source BT5 now hears tone from source AT5, and the operator who heard tone from source CT5 now hears tone from source BT5.

Should the operator having the call extended to selector W have restored said selector W as set forth, and now initiates a new call in which the selector W is set upon the first (pre-testing) bank position of the concerned group of lines wherein its wipers W505, W506, W507, W509 encounter ground potential, its relays W515 and W518 will actuate, relays W513 and W514 being short-circuited, due to wiper W509 receiving ground. Under the condition, tone source CT5 will be applied through armatures W535, W536, W534, W529, W520 to conductor W525.

If the selector V is restored, the ground will be removed from the bank contacts grounded by wiper V509, so that relay W514 will actuate (relay W513 being short-circuited by ground from wiper U506) and cause tone from source BT5 to be applied to conductor W525 in lieu of from tone source CT5.

Attention is directed to Figs. 17, 18, 18A, 18B and 18C, showing details of the mechanical arrangement of selector Q5. The rotary release magnet RR5 causes the wipers to retract under the tension of the coil spring 801' in the generally well known manner. However, a stop-ridge 802' attached to the shaft is retained by the end of the arm 803', which prevents the wipers 501 to 512 from retracting beyond the first set of bank contacts described as used for pre-testing purposes. That is, if the wipers have rotated-in past the pre-testing position at any level, and the rotary release magnet RR5 is then caused to operate, the wipers will retract into engagement with the first set of bank contacts (as in Fig. 18B) and not past the latter said set (as in Fig. 18A). However, if the vertical release magnet VR5 operates, its arm 804' will cause the arm 803' to swing clear of the stop-ridge 802' on the drum 805' and close a local energizing circuit at contact spring set 806' to energize the rotary release magnet RR5. Under the latter condition the shaft will disengage the vertical dog, so when the wipers have retracted off the first set of bank contacts, it is free to restore to normal and disengage the pairs of springs of off-normal set ON5 and also, the pairs of springs RO5. It will thus be clear that operating the rotary release magnet RR5 accomplishes a partial rotary restoration only, while operating the vertical release magnet VR5, the arm 804' applied against arm 803', will cause a complete restoration of the shaft.

Again referring to Figs. 23 and 26, it will be assumed that a call is made from spring-jack J2 to springjack J6, the calling number of the latter being "420". The plug S10 is assumed into springjack J2. When the sending device D10 is operated in accordance with the digit "4" the selector C3 will function as when it was caused to function responsive to the sending of digit "7", only that its wipers

will now rotate-in at the fourth bank level, seizing selector D4 over the same conductors as before. The relationship of wipers 313 to 318 to bank contacts 376 to 381 first engaged 5 will be as when the latter said wipers engaged bank contacts 329 to 334, so if the selector D4 were busy the wiper 313 would receive ground potential and rotate-off as described. The wiper 312 will engage bank contact 375 10 in lieu of 328, so if ground is applied from the code-switch to wiper 312 the said ground will be communicated over conductor 383 to the winding of relay 455, for an object which will appear, presently, in lieu of to the winding of relay 361 to restore the shaft of selector C3 as before described. In the present instance the call is destined to a toll line L6 while in the former instance, when selector D4 was seized from the seventh level of selector C3, the call was destined to a local 15 exchange line to substation T15.

Upon sending the next digit "2", the selector D4 will function as it did when it was operated through the sending of digit "8", 20 the wipers rotating-in at the second level, the wipers 415 to 421 being related to bank contacts 458 to 464 as they were to bank contacts 424 to 430. Assuming also that the selector Q5 is idle, the selector D4 now seizes. 25 The circuits with relation to selectors C3 and D4 are as they were when digits "7-8" were sent, in lieu of the present digits "4-2". A circuit can now be traced from the winding of control relay 548, armature 549, conductor 353, bank contact 460, wiper 417, armature 405, conductor 355, bank contact 377, wiper 314, armature 352 to ground through attracted armature 351, relay 548 actuating. Slow-releasing relay 550 will operatively 30 energize in a local circuit of relay 548. Armature 551 will apply ground to conductor 544.

Consequent to sending the last digit "0", the vertical magnet V5 will operate ten times, 40 stepping the shaft carrying wipers 501 to 512 into alignment with the "0" level, it being energized from grounded armature 552, armature 553, series winding of slow-releasing relay 554, armature 555. The contact armature on the vertical magnet V5 will apply its ground ten times to conductor 556, armature 557, conductor 527, bank contact 381, wiper 318, armature 349, conductor 231, winding of solenoid 230 to the winding of relay 207, the relay 207 actuating ten times effective to correspondingly vibrating the armature of relay P10 to cause pointer 203" of indicator M10 to move over ten scale divisions in the manner before described. Consequent to the actuation of relay 554, its armature applies ground from conductor 544 through the winding of relay 558, armatures 559, 560 and 561 to grounded battery, the relay 558 actuating and sustaining until 55 armature of relay 554 retracts following the

last impulse to the vertical magnet. Due to the off-normal spring set ON5 operating consequent to the first off-normal movement of the shaft carrying wipers 501 to 512, a locking circuit path can be traced from the upper winding terminal of relay 558, off-normal springs, armature 562 to conductor 544. When armature on relay 554 retracts, the path from armature 559 to the upper terminal of the winding of relay 558 is shunted by the windings of the rotary magnet R5 and slow-releasing relay 563; in fact, the latter said windings are included between grounded battery source and grounded conductor 544, so the relay 563 and the rotary magnet R5 70 actuate. The rotary magnet R5 rotates the wipers 501 to 512 into engagement with the first set of bank contacts 564 to 575, respectively, it being noted that bank contacts 564 and 565, extend across the level either as solid bars, or as bank contacts tied in multiple in an equivalent arrangement, so the wipers 501 and 502 will be engaged with bank contacts 564 and 565, respectively, at all bank contact set positions at the "0" level. Of course, an 80 equivalent off-normal contact set would suffice for each level. The object of bars 564 and 565 will appear, presently. The wipers 501 and 502 engage bars similar to 564 and 565 at all levels. 85

The attraction of armature 559 disconnects the energizing current from relays 563 and 558, causing them to unlock. The upper terminal of the winding of switching relay 576 is grounded to conductor 544, and the lower winding terminal of relay 576 is applied to conductor 544 by way of armature 562 during the time the vertical magnet is operating and until the rotary magnet unlocks relay 558. When armature 562 retracts, as described, a circuit path can be traced from the permanent ground on bank contact 570, wiper 507, armatures 577 and 578 to the lower winding terminal of relay 576, maintaining relay 576 short-circuited. The ground traced to armature 578 is communicated through off-normal springs to the upper terminal of the winding of relay 558, energizing relays 558 and 563 and the rotary magnet R5, the armature 562 forming a direct path to conductor 544 independent of ground received from bank contact 570. The rotary magnet R5 will advance the wipers 501 to 512 to the second rotary position, where if wiper 507 receives ground from private bank contact 601, the wipers will be again advanced, the cycle of functioning continuing as long as wiper 507 receives ground. 100 105 110 115 120

It will appear that the first set of bank contacts of the various levels (as relates to wipers 505 to 512), are preliminary or pre-testing contacts and that the following sets (as relates to wipers 507 to 512) are trunk contact sets. It is clear that under the stated condition the wipers will not be enabled to 125 130

normally stop on the first bank position, due to the permanent ground on bank contact 570. It will, however, appear presently, how this condition is subject to modification, dependent upon a busy condition of all the trunks terminating in respective levels of bank contacts.

By referring to Figs. 6, 6A, 6D and 7 assembled as in Fig. 26, it will be noted that 10 bank contact 601 leads over conductor 602 to the winding of chain relay 701. The windings of chain relays 703 and 704 are similarly attached to bank contacts 603 and 604, respectively. In this connection, it will be 15 understood that bank contacts corresponding to 601, 603 and 604 in all corresponding levels of a group of selector banks are tied together, respectively. This also applies to the remaining bank contacts of the said tenth 20 or "0" level engageable to wiper 507, which are shown unconnected. The latter assumes the "0" level has a group of nine connected trunks. The same holds for corresponding bank contacts of the other levels of Fig. 6A. 25 It will appear, presently, that in the case of the fourth level there are but eight trunk positions due to the last being employed for a special use. The latter use may, of course, be applied to all levels. The wiring arrangement of the first (only) set of bank contacts 30 of the different selector banks of a group of selectors indicated by Q5, U, V and W in Fig. 23 is shown at the right of Fig. 5 and in the attached Fig. 6, indicated by Q', U', 35 V' and W'. In a commercial installation there would ordinarily be a larger plurality than the four selector banks indicated. The Fig. 17 shows the full set of bank contacts which cooperate with selector Q5 of Fig. 5 40 (and its companion selectors), but in order to simplify the disclosure, only the first, fourth, seventh and tenth levels shown in Fig. 17 are shown in Fig. 6A; these latter levels being the only ones assumed to have 45 trunks connected, in the description. Dead trunk positions will have their bank contacts adapted to be engaged by wiper 507 permanently grounded.

Assuming that wiper 507 does not encounter ground on bank contact 601, the relays 558 and 563 and the rotary magnet R5 will not function to advance the wipers therefrom. Under the condition of bank contact 601 not constituting ground potential the short-circuit to ground will not exist on the lower terminal of the winding of relay 576. On the other hand, grounded battery will be applied through armatures 561, 560, 559, winding of relay 558 (shunted by the windings of 50 the rotary magnet R5 and lower winding of relay 563 in series), off-normal springs, winding of relay 576 to grounded conductor 544, the relay 576 actuating but the relays 558, 563 (optional) and the rotary magnet R5 not 55 actuating due to the inclusion of the wind-

ing of relay 576 in the energizing path. The armature 578 will apply ground from conductor 544, wiper 507, bank contact 601 (and multiples), conductor 602 to the winding of relay 701, the latter said relay actuating.

It will be noted that consequent to the attraction of armature 549, the winding of relay 548 is disconnected from conductor 523 and applied through winding of relay 579 to conductor 522, leading to bank contact 459, wiper 416, armature 431 to grounded conductor 410. That is, regardless of impulses being applied over conductor 523 the relay 548 will not respond. The conductor 525 is applied through armatures 549, 580, wiper 508, bank contact 605, conductor 606, windings of repeating coil C6, line L6, windings of repeating coil C'6, conductor 607 to the winding of line relay 608. Armature 609 applies its ground over conductor 610, auxiliary springs of springjack J6 to lamp 611, the latter glowing as a calling signal. It is clear that the selectors of the well known Gill type represented by A6, B6 and C6 may be selectively operated by predetermined impulse series sent from the calling device D10, effective to glowing any or all lamps a6, b6, and c6. The latter lamps may be located at different operators' positions at which may be multiples of springjacks J6 and J6'. The calling operator is thus enabled to call a desired operator selectively. Moreover, the lamp glowing may indicate intelligence of any predetermined nature, such as the nature of the call or the origin of it, for example. The called operator will respond by inserting a common form of switching plug (or one like S'10) into springjack J6, whereupon the operators are in talking relation when their listening keys are operatively manipulated. The talking path will be as before traced from springjack J2 to wipers 418-419. It will continue through bank contacts 461-462, conductors 524-525, armatures 541-533, wipers 509-510, bank contacts 612-613, conductors 614-615 to the right-hand winding of repeating coil C6, and from the left-hand winding over line L6, coil C'6 to the tip and ring springs of said J6.

The connection can be destroyed by the calling operator removing the plug S10 or by sending the index series "12", followed by the digits "3-5-7" to cause the code-switch C'3 to restore the selector C3. The latter has in view there may be a plurality of toll line links intermediate of the selector C3 and the selector D4, linked in the general manner shown in Fig. 22, in view of the alternate linking means shown in Fig. 23, wherein the line selector may link directly or where two local selectors (as D4 and Q5) may be interposed between the in-coming line selector and the out-going line. If the plug S10 is removed or code-switch like C'3 is effectively operated, the selector D4 will restore as has

- been described. Relay 548 will deactivate, followed by relay 550, whereupon a circuit can be traced from grounded armature 552, armature 553, winding of relay 554, off-normal springs to the winding of the vertical release magnet VR5, effective to operating the latter said magnet and the rotary release magnet RR5 to restore the selector Q5. 5
- With further reference to the call over line 10 L6, should the second digit sent have been "1" in lieu of "2". The selector D4 would have functioned correspondingly, and in view of the multiple relation of the bank contacts 459—489, 460—490, 461—491, 462—492, 463—493, 464—494, engaged by wipers 416 to 421, the selector Q5 will be seized as before. However, in the last instance, wiper 415 engages bank contact 468 leading over conductor 521, winding of relay 581 to the 20 free contact 582 on relay 579. Thus, when relay 576 actuates, as will occur when the line L6 is seized upon the last (next) digit "0" being sent, the relay 579 will energize in series with the winding of relay 548, causing contact 582 to become grounded. A circuit path can now be traced from grounded contact 582, winding of relay 581, conductor 521, bank contact 468, wiper 415, to the winding of relay 471, the relays 581 and 471 actuating. 25
- 30 The traced path including the winding of relay 608 is now open at armature 580 so lamp 611 does not glow. However, due to the actuation of relay 471, a circuit path will be closed from winding of solenoid 472, armature 473 to grounded armature 474, the plunger-arm 475 being drawn upwardly. Ground from bar 476 is applied to contacts 477, 478 and 479 in code-order, but due to armature 480 being retracted there will be no operative effect 35 until contact 479 is reached, causing relay 481 to actuate and lock from its make-before-break spring, armatures 482, 483 to grounded conductor 410, the contact 479 being disconnected from the winding of relay 481. As 40 the plunger-arm 475 recedes, contacts 478 and 477 will become grounded in sequence, and this grounding will be communicated through armature 480 to the winding of ringing relay 484, causing said 484 to actuate two times to 45 apply ringing current source G4 to wipers 418—419 in bridge and over the traced path to tip and ring springs of springjack J6, anvils of said J6 to tip and ring springs of springjack J'6 and to bridged signal drop 50 D6. The operator at said J'6 will recognize the code of two rings as the call station code or as a code indexing the source of the call. That is, the frequency of vibrations effective to signal drop D6 (or a selectively responsive 55 one of a plurality) or the code of application will serve to index predetermined intelligence to the called operator. Due to the armature 474 being attracted because of the locked condition of relay 481, the solenoid winding 472 will not energize to apply further ringing 60
- current to said D6. However, if the calling operator will cause eleven open impulses to be transmitted from calling device D10, effective to the code-switch like C'3 wherein wiper corresponding to 347 will apply ground to wiper corresponding to 312 in the manner before described, the relay 455 will be caused to actuate to unlock relay 481. This will complete the energizing circuit for the winding of solenoid 472, to re-initiate the application of ringing current to the signal device D6, after which relay 481 will lock as before. It is thus manifest that the sending of eleven impulses causes the code-switch like C'3 to operate differently dependent upon whether the call is to a local line or a toll line. In the former case the toll line selector is caused to be released. Attention is directed to the fact that in the latter (toll) case, the called toll line has no directly controlled switching equipment at its far end, though of course, it may be so provided; controlled over conductor 607 which will correspond to conductor 654 in Fig. 1, and the conductors leading to the left from repeating coil C'6 correspond to conductors 651 and 652 in said Fig. 1. 70 75 80 85 90 95 100 105 110 115 120 125 130
- Assume that at the time the wipers rotate in at the "0" level all the trunks thereof are busy, and therefore, the chain relays thereof are actuated. Only three of the latter relays (701, 703 and 704) are shown. Of course, the trunk group occupying the "0" level may contain one only or nine (or more) trunks as a group. If there is only one trunk the armature of the chain relay (corresponding to relay 701) will be grounded. When the chain relays 701, 703 and 704 are actuated the chain ground is closed to conductor 705 leading to bank contact 568 and its multiples. Under the condition of wiper 505 now engaging bank contact 568, relays 513, 514, 515 and 518 will actuate to apply tone source AT5 audible to the calling operator and disable the rotary magnet R5, so that wipers cannot be advanced to test the trunks of the group, which are all busy. Upon any trunk of the "0" level group becoming idle, thereby opening the chain ground to conductor 705, the relays 513, 514, 515 and 518 will deenergize, relay 518 promptly deactuating so the selector Q5 will forthwith self-initiate its selective operation. Relays 513 to 515 will sustain for a brief period due to the slow-release characteristics. 110 115
- In this connection it will be understood the second rotary step off-normal spring set RO5 will operate when the wipers advance from the first (test) bank contact set, so ground will be applied through the latter said off-normal springs, contact armature on the rotary magnet R5, conductor 527 to operate the indicator M'10 in the manner as before described, which will thus indicate to the calling operator how many steps in from the first or pre-testing position the wipers are. 120 125 130

advanced before the selector Q5 seizes. In other words, the calling operator is apprised as to what particular trunk (toll line) has been seized. If, as will appear possible, the 5 idle trunk becomes seized from the opposite end thereof, or is converted manually by an operator, perhaps, before the wipers have had time to test and seize, the wipers will advance to the eleventh rotary position and 10 automatically release, the indicator M'10 showing the condition, if connected. The tone source 5T will apply tone to talking conductor 525, as well, in case the indicator M'10 is disconnected and the calling operator 15 is listening.

Having in mind previous descriptions with reference to selectors Q5, U, V and W, it will be clear that if all the said chain relays of the "0" level are actuated wherein conductor 705 is grounded, if selector Q5 is caused to rotate-in to the pre-testing position at the "0" level, the relays 513, 514, 515 and 518 will actuate to apply the order-of-access busy tone source AT5 and to ground the bank contacts multiplied with 569. If selector U now functions by way of rotating-in to the pre-testing position at the "0" level, its wipers U505 and U506 will receive ground from bank contacts U568 and U569 so its wiper U509 will apply ground to bank contact U572 and multiples thereof and to apply order-of-access busy tone source BT5. In view of the foregoing, it will be manifest how subsequently operated selectors which rotate-in to the pre-testing 35 position at the "0" level will function.

Having in mind further that bank contacts 564 and 565 (and bank contacts of all levels engageable to wipers 501 and 502) extend across the level, and the fact the spring set 40 RO5 operates incidental to the second rotary step, it will be assumed the chain ground becomes opened, due to one of the trunks becoming idle. Relays 513, 514, 515 and 518 will deenergize and relay 518 will deactivate first, followed by the other said relays, the selector Q5 starting its hunting operation forthwith upon the said relay 518 deactuating. However, it will be assumed the trunk which became idle, causing the said chain 50 ground to open, becomes again busy before the private test wiper 507 of selector Q5 has had time to test it after leaving its pre-testing bank contact 570. Under the latter condition, the wipers will rotate-off the private bank contacts and into the eleventh rotary position, unless, perchance, some other trunk 55 becomes idle before being tested.

The bank contacts of the various levels engageable to wipers 501 and 502, and which extend across the level, are tied to the respective pre-testing bank contacts engageable to wipers 505 and 506, which latter bank contacts concern the first rotary or pre-testing position only. That is, for example, if bank 60 contact 664 becomes grounded bank contact

568 and multiples attached to the chain ground conductor 705 will also be grounded. Likewise, grounding bank contact 665 will ground bank contact 569 and its multiples attached to conductor 706. It is thus clear, in 70 this connection, that the bank contacts 564 and 565, as well as corresponding bank contacts accessible to other selectors of the group, are in multiple relation with bank contacts 568 and 569 and their corresponding 75 multiplied bank contacts accessible to the said other selectors of the group.

Ground from conductor 544 applied through armature 583, off-normal spring 584 to wiper 502 is thus applied to falsely ground 80 the bank contact 569 and its multiples consequent to the first advancement of the wipers from the pre-testing position. This forestalls a lapse of ground occurring to the latter contacts after wiper 506 rotates-off bank contact 569, it being borne in mind that, due to the slow-releasing characteristic of relay 513, its armature 519 will not retract from grounded spring 531 until the off-normal spring set 85 RO5 has operated. That is to say, if selectors 90 Q5, U and V have the first, second and third orders-of-access, respectively, as exemplified in previous descriptions, and the chain ground on conductor 705 opens and selector 95 Q5 thereupon self-initiates its selective functioning, the selectors U and V will be falsely barred from advancing their respective orders-of-access while the selector Q5 is hunting. When the selector Q5 seizes, by virtue 100 of relay 576 actuating consequent to wiper 507 encountering an idle trunk test contact, the armature 583 opens the ground applied from the chain relays through wiper 502. Ground will be applied to chain conductor 105 705 and to wipers U505 and V505 consequent to the seizure of the idle trunk of the group, before relays U518 and V518 have had time 110 to effectively retract their armatures U561 and V561, respectively. The ground being removed from bank contact U569, relay 115 U513 will have its short-circuit removed so it will actuate and forthwith apply ground from spring U531, armature U519 to wiper U506, bank contact U569 and multiples; the spring U531 maintaining ground through 120 armatures U530, U532, P533, wiper 509 to bank contact U572 and multiples thereof until the ground has been applied to wiper U506. If the ground were not applied to wiper U506 before the ground is removed from wiper U509, the short-circuit would be 125 removed from relay V513 before relay U513 actuates, so relay V513 would also actuate. That is, in selector U, relays U513, U514, U515 and U518 will now be actuated and tone applied to talking conductor U525 from source AT5, in lieu of from source BT5.

Consequent to ground being removed from wiper U509 and engaged bank contact U573 and multiples, the short-circuit to 130

ground from armature V530 is removed so relay V514 will actuate, the relay V513 being short-circuited by ground received from bank contact V569 and wiper V506. That is, in selector V, relays V514, V515 and V518 will now be actuated and tone applied to talking conductor V525 from source BT5, in lieu of from source CT5. Under this condition, wiper V510 does not receive ground from armature V537, due to it being retracted, so should a new call to the "0" level now occur the terminating selector belonging to the group containing Q5, and which may be assumed to be selector W, will have its wipers W505, W506 and W509 encounter ground upon rotating-in to the pre-testing position. As previously described with relation to selector V, the relays W515 and W518 will be the only relays actuated, causing the order-of-access tone CT5 to be applied to talking conductor W525, the wiper W510 receiving ground from armature W537 in the manner described with relation to wiper V510.

Should a second trunk in the said "0" level become idle, the selector U will forthwith hunt and seize whereupon selectors V and W will be assumed the first and second order-of-access, respectively, in the manner described with relation to selectors U and V.

If, after selector Q5 rotated-off the pre-testing set of bank contacts, and before its wiper 507 reached the test contact of the idle trunk, the idle trunk is seized manually by an operator, or from the opposite end in the manner as has been referred to, the wipers will rotate-off the last bank contact set and the shaft cam (Fig. 18C) will operate the eleventh rotary off-normal spring set. Tone source 5T will be applied to conductor 525, to index the condition to the calling operator, the right-hand contact armature of the rotary magnet R5 sending reverting impulses from spring 588 to operate the selective indicator M'10 if the calling device key K10 is in an operated position. Ground on spring 585 will be applied to the rotary release magnet RR5 to restore the wipers to the pre-testing position, and ground will also be applied to operatively energize slow-releasing relay 586, causing it to lock through armature 587 to spring 588. Armature 589 attracting operatively energizes the upper winding of relay 563, causing relay 563 to remain actuated until relay 586 deactuates. The relay 586 will not deactuate until spring 588 disengages upon the wipers retracting to the pre-testing position, the armatures of relay 586 sustaining consistent with its slow-releasing characteristic. The relay 563 will remain actuated until armature 589 retracts. That is, armatures 590, 591, 532 and 540 will not retract until a period after the wipers have retracted to the pre-testing position. It will be manifest that when the wipers start to

rotate-off the last bank contact set into the eleventh rotary position, the attraction of armature 577 disables the wiper 507 against affecting contacts retracted over, and the attraction of armature 560 disables the rotary magnet R5 and the relay 576 against actuating, since the short-circuit to ground from the upper winding terminal of relay 576 is removed by the attraction of armature 577 as well as by the wiper 507 advancing from the last bank contact. Having in mind the bank contact 565 extends across the level (and is tied to bank contact 569 and multiples), it will appear that the wiper 506 will receive ground from bank contact 569 until armature 590 retracts, which prevents relay U513 in selector U from actuating and changing from its second order-of-access, as well as preventing any change in the order-of-access condition of selector V, which latter condition is dependent upon the condition of selector U.

It is thus clear that though the selector Q5 hunted consequent to the chain ground to conductor 705 opening and has retracted back to the pre-testing position, there has been no change in the condition of selectors U and V. Moreover, due to armatures 591, 532 and 540 being attracted when the wipers have started to retract, wipers 506, 509 and 510 have no operative relation to the selectors Q5, U and V. However, since armature 592 is attracted, applying ground from armature 590 through wiper 501 to bank contact 568 and attached chain conductor 705 it is not essential that the chain ground to conductor 705 be maintained if the wiper 507 fails to encounter an idle test contact, though such an idle condition again ensues forthwith after the wiper 507 has passed the last idle test contact as busy in hunting. That is, the armature 592 serves to apply a false chain ground to conductor 705, thus enabling the selector Q5 to test the condition existing after armature 592 retracts and while armature 590 is still attracted. If the chain ground is intact when armature 592 retracts, relays 513, 514, 515 and 518 will actuate unaffected by the disconnected wipers 506, 509 and 510. However, if the chain ground is open when armature 592 retracts, the hunting operation will initiate forthwith because relay 563 is still actuated, and therefore relay 518 will be deactuated regardless of the condition of bank contacts engaged by wipers 506, 509 and 510. Ground will be applied from conductor 544, armature 583, off-normal spring 584 to wiper 502 before armature 590 retracts, to sustain the set-up condition in selectors U and V as before described while a re-hunting is taking place. In case relays 513, 514, 515 and 518 actuate upon the retraction of the wipers, as set forth, the spring 531 will apply its ground through armature 519, wiper 506 to bank contact 569 before armature 590 re-

tracts, so no lapse of ground occurs to conductor 706 to affect the set-up condition in selectors U and V. It is thus manifest that if the chain ground on conductor 705 opens 5 and the selector (Q5 in the present instance) having the first order-of-access initiates its hunting operation, the selectors having subsequent orders-of-access are maintained in the orders existing until the selector has 10 seized an idle trunk. Further, if the hunting selector fails to seize an idle trunk it will restore to its condition of first order-of-access in readiness to again hunt when the chain ground (on conductor 705) again opens, or 15 if it is open when the wipers have retracted to the pre-testing position.

With reference to the springs which apply tone source 5T to conductor 525 upon the selector Q5 rotating to the eleventh off-normal 20 position, it is to be understood this function is capable of alternative purposes. For example, the lower pair of springs on the eleventh rotary set may be transferred to the rotary magnet R5 and thus cause the tone 25 source 5T to be applied consequent to each actuation of said R5, to index to the calling operator the selector is hunting, in the event the key K10 is operated, thereby having the selective indicator M'10 disconnected from 30 the concerned connection.

The restoration of the selectors Q5, U, V and W have been referred to generally. This is effectuated by the calling operator withdrawing the switching plug S10, which will 35 cause relays 548 and 550 to deactivate. The latter will also occur if the code-switch C'3 is caused to restore selector C3 as described. Upon the latter said relays deactivating, a circuit can be traced from grounded arma- 40 ture 552, armature 553, winding of relay 554, armature 555, off-normal springs to the vertical release magnet VR5.

In this connection, it will be noted that if 45 at the time selector Q5 was first operated a series of eleven or more impulses had been sent in lieu of ten, the designated eleventh vertical off-normal spring set would have been operated and the selector Q5 would thereafter rotate to the first rotary position, 50 where due to the wiper 507 not encountering ground, since there are no eleventh level of bank contacts, the selector Q5 will seize. Further, directive impulses applied effective to relay 548 will have no operative effect in 55 selector Q5. Such a condition as last related would occur if the calling operator extends the call to seize selector Q5 and then sends an index series, followed by digits in the manner before referred to.

60 In foregoing descriptions contacts of relays 595 and 596 have been referred to. The object of said relays is to alter the number of selectors which may be given an order-of-access with relation to each specific level 65 group. That is to say, while the foregoing

specific descriptions had reference to the "0" level wherein three selectors may have an order-of-access, the present invention contemplates altering this number by setting switches. Further, each level has corresponding switches for determining how many 70 selectors may obtain an order-of-access when functioning at the specific level. For example, a selector may be enabled to attain a third order-of-access when seeking an idle line in the "0" level and when seeking an idle line in the fifth level may not be enabled to gain higher than a second or a first order-of-access. Moreover, the said conditions may be modified at will through the agency of a 75 switch. In commercial operation the number of lines connected in a level will, in a measure, determine the number of selectors seeking a line of the level it is desirable to give an order-of-access thereto, for obviously 80 the average waiting time for an idle line in a group of eight lines will be less than if the group contains four, or possibly one line only. Again a group normally containing eight 85 lines may, due to line trouble have a less number, and under the latter condition it is desirable to reduce the number of selectors 90 enabled to attain an order-of-access condition with reference to the level.

The switch-arms 616 to 619 and 708 to 711 95 are for the purpose of changing the number of selectors which will be enabled to attain an order-of-access condition with relation to levels "0", "7", "4" and "1", respectively. The number of selectors enabled to attain an order-of-access condition being three at each 100 said level with the said switch-arms in the position shown in the drawings. If it is assumed it is desired to change the number of 105 selectors enabled to attain an order-of-access condition at the "0" level from three to two, switch-arms 616 and 708 will each be rotated counter-clockwise into engagement with the first successive contacts 621 and 716, respectively. If it is assumed the selector Q5 is 110 now operated and rotates-in at the "0" level as before, under the condition of all the lines of the "0" level group being busy, and therefore, chain conductor 705 is grounded, conductor 706 will also be grounded by reason of the switch-arm 708 tying said conductors 705 and 706. Under this condition the winding of relay 513 will be short-circuited by the switch-arm 708, so the latter said relay will not actuate, but that relays 514, 515 and 518 115 will actuate. In previous descriptions this state would indicate that a selector had a first order-of-access and that the present selector has the second order-of-access, the conductor 706 being then grounded from the selector having the first order-of-access. The selector having the second order-of-access, 120 determined by the relay therein corresponding to 513 being normal will cause busy tone source BT5 to be applied to the talking con- 125 130

ductor corresponding to 525 of the concerned selector. In the present instance, due to conductor 622 being grounded through switch-arm 616, wiper 503 will receive ground from bank contact 566 and apply it to operate relay 595. The relay 513 being normal, due to its winding being short-circuited, the source AT5 will be applied through armatures 593, 528, 529, 520 to conductor 525. That is, under the before described condition under which tone source BT5 was applied to conductor 525, tone source AT5 is applied. If selector U now rotates-in at the "0" level, its relays U514 and U518 will actuate, whereupon tone source BT5 is applied through armatures U535, U536, U534, U529, U520 to conductor U525, the relay U595 operatively energizing in multiple with relay 595. That is, under the before described condition under which tone source CT5 was applied to conductor U525, tone source BT5 is applied. If selector V now rotates-in at the "0" level its relay V518 will actuate and apply the final busy tone from source T5 to conductor V525.

If the switch-arms 616 and 708 are rotated on to the next successive contacts 623 and 717, respectively, conductor 625 thereby becomes grounded. Conductor 719 will become grounded when all the lines of the "0" level group become busy, closing the chain ground to conductor 705 to which conductor 719 is now attached through the switch-arm 708. If it is assumed the selector Q5 is now operated and rotates-in at the "0" level as before, under the condition of all the lines of the "0" level group being busy, and therefore, chain conductor 705 (and also linked conductor 719) is grounded, the windings of relays 513 and 514 will be short-circuited by the switch-arm 708, so the latter said relays will not actuate, but that relays 515 and 518 will actuate. In previous descriptions this state would indicate that antecedent calling selectors had a first and a second order-of-access, and that the present selector has the third order-of-access, the conductor 719 being then grounded from the selector having the second order-of-access. The selector having the third order-of-access, determined by the relay therein corresponding to 513 and 514 being normal, will cause busy tone from source CT5 to be applied to the talking conductor corresponding to 525 of the concerned selector. In the present instance, due to conductor 625 being grounded through switch-arm 616, wiper 504 will receive ground from bank contact 567 and apply it to operate relay 596. The relays 513 and 514 being normal due to their windings being short-circuited, the source AT5 will be applied through armatures 536, 534, 529, 520 to conductor 525. That is, under the condition under which tone source CT5 was applied to conductor 525, tone source AT5 is applied.

If selector U now rotates-in at the "0" level,

its relay U518 will actuate and apply the final tone from source T5 to conductor U525.

The energization of either of relays 595 and 596 being dependent upon the condition found upon rotating-in at any level, thus adapts the selector Q5 to set-up an order-of-access condition consistent with the level attained, the idle or busy condition of all of the lines in the level group and the number of waiting selectors seeking an idle line of the group. The same holds for other selectors of the group containing Q5, calling subsequently.

If the switch-arm 708 is rotated on to the third successive contact 721, regardless of the position of switch-arm 616 (which latter arm is preferably mechanically linked to arm 708), the wipers of any selector (as Q5) rotating in at the "0" level will receive ground from chain ground conductor 705 and conductor 722 through its wipers corresponding to 505 and 510. This short-circuits the windings of its relays corresponding to relays 513, 514 and 515, causing the final busy tone from source T5 to be applied to the conductor corresponding to conductor 525. Under the latter setting of switch-arm 708 the final busy tone will be applied from all selectors rotating-in at the "0" level, if all lines of the said level group are busy, and therefore, no order-of-access will be possible of attainment at the "0" level.

The signal lamps 723 to 725 are normally connected to conductors 705, 706, 719 and 722, respectively, (with switch-arm 708 on the contact shown) so they index to the wire-chief or the operator or operators if all lines of the "0" level group are busy (by the glowing of lamp 723), and if any selectors are waiting, having an order of access as indicated by the glowing of any or all lamps 724, 725 and 726. The lamp 723 will glow only when switch-arm 708 is resting on its first contact as shown. The observer will then be enabled to know by the glowing of any of the lamps 723 to 726 (arranged in numerical order preferably) not only how many orders-of-access can exist, but what the present state is as regards to waiting selectors. For example, if lamp 725 only is glowing, it indexes all lines are busy and that only one selector can attain an order-of-access to the "0" level group, the switch-arms 616 and 708 resting on contacts 623 and 717, respectively. If lamp 726 is also glowing, it indicates a selector is waiting in the first order-of-access.

A springjack as 727 is provided for each level. The said 727 is in reality a switch operated by a switching plug to ground conductor 705, in the case of the "0" level group. Thus, regardless of how many selectors may be waiting in an order-of-access for an idle line of the "0" level group, the operator at the concerned switching center "357", for exam-

ple, can, by inserting a switching plug into springjack 727 falsely ground conductor 705 through the auxiliary contacts of said 727 to prevent any waiting selector from rotating-in in case one of the chain relays (701, 703 or 704, for example) should deactivate. It is noted that the chain conductor 705 loops through make-before-break spring 728 of springjack 727 so in the event of inserting 10 a plug into said 727, grounded spring 729 is applied to spring 728, disconnecting spring 730. Under the latter condition the glowing of the lamps 723 to 726 will depend upon the state of the chain relays, and not upon 15 the state of conductor 705, now falsely grounded by spring 729. The operator is thus enabled to note the condition as regards to all lines being busy, as well as the waiting state of any selectors seeking connections. Under this condition the operator can, upon observing the idle condition of a 20 line of the "0" level, convert it through the agency of a switching cord and plug, as by inserting a plug like S'10 into springjack 25 6J (or 6J') if the first line of the group is the idle line wanted. The auxiliary contact on the springjack 6J will cause conductor 602, leading to bank contact 601 and to the winding of chain relay 701, to become ground- 30 ed. This places a busy guard on the trunk at the selector bank and causes the relay 701 to actuate to again close the chain ground, causing lamp 723 to glow. The plug may now be removed from springjack 727, leaving conductor 705 still grounded. Under 35 the last stated condition, the operator was enabled to effect a connection to a first idle line of a group, regardless of an operator at a remote switchboard awaiting the said 40 idleness, to seize the line through a waiting selector having the first order-of-access.

If it is assumed the call is made to line L2, leading to springjack J2 in lieu of to line L6, the last digit will be "7" instead 45 of "0." The private conductor 627 (attaching to conductor 217) and chain relay 731 will correspond to conductor 602 and chain relay 701, respectively. The corresponding elements relating to switch-arms 617 and 709 50 have a prime added. In view of the stated conditions it is not thought necessary to detail the operation of the selectors Q5, U, V and W, with respect to the "9" level. However, since the call is assumed to come from springjack J2, the present call could not be completed to the line L2 due to the fact conductor 217 is grounded at armature 215 as 55 has been described, which places a guarding ground on private bank contact 628, and multiples thereof, the relay 731 being actuated, also.

In order to simplify the disclosure it will be assumed for the present call, that the calling operator is calling over a companion line 60 to L2 which terminates in a selector and code-

switch like C3 and C'3, respectively, in the same group with said C3 and C'3, possibly, though in commercial operation it would ordinarily belong to a different group of lines of the said group containing selector C3. 70 The selectors D4 and Q5 are assumed as linked in the call to line L2.

In order to not confuse the descriptions relating to the assumed call to line L2, the letter "Z" will be prefixed to designations in 75 Figs. 2 and 3 which refer to the assumed substituted figures therefore, at the calling end.

At the time selector Q5 rotates-in on the 80 seventh level in the manner as last before described with relation to the "0" level and seizes the first set of bank contacts (the line L2 being assumed idle) the bank contact 628 receives ground from wiper 507. The latter 85 said ground is applied over conductor 627, conductor 217 to the winding of chain relay 731. It is also applied to the free terminal of lamp 219 and through armature 215 to the winding of relay 216. Relays 731 and 216 90 actuate and lamp 219 glows. Conductor 221 leading to the winding of relay 301 is disconnected at armature 220. Armature 251 applies its ground to conductor 306 to operatively energize relay 222 to disconnect the winding of signal drop D2'. 95

The selector Q5 having seized bank contacts, 628 to 633, relay 576 is actuated, so the talking path from springjack ZJ2 is continued over conductors Z228-Z209, 100 Z229-Z225, armatures Z343-Z338, armatures Z344-Z339, wipers Z315-Z316, bank contacts Z378-Z379, conductors Z346-Z341, armatures 402-401, armatures 432-433, wipers 418-419, bank contacts 491-492, conductors 524-525, armatures 533-541, 105 wipers 509-510, bank contacts 630-631, conductors 228-209 to the tip and sleeve springs of springjack J2, respectively. Under the present condition ringing current is being applied in bridge of conductors 110 228-209 from source G4 effective to calling signal drop D2'. Armature 580 being attracted, the wiper 508 has no operative function under the condition.

A circuit path can be traced from the armature on relay ZP2' (attracted to the right-hand contact), conductor Z212, armature Z220, conductor Z221, armature Z347, wiper Z317, bank contact Z380, conductor Z348, armature 403, wiper 420, bank contact 493, 115 conductor 526, armature 594, wiper 511, bank contact 632, conductor 635, make-before-break spring 252 to the winding of relay 255, the latter said relay actuating and locking to conductor 217. A circuit path can now be 120 traced from conductor 635, armature 256, to the winding of relay 207, the latter said relay actuating to change the polarity normally existing at the center point of the winding of relay P2' so relay P'2 will attract its arma- 130

ture to its right-hand contact, which in turn causes relay $P''2$ to actuate to change the polarity normally existing at the center point of the winding of relay $P''2$.

5 A circuit path can be traced from the winding of relay Z207, winding of solenoid Z230, conductor Z231, armature Z349, wiper Z318, bank contact Z381, conductor Z350, armature 404, wiper 421, bank contact 494, conductor 10 527, armature 557, wiper 512, bank contact 633, conductor 212, to the right-hand contact of relay $P'2$.

If it is now assumed the called operator responds by inserting a switching plug like S10 15 into springjack J2, the relays therewith associated corresponding to relays 210" and P10 will operate, due to relay $P''2$ being operated as set forth. This will prevent the supervisory lamp corresponding to 238" from 20 glowing. The relay corresponding to $P10$ being deactuated, the relay $P''2$ will operate its armature to the right-hand contact, which in turn will cause relay $P'2$ to do likewise. The latter function will cause conductor 212 25 to become grounded and, in turn, cause relay Z207 to actuate. The latter function will cause relays ZP'2, Z235, Zp''2 and P10 to operate, the latter relay extinguishing the supervisory lamp 238", to index to the calling 30 operator that a response has been attained. The corresponding lamp of the responding cord set referred to being extinguished indicates a corresponding switching cord plug is in the calling springjack ZJ2. It is clear, in 35 view of previous descriptions that if the calling or the called operator now removes the switching plug from the line springjack, the opposite end said supervisory lamp will glow to index the condition.

40 It will be understood, of course, that intermediate switching links, in any plurality may be interposed intermediate of the calling selector ZC3 and the selector Q5. Also, that the call may extend through a selector at the far 45 (left) end of line L2 to a link (and perhaps re-extended) as if the call originated at the near end of the line L2 at springjack J'2, wherein Fig. 16 is introduced as indicated. Under the condition of relay 216 being actuated, the sleeve conductor of springjack J'2 50 is opened at armature b2, so in the event a switching plug is inserted into springjack J'2 the call cannot be vitiated thereby. Of course, the conductors leading to the tip and 55 ring springs of springjack J'2 may include normally closed contacts on relay 216 (as in Fig. 12) so as to disconnect all conductors of the springjack J'2 in the event the right-hand end of line L2 is seized by a switch.

60 It will be clear, in this connection, that if the telegrapher's key TK10 is operated after the response is obtained, the relay corresponding to P10 of the answering switching cord equipment will operate responsively. Also, 65 if the telegrapher's key corresponding to

TK10 of the answering cord equipment is operated, the relay P10 of the calling cord equipment will operate responsively, so telegraphing may be effectuated in both directions. Of course, the code-switch ZC3 will 70 operate responsive to all impulses transmitted from key TK10, but to no operative purpose.

Returning to the condition wherein the call is extended from springjack J2 through selectors C3, D4 to selector Q5, it will be assumed that the latter said selector is operated to the fourth bank level, in lieu of the tenth or the seventh, as before exemplified. The operation of selectors Q5, U, V and W under 75 busy and other conditions being known from previous descriptions, it will be assumed the first line of the fourth level group is seized. That is, wipers 507 to 512 seize bank contacts 638 to 643, respectively. Bank contact 639 is dead. Bank contacts 638, 640, 641, 642 and 80 643, and multiples thereof, attach to conductors 803, 371, 372, 373 and 374, respectively. Wiper 507 thus applies its ground through armature 802, spring 801 to the winding of relay 800, the armature 810 energizing guard 85 lamp 812, armature 804 energizing relays 808 and 809 to disconnect signal drop D'8 and open the connection from the sleeve of springjack J8, respectively. Armature 815 disconnects conductor 833 leading to relay 901. The 90 talking springs of springjack J2 are now extended to the corresponding springs of springjack J'8 over line conductors 820 and 821. Conductors 373-374 (in Fig. 6) which have been traced from terminal c2 and the 100 winding of relay 207, lead to the winding of relay $P'8$ and to the right-hand local contact of relay $P'8$, respectively. The armature of relay $P'2$ being against the right-hand contact, relay $P'8$ will be actuated, but due to the 105 armature of relay $P'8$ being against its left-hand contact the relay 207 will not be energized.

If it is assumed plug S8 is inserted into springjack J'8, the armature of relay P8" 110 will be caused to move against its right-hand contact, in turn causing the armature of relay $P'8$ to move against the right-hand contact. The latter function will cause relay 207 to actuate to, in turn, cause the armature of relay P10 to deenergize lamp 238". If calling device D10 is operated, causing the armature of relay $P'2$ to vibrate, the armature of relay $P'8$ will, in turn vibrate, causing the armature of relay P8 to vibrate and deenergize the lamp 828 correspondingly. The telegraphers' keys TK10 and TK8 may be employed in lieu of the calling devices D10 115 and D8, respectively. In this connection, it will be understood that equipments as represented to the right of section line A2 in Fig. 2 may be substituted for the equipments shown at the right of section line A8 in Fig. 8, so the call can be further progressed to 120 125 130

include a plurality of switching centers as indicated in Figs. 21 and 22.

If it is assumed Fig. 1 is substituted for Figs. 8 and 9 in the assembly shown in Fig. 26, and the selector D4 has rotated-in at the second level as when line L6 was last called, and that selector Q5 has now been operated to the first level in lieu of to the tenth level as when line L6 was called, and the first set of line bank contacts is seized, the wipers 507 to 512 will be in engagement with bank contacts 645 to 650, respectively. The bank contacts 649 and 650 are not connected, as the duplex impulse control does not extend to the lines of the first level, the first line thereof L leading to selector A, for example. The latter said selector is operated by a simplex impulse control, translated from the duplex impulse control. The talking springs of springjack J2 are now extended to the corresponding springs of springjack J' over bank contacts 647-648 to line conductors 651-652 of line L. Wiper 507 applies ground to bank contact 645, conductor 653 to the winding of relay 101, causing armature 102 to attract to disable the calling device 103. A circuit path can now be traced from attracted armature 351, armature 352, wiper 314, bank contact 377, conductor 355, armature 405, wiper 417, bank contact 460, conductor 523, armatures 549, 580, wiper 508, bank contact 646, conductor 654, retardation coil 104, line conductor 652, retardation coil 105, conductor 106 to control relay 107, the latter said relay actuating. Relay 108 will now operatively energize in a local circuit of relay 107. Operating the calling device D10 will cause relay 301 to correspondingly de-actuate and reactuate to, in turn, correspondingly deactuate and reactuate relay 107. It will appear, presently, how the operation of relay 107 will cause the shaft of selector A to correspondingly operate and extend the line L to a directively called line, incidentally capacitating the code-switch A' auxiliary to said A to thereafter directively function, controlled by relay 107 over conductor 654 from calling device 103; the latter alternatively with calling device D10 over a duplex control circuit including the sleeve spring of springjack J2, depending upon whether the call originates at springjack J2 or J.

It is clear from foregoing descriptions that the left-hand end of line L8 terminates in the first set of bank contacts in the fourth level accessible to selectors Q5, U, V and W, and other selectors of the group containing the latter said selectors. Chain relays 735 and 736 are attached to the private conductors leading from bank contacts 638 and 656, occupying the first and eighth bank positions, respectively. Having in mind there are similarly connected chain relays corresponding to 737, one for each bank position, it will appear that if all the lines of the

fourth level group are busy the chain conductor 738 receives ground from key spring 659, armature 658, conductor 739, armatures 740, 741, conductor 742, spring 743. The latter path is closed only when all chain relays (only three of which are shown) are actuated. The switch-arm 744 has engageable contacts corresponding to chain ground and order-of-access conductors 745, 746, 719' and 722', respectively. The switch-arm 744 attaches to the free winding terminal of relay 749 so that the arm 744 can be set into engagement with any of its contacts desired which will cause the relay 749 to operate whenever the corresponding conductors 745, 746, 719' and 722' are grounded. That is, the relay 749 will be caused to actuate upon the chain conductor 745 becoming grounded from the chain relays, or upon any desired order-of-access condition occurring in the fourth bank level. The relay 749 will actuate if any selector as U, for example, has a first order-of-access relating to the fourth level. If the arm 744 is set upon contact 750, the relay 749 will actuate if any selector V, for example, has a second order-of-access, relating to the fourth level. Thus, if the arm 744 is in the position shown, and wherein any selector has the first order-of-access to the fourth level, applying ground through its wiper corresponding to 506 to a pre-test contact attached to conductor 746, the relay 749 will be actuated, its armature 751 applying ground over conductor 752 through armature 260 to the winding of relay 241, the latter relay actuating.

The solenoid 230 will become operatively attracted consequent to its energizing conductor 231 becoming grounded for a prolonged period (ten seconds, for example), as would occur upon a call being responded to at springjack J'8 for the said period. Thus, though conductor 752 becomes grounded, the path from interrupter R2, armature 261, series winding of slow-releasing relay 262, arm 263 to the winding of relay 208 will not be energized until the arm 263 has had time to effectively attract. Upon the latter said path becoming closed, wherein armature 266 attracts, relay 208 will vibrate its armature 265 responsive to said R2, effective to changing the polarity applied to the center point of the winding of relay P2'. However, relay 207 will be actuated at this time; energized in the path with the winding of said 230 from armature 266. The relay 262 will not de-actuate while an impulse series is being transmitted from the said R2, but will following each train of series sent periodically, say every fifteen seconds, for example. It will thus be manifest that armature 266 will short-circuit conductor 231 to ground during a train of series of impulses from said R2. The latter function causes relay 207 and the solenoid 230 to be maintained actuated, regardless of any

condition occurring ahead to unground conductor 231; such as the called party disconnecting, or impulses being sent back from an interrupter device equivalently situated as 5 R2 at a switching center ahead. The impulses sent from the interrupters, as R2, will operate the relays (as 208) and supervisory signal devices in a manner to enable the calling operator to recognize from which 10 switching center the impulses are projected. Thus, if at the termination of a series of impulses from said R2, whereupon armature 266 retracts, a series of impulses is projected back from an interrupter associated as R2 15 at a switching center ahead the circuit openings will cause relay 207 to retract its armature 267 correspondingly. In this connection it will be understood that the slow-releasing relay 268 is energized in a local 20 circuit of relay 207 and will sustain over digit impulse lapses. The retraction of armature 267 due to the called party having disconnected or because impulses from an interrupter source situated as R2, ahead, occur, 25 will cause the relay 270 to actuate and lock to arm 271, the ground on the contact upon which arm 271 rests also energizing the winding of the solenoid 273, the latter arm locking the latter said winding. The arm 260 at 30 tracts from its resting contact forthwith upon the winding of said 273 energizing, the arm 271 flexing from its resting grounded contact to unlock said 270 and 273 after a period of say, fifteen seconds, causing the plunger 274 35 to then recede to normal. It is thus clear, that while the source R2 is being applied through relay 262 to relay 208 and is sending impulses to the supervisory lamp 238" the relay 207 is maintained actuated regardless of conditions ahead. However, upon armature 266 40 retracting any open condition from ahead will cause relay 207 to retract its armature 267 to cause the solenoid 273 to attract arm 260 and disable relay 208 until arm 271 is 45 attracted to unlock relay 270 and the winding of solenoid 273.

It will be manifest from foregoing descriptions that if relay 208 is actuated from armature 266, relay 207 will necessarily be actuated, so the actuation of relay 208 under the condition will not change the polarity at the center point of the winding of relay P2'. Relay 208 may deactivate without the deenergization of relay 207 occurring, due to the 55 armature 266 sustaining over short current lapses to the winding of relay 262.

It will thus appear that if a series of impulses is projected back from source R2 no interference can occur to the said impulses 60 from a source similarly situated ahead, for example. Also, if the last referred to source ahead is transmitting impulses to relay 207 the arm 260 will be attracted from its resting contact so no impulses can be transmitted 65 from the source R2. The time element in-

volved in the solenoid 273 is to insure that relay 262 will not operate to nullify impulses from ahead until after a period has elapsed sufficient for the calling operator to observe a clearing signal or other signal controlled 70 from the called line or from some point intermediate of the switching center "357" at which R2 is located, and the called line. Further, the conductor 360 which attaches to the windings of 270 and 273 leads to off-normal 75 spring ON3" and thus causes the solenoid 273 to disable relay 262 and 208 for a time interval after any index series is applied from the calling station. This latter function is to prevent interference with reverting, clear- 80 ing and other impulses by impulses from sources situated as R2, and to allow a suitable time thereafter for response impulses without possibility of confusion. It will be understood, of course, that the cam shown 85 in Fig. 3B may be made to cause spring set ON3" to close coincidentally with ON3' so that any impulse effective to rotating wipers 347-348 will disable relay 208 for the contemplated period. Switch-arm 386 may be 90 closed and the conductor 360 disconnected from the spring set ON3" so the relay 270 and solenoid 273 will energize when relay 346 is caused to actuate directly. The latter application will apply where the code-switch 95 wipers do not rotate unless the switching center numerical designation is called first as will appear, presently, with reference to Fig. 20.

If the switch-arm 744 is moved to contact 100 755, the conductor 752 will become grounded from armature 751 whenever all the lines of the seventh level group (containing calling line L2) are busy, though no selectors may have an order-of-access thereto as necessary 105 when the arm 744 is resting on any other contact.

The switch-arms 756, 710 and 711 are for the same purpose as 744, though the wiring has been omitted. A calling operator is thus 110 apprised if a line in a call belongs to a group in which there are no idle lines, and perhaps, have waiting selectors, depending upon the position of arms corresponding to 744. The calling operators on all lines of the said busy 115 group or groups will be supposed to release lines held as soon as possible. Conductors corresponding to 752 will lead to all the selectors of the seventh level group at the "357" switching center. The far ends of lines may 120 be likewise arranged to project prompting impulses to calling operators on calls going in the opposite direction, provided all the lines join the same switching centers. Of course, the switch arms at both ends corresponding to arm 744 may be set differently 125 depending on the general traffic directional characteristics since ordinarily the switch-arms corresponding to 744 will be set so as to not be effective unless a critical congestion 130

of traffic occurs, as where two or more selectors are awaiting for an idle line condition to occur.

Referring to the device M'2 it is clear that due to each attraction of the armature of relay P'2 against its left-hand contact after a response has been obtained will cause an open impulse to be applied to magnet MM'2 if the responding operator operates the telegrapher's key TK8 or otherwise transmits impulses to relay p8', the lamp 206 can be caused to glow as an attracting signal and the pointer 201' may be directly operated to convey intelligence relating to calls, perhaps. The calling operator can also transmit intelligent impulses from key TK10 or calling device D10 to the called operator wherein the relay (corresponding to) relay P10 will operate as a sounder and lamp corresponding to 238" will flash.

Fig. 6D shows equipment which may be located on an operator's or wirechief's switchboard, or on both, for the purpose of successively talking to calling operators having calls extended to selectors having an order-of-access at the fourth level of the concerned switching center selector. This would be occasioned, perhaps, if the switching center operator has the chain ground locked as by having a switching plug in springjack 727" and wishes to so inform waiting operators. In this connection, it will be understood the spring 729", which is shown grounded, is preferably grounded through armature 675 on relay 676, rather than direct to ground. The latter is to unlock the chain ground in the event relay 676 is caused to actuate while a plug is in springjack 727". The tenth bank position is reserved to the special purpose and has its private common conductor 677 grounded through armature 678 to spring 659.

If it is assumed that it is desired to not permit any calls to attain an order-of-access, the push of key 659 will be depressed into its locked position, opening the ground on armature 740 and bank contact 679. Under this condition, no selector will be restrained from testing if it rotates to the first or pre-testing position at the fourth bank level. However, it will seize when wiper 507 engages bank contact 679. The tone source T6 will then be applied through spring 680 of springjack J6", conductor 681, bank contact 682, wiper 509, audible to the calling operator, to index the condition. If a second test is made while bank contact 679 is thus seized the wipers will rotate past and retract to the pre-testing position in the manner set forth and re-test. The calling operator formerly receiving the tone from source T6 will perhaps have released the connection before the second (or following) re-test is made.

If it is assumed a switching plug is in springjack 729" and the lamps 724" and 725"

indicate two selectors have orders-of-access (at the fourth level), the operator at switching center "357" desiring to talk to the calling operator having the first order-of-access will insert a switching plug (as S'10) into springjack J6". This will cause ground from auxiliary spring 683 to be applied through make-before-break spring 684 to the winding of slow-releasing relay 676, the latter said relay actuating, armature 658 closing an operative path to the winding of relay 685. This will open the chain ground from conductor 739 and from spring 729", so the selector having the first order-of-access will forthwith hunt.

Upon relay 685 actuating the energizing circuit for relay 676 will be opened so the ground will be re-applied to conductor 739 and spring 729" consistent with the release period of relay 676. Armature 678 being attracted, the conductor leading to private bank contact 679 will be ungrounded, so the hunting selector will seize, the wipers 509—510 extending the talking connection through bank contacts 682—686, conductors 681—687 to the tip and ring springs of springjack J6", the calling, and the intercepting operator being in talking relation. When relay 676 deactuates, and while relay 685 is held actuated, a circuit path can be traced from ground through armatures of relays 676 and 685 to the winding of relay 688, the armature 689 attracting to open the tie from conductor 690 (attached to the bank contacts of the fourth level engageable to wipers corresponding to 501) to conductor 691 (attached to the bank contacts of the fourth level engageable to wipers corresponding to 506), to unbar the selector having the second order-of-access so it will assume the first order-of-access forthwith and not be in control of wiper corresponding to wiper 502 while the last selector unbarred from its waiting condition, is hunting. The ground applied through armatures 692 and 693, conductor 694 to chain conductor 738 bars any selector attaining the first order-of-access from rotating over the trunk contact sets. That is, regardless of the condition of the chain relays of the lines of the fourth level, no selector can hunt if the operator has caused the selector having the first order-of-access to rotate and be in seized relation with the bank contacts corresponding to springjack J6".

If the operator withdraws the plug from springjack J6", a circuit can be traced from ground, armature 695, armature 696, conductor 697, bank contact 698, wiper 505, (assuming selector Q5 is concerned), series windings of relays 513, 514, 515, 518, the armature 561 disconnecting battery from relay 576, causing the selector Q5 to unseize. Relay 685 being now unenergized, ground from spring 689, armature 678, conductor 677, bank contact 679, wiper 507, armatures 577, 578, off-normal springs, make-before-break spring on 130

relay 554, lower winding of relay 563, winding of rotary magnet R5, armatures 559, 560 and 561 to grounded battery, the rotary magnet R5 operating to drive the wipers 501 to 512 into the eleventh rotary position, the rotary release magnet RR5 restoring the wipers to the pre-testing position. The selector will set-up a condition in itself as if it rotated to its present pre-testing position primarily, 10 and not as before described with relation to retracting from the eleventh rotary position, due to failing to seize as before described, it being remembered that the tie conductor from conductor 690 to conductor 691 is opened 15 at the armature 689 of relay 688 while the selector is hunting. If the operator now re- inserts the switching plug into springjack J6'', the selector now having the first order-of-access will rotate-into the tenth set of 20 bank contacts and seize as before, the selector having the second order-of-access attaining the first order-of-access incidental to the initiation of the latter said rotating-in.

In order to provide against the selector rotating towards the tenth set of bank contacts seizing an intermediate idle line which may become disengaged while the selector is thus hunting, ground from spring 683 is applied over conductor 698 to bar 699, which latter bar 25 extends as a continuous bank contact from the second to the ninth (inclusive) bank positions engaged by wiper 503. The latter condition will cause relay 595 to be actuated so its upper armature will apply ground to armature 578 30 to cause the rotary magnet R5 to operate as if wiper 507 were encountering grounded test contacts. That is, under the condition of the operator inserting a switching plug into springjack J6'' the selector having the first 35 order-of-access will forthwith rotate its wipers to complete a talking connection with the latter said springjack regardless of the condition of the line test contacts passed over. Further, that withdrawing the said switching plug from the springjack J6'' will cause the latter said selector to restore to the first 40 off-normal rotary position and set itself as if it initially rotated-in at the concerned level. Any selector having a second order-of-access 45 when the selector having the first order-of-access was directly caused to rotate to the tenth bank contact set will forthwith assume the first order-of-access upon the selector having the antecedent order initiating its rotation from the pre-testing position, the first 50 order-of-access not being retained by the rotating selector because of the tie between conductors 690 and 691 being opened.

Referring to Figs. 28 and 23, it will be 55 noted that the assembly of the drawings is like shown in Fig. 24, but with Fig. 1 attached below Fig. 3. If a call is assumed made from springjack J to substation T15, the same calling numbers ("78411" and 60 "77411") will be employed as when the call

was from springjack J2. However, the impulses sent from the calling device 103 to the control relay 107 is over a "simplex" control path in lieu of a duplex control path, as it was from springjack J2. The bank contacts accessible to selectors A and C3 being in multiple, it will be clear, in view of the descriptions with relation to other operations to be described, that the effective operation of selector A will be like that of C5, in calling substation T15. 70 75

It is thought a more comprehensive understanding of the functioning of selector A and the code-switch A' will be had by detailing a call to toll line L2, the cooperating figures being assembled as in Fig. 26, the Fig. 1 being joined below Fig. 3. The calling number will be "427", as before. 80

Upon inserting plug a' into springjack J, a circuit path can be traced from grounded armature 102, spring 109, calling device 103, coil 104, conductor 652, coil 105, conductor 106 to the winding of relay 107, relays 107 and 108 actuating, armature 110 applying ground to conductor 112. When the calling device 103 is operated in accordance with digit "4" the relay 107 will deactuate and re-actuate four times responsive thereto, the relay 108 sustaining over the lapses. Each of the four times armature 113 retracts its ground is applied through armatures 114, 115, series winding of slow-releasing relay 116 to the vertical magnet V. The vertical magnet will thus cause the wipers 117 to 121 to be stepped into alignment with the fourth bank level, the off-normal set ON operating incidental to the first off-normal movement. Ground from conductor 112 is applied through armature 123, off-normal springs to the winding of shunted relay 124, causing said relay 124 to actuate and lock by way of armature 125 on the rotary magnet R to armature 126. When armature 123 retracts, following the fourth impulse, a circuit path can be traced from said armature 123, armature 127 to the rotary magnet R, the rotary magnet operating to rotate the wipers 117 to 121 into engagement with the first set of bank contacts 131 to 135, which attach over conductors, 136, 137, 354, 345 and 340 to conductors 383, 410, 355, 346 and 341, respectively, leading to selector D4. If conductor 383 is grounded, indicating a busy condition of D4, bank contact 132 will constitute ground, so the ground applied to the upper winding terminal of switching relay 139 by armature 126 is maintained. Thus, when armature 125 retracts, ground on test bank contact 132 is applied over wiper 118, 120 armatures 140, 125, off-normal springs to 125 operatively energize the winding of relay 124, the rotary magnet R again operating to advance the wipers; the cycle of operations continuing as long as wiper 118 continues to receive ground from an engaged (busy) 126

bank contact. When the wiper 118 fails to receive ground, the upper winding terminal of relay 139 becomes ungrounded, and since the lower winding terminal of relay 139 is attached to grounded conductor 112, a circuit path can be traced from ground through the winding of relay 139, armature 125, off-normal springs to the winding of relay 124, the windings of relays 124 and 139 being thus energized in series. Due to marginal adjustments relay 139 only will actuate under the last stated condition, the selector A thus having seized. The relay 139 will thus actuate if the first bank contact 132 (corresponding to selector D4) engaged by wiper 118 does not constitute ground, which latter condition is assumed. The selector D4 will now be guarded against subsequent seizure due to wiper 118 applying ground to bank contact 132, and multiples, from conductor 112, armature 140.

A circuit can now be traced from the winding of relay 406, armature 405, conductors 355, 354, bank contact 133, wiper 119, armatures 141, 142 to grounded make contact, the relay 406 actuating, followed by the local relay 408. Upon the calling operator sending the second digit "2", causing relay 107 to vibrate its armatures responsively, relay 406 will, in turn, vibrate its armature, causing the selector D4 to function to seize selector Q5 as before described, in relation to selector C3 cooperating therewith.

The sending of the last digit "7" will cause selector Q5 to seize the line L2 in the manner hereinbefore described. However, since the duplex control conductors 348—350 (leading in to selector D4) are not concerned, the wipers 511—512 will have no operative object, and therefore, the conductors 635—212, leading from bank contacts 632—633, respectively, will have no operative object so far as selector Q5 is concerned. In the present instance, conductor 280 included from the winding of relay 207, armature 256, resting contact, terminal d2 to bank contact 629 will be continued over wiper 508, armatures 580, 549, conductor 523, bank contact 460, wiper 417, armature 405, conductor 355, conductor 354, bank contact 133, wiper 119, armatures 141, 142 to grounded make contact, the relay 207 actuating, followed by dependent relay P'2. The relay 255 remains normal, due to conductor 635 being operatively free at its bank contact end. The relay 216 actuates due to conductor 217 receiving ground through bank contact 628, wiper 507, armatures 577, 578 to conductor 544 as before described, so the sleeve of springjack J'2 is disabled, (Fig. 16 being assumed introduced into Fig. 2), and signal device D2' is disconnected.

If the calling operator now operates sending device 103, the relay 207 will operate responsive thereto, causing relay P'2 and other

dependent relays to operate, in turn, as has been set forth. The call may be progressed from the left-hand end of line L2 in the manner as has been referred to when the call was assumed extended from springjack ZJ2. However, since the conductor 212 has no operative function in the last assumed call, reverting impulses and supervisory and other signals will not be effective towards the calling end from conductor 212 as when the call was assumed as originating at springjack ZJ2.

When the call has been completed to line L2, the calling operator can attract the attention of the operator at springjack J2 by sending impulses effective to relay 107, and in turn, to relays 579 and 548. Due to conductor 521 being free at bank contact 468 relay 581 will remain deactuated. However, the relays 207, P'2 and 235 will operate responsive to relay 548. The lamp 206 may be thus caused to glow as a calling signal. The calling operator, can, by sending eleven impulses (the called line L2 being for the present assumed as the first line link beyond selector A) cause ringing current from source G to be applied in bridge of the before traced talking conductors from bank contacts 134—135 through selectors D4 and Q5 to line L2, to operate the signal device D'2. The calling operator's telephone circuit C will, upon response of the operator at springjack J2, by inserting a switching plug as S'10 therein and manipulating key K10, be in talking relation with operator's telephone circuit C10 over the heavy lines joining springjacks J and J2.

If the calling operator removes the plug from springjack J the relays 107 and 108 will deactuate, causing a circuit path to be completed from grounded armature 113, armatures 114 and 115, off-normal springs to the release magnet Re, operative to restoring the wipers of selector A. The relay 406 will now deactuate, causing selector D4 and succeeding selectors to restore as has been described.

The function of the code-switch A' is generally similar to code-switch H'9, the ground from armature 113 being applied through armature 114, winding of slow-releasing relay 145 to stepping magnet M at each deactivation of relay 107 subsequent to relay 139 actuating. Due to code-switch A' being generally similar in circuit details and in its operation to code-switch H'9, the operation of code-switch A' will not require complete detailing in order for its operation to be fully comprehended.

Having in mind that a selector and companion code-switch may be introduced at the far end of line L2, and, in fact a plurality of line links may form a connection to a called line beyond line L2, it will be assumed it is desired to restore the selector A. The index

series of twelve impulses will be sent from the calling device 103 whereby stepping magnet M will advance the wipers 146—147 to the twelfth position, the relay 145 retracting its armature 148 following the last impulse. Upon the retraction of armature 148 a circuit path can be traced therefrom, armature 149 on the slow-releasing release magnet Re', series winding of slow-releasing relay 150, make-before-break spring 151, wiper 146 and its twelfth cooperative bank contact, winding of relay 153, the latter said relay actuating and locking through its upper armature, conductor 154, armature 155, conductor 156, off-normal springs, conductor 157, armature 158 to grounded conductor 112. The relay 150 actuates and applies ground to the release magnet Re' to restore the wipers 146—147, incidentally opening the conductor leading to wiper 147 at armature 149, which latter wiper was attached through armature 159 consequent to the actuation of relay 153, the wiper 146 no longer being attached to an operative conductor.

The number of the switching center at which code-switch A' is located being "357", the said digits will next be sent. Sending digit "3" will cause wiper 147 to rotate to and ground its third cooperative bank contact, causing relay 160 to actuate and lock to conductor 154. The release magnet Re' will operate to restore the wipers 146—147 as before. Sending second digit "5" will cause wiper 147 to rotate to and ground its fifth cooperative bank contact causing relay 161 to actuate and lock to conductor 154, the wipers 146—147 being restored as before. Sending the third digit "7" will cause wiper 147 to rotate to and ground its seventh cooperative bank contact causing slow-releasing relay 162 to actuate and lock to conductor 154, the wipers 146—147 restoring as before. At the time relay 162 actuates its armature 163 will apply ground through armature 164, conductor 165, off-normal springs to the release magnet Re', operative to restore the wipers 117 to 121. This will cause all succeeding switches in the call to restore in the manner as described wherein selector C3 restored from selector D4. The lower armature of relay 162 will apply its ground to the winding of relay 166, so armature 155 will attract to open ground from conductor 154 to unlock the relays 153, 160, 161 and 162.

If it is desired to apply ringing current in bridge of the bank contacts 134—135, the index series of fourteen impulses will be sent, wiper 146 apply ground to its fourteenth cooperative bank contact, causing slow-releasing relay 167 to actuate to apply ringing current from source G in bridge of wipers 120—121, the wipers 146—147 forthwith restoring. If it is desired to introduce the two-direction speech amplifying repeater SR, the index series of sixteen impulses will be sent, wiper 146 applying ground to its sixteenth cooperative bank contact, causing relay 168 to actuate and lock through make-before-break spring on relay 162 to conductor 154 and apply ground to the winding of relay 153, causing the latter said relay to also actuate and lock to conductor 154. The wipers 146—147 will forthwith restore. If the digits "3—5—7" are now sent to actuate and lock relays 160, 161 and 162, the armature 163 applies its ground through armatures 164, 169, conductor 170 to the lower winding of relay 171, the latter said relay actuating and locking through its lower armature to conductor 112. Line conductor 652 leads through armature 172 to terminal 173, and line conductor 651 leads through armature 174 to terminal 175. The conductor leading from wiper 120 extends through armatures 176, 177, 178 to terminal 179, and the conductor leading from wiper 121 extends through armatures 180, 181, 182 to terminal 183. Terminals 173—175 and 179—183 are the two pairs of line terminals leading in opposite directions. The latter said pairs of terminals may be considered as equivalent to those of lines 2 and 21 shown in the patent to Shubert, No. 1,029,724, granted June 18, 1912. The repeating coil Fig. 4A can be substituted for said SR, the terminals 490—491 and 492—493 corresponding in the connection to 173—175 and 179—183, respectively. In the latter instance the actuation of relay 171 will interpose the repeating coil Fig. 4A. Consequent to the actuation of relay 162 the relays 153, 160, 161 and 162 will become unlocked and the release magnet Re' will operate to restore wipers 146—147. The relay 168 is maintained locked from grounded upper middle armature of relay 162 locally, so that armature 164 will not retract before armature 163, as otherwise a false impulse would be applied over conductor 165.

After relay 171 actuates, and after relay 162 deactuates, a circuit path can be traced from grounded conductor 112, armature 158, conductor 184, armature 185 to the winding of relay 186, the latter said relay locking through its upper armature to conductor 184. If it is desired to exclude the repeating coil Fig. 4A at any time after relay 186 has actuated, the index series of sixteen impulses will be sent, followed by digits "3—5—7" (as when including the repeater SR), whereupon armature 163 will apply its ground through armatures 164, 169 (as before), but due to the relay 186 being actuated, the ground is applied to the upper winding terminal of relay 171 the windings of relay 171 are now energized in opposition, so the said relay 171 will deactuate. Conductor 184 becoming ungrounded unlocks relay 186. It is clear that the repeating coil Fig. 4A will not be excluded by any operations of the code-switch other than the specific ones stated.

- wherein relays 168 and 153 are caused to first actuate and lock. Of course, if the connection is destroyed from a point antecedent to selector A, as by the operator withdrawing the 5 plug a' , for example, wherein relay 108 de-actuates to disconnect ground from conductor 112, the relay 186 will unlock along with other relays which may then be actuated in selector A and code-switch A'.
- 10 If the calling operator desires to gain the attention of the operator at switching center "357", sending a series of ten impulses will cause the wipers of selector A to rotate-in at the "0" level where wiper 117 will seize 15 the first bank contact 188, local to selector A. This will cause relay 189 to actuate and lock through armature 190 and auxiliary spring 191 to conductor 112. Calling lamp 192 will energize in multiple with the winding of relay 189. Incidental to the actuation of relay 189 its armature 194 applies ground through off-normal springs to the release magnet R_e to restore the wipers. The called operator opens the said locking path for relay 189 20 incidental to inserting a switching plug into springjack J'.

It will be noted that if the selector A is at normal, terminating a connection, and the calling operator sends eleven or more impulses as a single series the wiper 117 will rotate-in at the eleventh bank level to first bank contact 195 local to selector A, thus preventing the call being idly progressed to lines, in the event some directive operation 30 is to be carried out by the code-switch A' or other antecedent code-switch. Sending a series of eleven impulses will cause the code-switch A' to apply ground to wiper 117, bank contact 195 to the winding of slow-releasing relay 196, armature 197 applying ground through off-normal springs to the release magnet R_e , operative to restore the wipers. That is, after a code-switch (or switches) 40 is directly operated wherein a call has 45 not been completed to a local line, and therefore, has a terminating operative linking switch responsive, sending a series of eleven impulses will eradicate the falsely set-up condition (caused by the index series of over 50 ten impulses), so the call may be progressed as if the code-switch (or switches) had not been operated.

In this connection, it will be noted that 55 the "eleventh vertical" off-normal springs will operate to apply the source T' to talking conductor 652 to apprise the calling operator what has taken place. The tone source T will also be applied to said line conductor 652 when relay 108 actuates, and until the off-normal spring set ON operates to indicate the line to the selector A is intact, and to further index or confirm what switching center the connection has been progressed to, 60 having in mind the said tone sources T and

T' will preferably be distinctive to the switching center concerned.

The introduction of Fig. 19 into Fig. 1 where indicated at section lines AA and AA' provides a preferred means for including and 70 excluding a repeating coil RC9' in addition to the inclusion and exclusion of a speech amplifying repeater. Relays 901', 902' and 903' are added, and an additional bank position (17th) is added in the code-switch A'. 75 Thus, by the calling operator sending the index series of seventeen impulses, relay 902' will actuate and lock to conductor 154. When the digits "3-5-7" are sent following, and relay 162 actuates and its armature 904' applies ground through armature 905', make-before-break spring 906' to the upper winding of relay 901', the latter said relay actuates and locks through armature 907' to conductor 156, the repeating coil RC9' being 80 introduced into the heavy (talking) conductors intermediate of section lines AA and AA'. Relay 166 will actuate and unlock relay 162. Upon relay 901' actuating, and after relay 162 deactuates, a circuit path can be traced from conductor 156, armatures 912', 185 to the winding of relay 903', the latter said relay actuating and locking through its upper armature to conductor 156. Relay 902' will deactuate before relay 903 actuates. If 85 it is desired to exclude the said repeating coil RC9', the same directive operations as employed to introduce it will be transmitted from the calling device 103 (or antecedent calling device controlling over conductor 654 90 as before described) whereupon when armature 905' attracts to its locked condition, a circuit is prepared so when armature 904' attracts responsive to the sending of digits "3-5-7", a circuit can be traced from 95 grounded armature 904', armatures 905', 918' to the lower winding of relay 901'. The windings on relay 901' are energized in opposition, so the said relay 901' will deactuate to exclude the repeating coil RC9'. It is 100 thus clear that the sending of the index series of sixteen impulses, followed by the switching center numerical designation digits "3-5-7" will introduce the speech amplifying repeater SR, as has been described and 105 that the index series of sixteen impulses, followed by the said "3-5-7" will introduce the repeating coil RC9', independently. Also, that like directive operation will exclude, respectively. 110

The introduction of Fig. 20 (being a modification of code-switch H'9) into Fig. 9 where indicated by section lines a_9 , b_9 , c_9 and d_9 in lieu of the code-switch H'9, discloses a 115 preferred means for directly operating a code-switch interlinked with selector H9. The general plan of the code-switch shown in Fig. 20 (and also Fig. 30) may be followed with respect to the selectors A and C3, displacing code-switches A' and C'3, and 120

in fact, the latter would be carried out in the general application of code-switches like shown in Figs. 20 and 30 to a comprehensive toll system as is contemplated.

5 The effective operation of code-switches A', C'3 and H'9, including the preferred modification of A' involving Fig. 19, contemplates an index series followed by a digit train corresponding with the numerical designation of the switching center at which the effective operation of a code-switch is to take place. The effective operation of code-switches, such as Fig. 20; the latter being specific to code-switch H'9, for example.

10 contemplates sending a digit train corresponding to the numerical designation of the switching center at which it is located, followed by an index impulse series corresponding to the function to be effectuated at the 15 directed switching center. For example, if it is desired to cause the relay 932 to actuate, digits "3—5—7" will be sent, the armature 975 applying ground over conductor 934, make-before-break spring 201' to the 20 winding of the selective device GL. The latter said device may be assumed to be a well known so-called "Gill selector," belonging to the general class to which U. S. patent to Gill, No. 906,523, granted December 15, 25 30 1908, belongs, and therefore, has the function of closing a pair of contact springs 202' consequent to the winding of said selective device GL being energized by impulses corresponding to "3—5—7," and to not close 35 the contact springs 202' responsive to any other directive control. It will be understood that where there are a plurality of switching centers, as contemplated, each said center having a specific numerical designation, the digit train which will be functionally effective to the code-switches associated in an extended call, will correspond to the latter referred to designations. It will thus appear the preferred form of code-switch 40 45 (having in mind the before described type of code-switch may be advantageously employed under certain operative conditions), will not operate its wiper 204' over the cooperating bank contacts unless the code-switch has been 50 55 capacitated by the component selective device GL being operated to close contact set 202'.

Under the condition, after ground has been applied through set 202' to energize relay 205' and lock same through armatures 206', 944, off-normal springs to conductor 904, the winding of said selective device GL is disconnected at spring 201', conductor 934 being alternatively applied through the winding of relay 935 to the stepping magnet M9, armature 975 being attracted at this time. Upon the calling operator sending a series of fourteen impulses the armature 975 will consequently apply a corresponding number 60 65 of ground impulses through armature 933,

conductor 934, winding of relay 935 to said M9, stepping the wiper 204' in engagement with the fourteenth bank contact, armature 936 being attracted while the wiper 204' is stepping. When relay 205' actuates, its lower armature prepares a circuit path from the winding of selective device GL so when armature 936 attracts an impulse will be applied to selective device GL to open the contacts 202'. Following the last impulse to the magnet M9, armature 936 will retract and apply its ground over conductor 937, armature 938, wiper 204', engaged bank contact to the winding of relay 932, effective to apply the ringing current source G9 in bridge of wipers 908—909, as before set forth with relation to its functioning in code-switch H'9.

At the time armature 936 applies its ground over conductor 937 this ground is also applied through off-normal spring set ON9' (which operates on the off-normal movement of wiper 204') to energize release magnet Re9' to restore the wiper 204' and to the winding of relay 945 to open the locking ground from armature 206' so relay 205' will deactivate and re-connect the winding of said selective device GL in lieu of said M9. Thus, other linked code-switches may be effectively operated selectively without effectively operating irrelevant code-switches.

In this connection it will be clear that if after contact springs 202' are engaged, a series of eleven impulses are sent, ground will be applied from wiper 204' to wiper 905. If a series of twelve impulses are sent, ground will be applied from wiper 204' to the release magnet Re9. If a series of thirteen impulses are sent, ground will be applied from wiper 204', conductor 956 to the winding of relay 957.

Fig. 30 shows additional circuits in the preferred arrangement referred to with respect to Fig. 20, as introduced into Fig. 9, but not detailed therein. These additions contemplate introducing and excluding the repeating coil RC30 by sending a series of seventeen or eighteen impulses, respectively, after causing the springs of set 202' to engage, as set forth. Likewise, sending nineteen or twenty impulses, after causing the springs of set 202' to engage, will cause the speech amplifying repeater SR30 to be introduced or excluded, respectively. The calling device D10 has fourteen finger-holes, each hole indexing the number of impulses which will be sent by a corresponding setting. Of course, this number may be increased as desired, depending upon requirements of the equipments to be operated, it being twenty where Fig. 20 is employed.

In view of the detailing of Figs. 20 and 9 it is thought the functioning of Fig. 30 will be clearly understood from the following descriptions relating to bank contacts occupy-

ing the seventeenth to twentieth positions engageable to wiper 204', which latter wiper is caused to apply a ground to the bank contact engaged, and then restore upon its stepping being stopped. Upon the seventeenth bank contact being grounded, relay 220' will actuate and lock through armature 221' to conductor 904, thus introducing the repeating coil RC30 intermediate of conductors 818—819 and wipers 909—908. Grounding the eighteenth bank contact will cause relay 225' to actuate and thereby unlock relay 220', excluding the said RC30. Grounding the nineteenth bank contact will cause relay 227' to actuate and lock through armatures 228', 229' to conductor 904, thus introducing the speech amplifying repeater SR30 intermediate of conductors 818—819 and wipers 909—908. Grounding the twentieth bank contact will cause relay 230' to actuate and thereby unlock relay 227' excluding the said amplifying repeater SR30. It will be remembered that coincident to wiper 204' applying ground to an engaged bank contact, the relay 205' will unlock to disconnect the winding of relay 935 leading to magnet M9, so the wiper 204' cannot be thereafter driven until the contact springs 202' are reengaged. Thus, the operation of the relays 220', 225', 227' and 230', respectively, is dependent upon specific directive operation. However, a destroying of the connection antecedent to the selector H9, causing ground to be disconnected from conductor 904 will unlock any relays dependent upon conductor 904.

In the operation of the system incorporating the preferred code-switch involving Figs. 20 and 30 as set forth, when it is desired to directly operate a code-switch, a digit series of eleven or more impulses will be first sent to run-in any responsive terminating linking switch on its eleventh bank level, so as to not idly progress the call. The digits corresponding to the switching center of the concerned code-switch will then be sent, followed by the index series determining what function the said code-switch is to perform. Of course, it is not operatively necessary to first send the series to block the idle progression of the call, though it is desirable. In this connection it will appear that the first "digit" of a switching center may preferably be constituted of eleven or more impulses. That is, for example, in place of the designation being "357", it may be "12—5—7" the first series serving to run-in the terminating responsive linking switch on the eleventh bank level, as well as to set-up a preliminary condition in the selective device GL, as when "3" was the first effective series. Under the latter preferred plan, the first series effective to setting-up a preparatory condition in the selective device GL will also divert the remote extension of the call into a dead bank level or otherwise restrain it. The stepping

magnet M9 has an auxiliary armature 208' which applies ground impulses to conductor 373 in Fig. 3 so reverting impulses will be applied to operate the indicator M10 when the index series is sent. This assures the operator that the relay 205' operated and that the function indexed by the said index series will take place. The preferred modification of Fig. H'9 shown in Figs. 20 and 30 lends itself to the employment of the invention in temporarily interlinking telegraph lines directly, or where intelligence signals are transmitted after a talking circuit train has been directly established. This is because the various code-switches will not normally function responsive to all impulses transmitted, but only after a train of predetermined impulses specific to one of the concerned code-switches has been sent.

Fig. 11 as introduced into Fig. 10 shows a preferred modification of the latter said figure, an object of which is to prevent the calling device D10 employed by the calling operator in progressing a call from being set to send a successive impulse series, if the last series sent has not been normally effective. For example, if a selector is stepped into alignment with a bank level, but does not rotate-in to a trunk position, or rotates over all trunk positions, a locking pawl 101' in the calling device of the calling operator will not be moved out of its normal locking position with relation to the cam D'10 which is mounted on the same shaft as the finger-dial of the calling device D10.

In Fig. 11, a directive indicator M11 corresponds to M10, and a selective indicator M'11 corresponds to M'10 in Fig. 10. In M11, 102', 103', 105' correspond to MM2', Re2' and 201', respectively, and in M'11, 107', 108' and 109' correspond to 251'' and 253'', respectively. Wiper 110' normally rests upon bank contact 112', being driven over the cooperative bank contacts responsive to reverted impulses received through key spring 10'' when the calling device D10 is transmitting. The pointer 113' (corresponding to 203'') is attached to the shaft mounting wiper 110'. The pointer 113' thus indicates on the scale marking shown the position of the said wiper 110' which is obscured by the scale face. The off-normal spring set 114' operates upon the first off-normal movement of the wiper 110'.

The selective indicator M'11 will rotate its pointer 115' from impulses received through spring 10'', after the calling device D10 restores. The off-normal spring set 116' operates upon the first off-normal movement of the pointer 115'. The off-normal spring set 117' will operate from arm 118' when the pointer 115' rotates to the eleventh position.

The commutating device N11, mechanically similar to M11, is driven from locally transmitted impulses in multiple with relay

p10. It is thus clear that as directive impulses are applied from the calling device D10 through key spring 223' to relay p10 to directively operate the linking switches, for 5 example, reverting impulses are being sent from the respective operating switches effective to driving the wiper 110' and the pointer 113'. Since the slow-releasing series relay 120' and the stepping magnet 121' are 10 energized in multiple with relay p10, the wiper 122' and the pointer 123' will step in numerical correspondence with the impulse series sent from the calling device D10, the off-normal spring set 125' operating consequent to the first impulse being applied to the 15 magnet 121'. It is thus clear, that if the calling device D10 is set to transmit a digit series of three impulses and then released the wiper 122' will be stepped into engagement with bank contact 126'. If the selective switch being directively operated steps its wipers into alignment with the fourth bank level, four impulses will be thereby reverted through springs 10", 8", terminal 128', effective to stepping wiper 110' into engagement with the fourth bank contact 129'. The 20 calling device being now at normal, whereat spring 205" is disengaged from its cooperative spring, the release magnets 103' and 130' 25 are disabled against restoring wipers 110' and 122', respectively. At this time an operative circuit path can be traced from grounded off-normal spring 131', spring 132' to the winding of relay 133', thus attracting armature 134'. If the latter said selective switch rotates-in at the fourth level and selectively hunts, its rotary magnet will transmit reverting impulses through springs 211", 7", terminal 136', winding of relay 109' to the stepping magnet 107', the pointer 115' being 30 stepped correspondingly, in the manner as described with reference to selective indicator M'10. The pointer 115' thus indexes what set of bank contacts have been seized by the 35 latter said selective switch. Under the condition now ensuing spring 131' is free, which opens the energizing path for relay 133'. A circuit path can now be traced from the winding of the pawl magnet 138', key spring 139', 40 armature 134', wiper 110', bank contact 129', conductor 141', bank contact 126', wiper 122' to ground, the pawl 101' being thus attracted, permitting the calling device D10 to be set to transmit a succeeding series over the established 45 connection. If the spring 131' does not disengage due to the last switch directively operating not rotating-in, the relay 133' will remain actuated, to maintain the calling device D10 disabled. If the latter 50 said switch rotates in, but fails to find an idle set of bank contacts, and therefore, rotates off the tenth set, which means that eleven impulses have been transmitted back by the rotary magnet of the latter said switch, the 55 arm 118' will close contact set 117' to oper-

atively energize relay 133', in lieu of energizing said relay 133' from spring 131'.

It will be noted that while the calling device D10 is transmitting impulses, relay 120' 70 will remain actuated in a local impulse circuit. This will maintain the release ground open at armature 145', so none of the release magnets 103', 108' and 130' can be energized, though spring 205" is grounded on its companion spring. However, upon the calling 75 device restoring disengaging spring 205", the armature 145' retracts because of impulses through relay 120' ceasing, the release ground remaining open. When the calling device is thereafter set to send the succeeding impulse series, spring 205" becomes grounded so conductor 146' becomes grounded. The ground on conductor 146' is communicated through spring set 125', armature 148' to release magnet 130', operative to restore wiper 123'. The 80 ground on conductor 146' applied through spring 149', armature 150' operatively energizes release magnet 108' to restore pointer 115'. The ground on conductor 146' applied through spring 152', armature 153' operatively energizes release magnet 103' to restore wiper 110'.

Key 155' may be depressed to operatively energize magnet 138' to unlock the calling device if the lamp 156' (connected in multiple with magnet 138') does not glow to index that the pawl 101' has attracted. The key 155' will be required in the event a faulty condition has arisen wherein the wipers 110' and 122' have not stepped to corresponding bank contacts, and the pointer 115' has not progressed to indicate a set of bank contacts have been seized by the last switch directively operated. Under the latter condition the calling operator may desire to send an impulse 95 series to effect a partial release, or for other reasons, and unless the magnet 138' can be locally energized at will, the calling device D10 will remain locked so spring 205" cannot be grounded to restore the devices M11, 100 M'11 and N11. Of course, withdrawing plug S10 will open the sleeve at contact 160', so armature 161' will apply ground through spring 139' to energize the magnet 138', the key K10 being in an operated state. The key 162' may be depressed to energize the release 105 magnets 103', 108' and 130', if armature 145' is retracted and any of the spring sets 114', 116' and 125', respectively, are operated.

The corresponding bank contacts engageable to wipers 110' and 122' are electrically tied and all bank contacts from the twelfth to the seventeenth (or any greater number as may be employed in view of Fig. 20) are 110 mutually tied as shown, though they may be tied respectively, if desired.

In view of the descriptions if a local exchange connector as G15 is directively operated from calling device D10, the device M'11 130 will be caused to operate from the impulse

applied back consequent to the side switch-arm 530' passing over grounded contact 533' following the directive impulse series. This will cause spring 131' to disengage to disable 5 relay 133', so if wiper 110' has advanced corresponding to 122' the magnet 138' will be energized.

The keys 155' and 162' may be mounted as a unit with calling device D10, so the operator 10 will be able to depress one of the keys 155' or 162' and set the finger-hole plate with the same hand. Of course, the key 155' may be a mechanical trip as indicated by 165', so the pawl 101' may be disengaged from its locking 15 position by a direct mechanical operation.

The various so-called ringing current sources are preferably of a character to which a condenser is transparent, such as alternating, for example. Where the drawings show 20 ringing current sources applied directly to talking conductors of lines it will be understood that intermediate devices well known in the art, may be interposed to translate the character of ringing current for transmission over the line where other equipment not shown in the drawings may be interposed to re-translate the transmission current to the character to which the calling signal is susceptible.

25 It will be understood that selectors incorporating not only all the primarily disclosed devices and functions, but also, those disclosed in preferred and other modifications as well, may be employed cooperatively in a comprehensive system as contemplated in the present invention, wherein manifold special operating and traffic conditions are to be satisfied. Further, it is manifest that the devices of the invention, which have been shown 35 by way of example only, may be otherwise modified and varied without departing from the scope of the invention in view of the 40 claims.

I claim:—

45 1. In an automatic telephone system, a group of waiting group-selecting switches, a group of lines commonly accessible to the said switches, a group of group test contacts multiply accessible to each switch indicative if 50 all the lines of the group are busy as well as the number of switches in waiting relation thereto, independent test contacts multiply accessible to each switch corresponding to the individual lines of the group to indicate 55 their respective busy or idle state, means for operating the respective switches into testing engagement with the group test contact group, means for setting-up a successive order-of-access in the respective switches with 60 respect to the group being tested corresponding to the order in which the testing switches which have an order of access tested the group of group test contacts whereby when a line of the group becomes idle the switch having 65 the remotest antecedent order-of-access will

self-initiate its hunting operation with respect to the lines of the group and seize the first idle line tested, means for maintaining the order-of-access existing in the waiting switches until the hunting switch seizes an 70 idle line, means for restoring the hunting switch to its last waiting condition if it fails to find a disengaged line, and means for advancing the numerical order-of-access of each waiting switch by one order consequent upon 75 the hunting switch seizing.

2. In an automatic telephone system, a series of impulse circuit links in an established connection, automatic impulse senders at respective linking points for sending series 80 of impulses towards the calling end, the respective periods of sending being irrespective of other said senders, and impulse receiving means at each sending point responsive to impulses for disabling the senders at points 85 intermediate of the calling point and the point from which the sending is occurring whereby confusion between impulses sent by the various senders associated with a connection cannot occur.

90 3. In an automatic telephone system, a series of circuit links in an established connection, automatic impulse senders at respective linking points for sending series of impulses towards the calling end, another 95 circuit link normally having access to one of the links of the said connection, means for barring said other link from attaining connection to said one of the links of the connection, means operative upon the said other link becoming in connective relation to the said one of the links of the connection but barred therefrom to operate the sender at the linking point of the said one of the links and the next successive link, and means at 100 the antecedent linking points operated from the first sender to operate for disabling the sender at each said linking point intermediate of the calling end and the point from which the sending is occurring whereby confusion between the impulses sent towards the calling end by the various senders associated with the connection cannot occur.

105 4. In an automatic telephone system, a series of circuit links in an established connection, automatic impulse senders associated with the connection at respective linking points for sending series of impulses towards the calling end, a plurality of other circuit links normally having access to one 110 of the links of the said connection, means for barring said other links for attaining connection to said one of the links of the connection, means operative consequent upon the said other links becoming in connective relation to the said one of the links of the connection but barred therefrom to operate the sender at the linking point of the said one of the links and the next successive link, and means at 115 the antecedent linking points oper- 120 125 130

ated from the first sender to operate for disabling the sender at each said linking point intermediate of the calling end and the point from which the sending is occurring whereby confusion between impulses sent towards the calling end by the various senders associated with the connection cannot occur.

5. In an automatic telephone system, a series of circuit impulse links in an established 10 connection, automatic impulse senders at respective linking points for sending periodic series of impulses towards the calling end, a receiving device at the calling end to indicate the series of impulses sent to the calling end, 15 and impulse receiving means at each sending point for disabling the senders at points intermediate of the calling end and the point responsive to impulses from which the sending is occurring whereby confusion between 20 impulses sent by the various senders associated with a connection cannot occur.

6. In an automatic telephone system, a series of circuit impulse links in an established 25 connection, automatic impulses senders at respective linking points for sending periodic series of impulses towards the calling end, a receiving device at the calling end to indicate the series of impulses sent to the calling end, means for transmitting directive impulses out 30 from the calling end over the successive links in linking a connection to the remote end of the connection established, means at each said linking point operated by the impulses sent out from the calling end for disabling the 35 sender thereof for a predetermined period after the transmitting ceases from the calling end, and impulse receiving means at each sending point responsive to impulses for disabling the senders at points intermediate of 40 the calling end and the point from which the sending back is occurring whereby confusion between impulses sent by the various senders associated with a connection cannot occur.

7. In an automatic telephone system, a series of circuit impulse links in an established 45 connection, automatic impulse senders at respective linking points for sending periodic series of impulses towards the calling end, a receiving device at the calling end to indicate the series of impulses sent to the calling end, means for transmitting calling impulses out 50 from the calling end in linking a connection to the remote end of the connection established the said impulses being in series 55 greater than the number of impulses in a digit series, means at each said linking point operated by the impulses sent out from the calling end for disabling the sender thereof for a predetermined period after the transmitting 60 from the calling end ceases, and means at each sending point for controlling the senders at points intermediate of the calling end and the point from which the sending 65 back is occurring whereby confusion between

impulses sent by the various senders associated with a connection cannot occur.

8. In an automatic telephone system, a series of circuit links, linking switches terminating the far end of each of said links, operator control means for sending impulses from a calling station on the near end of a calling link to directly operate the successive switches to extend a connection to include a plurality of said links in tandem, impulse 70 means in the switches controlled by the operative movement of the connective element of the respective switches to revert impulses to the calling station, an indicator at the calling station responsive to the reverted impulses 75 to indicate the operation of the respective switches responsive to the said operator control means, a disabling mechanism in the operator's control means operative for disabling the latter said means against sending impulses, and means whereby if the indicator at the calling station does not operate correspondingly to the said operator's sending control means the said disabling mechanism will 80 become effective.

9. In an automatic switching system, a series of circuit links, a linking switch terminating the far end of each of said links, said switches having a directed primary movement to select a group and an automatic secondary movement to select an idle line of the group, operator controlled means for sending impulses from the calling station on the near end of a calling link to directly operate the successive switches in a primary direction to extend a connection to include a plurality of said links in tandem, impulse 95 means in the switches controlled by the operative movement of the connective element of the respective switches to revert impulses to the calling station responsive to the movement of the respective switches, an indicator at the calling station responsive to the reverted impulses to indicate the primary operation of the respective switches responsive to the said operator controlled means and the said automatic secondary movement of the respective switches, a disabling mechanism associated with the operator's control means for disabling the latter said means against sending, 100 and means whereby if the indicator at the calling station does not operate correspondingly to the said operator's sending control means and also operate from a secondary movement of the said element of the last switch directly operated the said disabling mechanism will become effective.

10. In an automatic switching system, a series of circuit links, a linking switch terminating the far end of each of said links, said switches having a directed primary movement to select a group and an automatic secondary movement to select an idle line of the group, operator control means for sending impulses from the calling station on the 105 110 115 120 125 130

- near end of a calling link to directively operate the successive switches in a primary direction to extend a connection to include a plurality of said links in tandem, impulse means in the switches controlled by the operative movement of the connective element of the respective switches to revert impulses to the calling station responsive to the movement of the respective switches, an indicator at the calling station responsive to the reverted impulses to indicate the primary operation of the respective switches responsive to the said operator control means and the said automatic movement of the respective switches, a disabling mechanism associated with the operator's control means for disabling the latter said means against sending, and means whereby if the indicator at the calling station does not operate correspondingly to the said operator's control means and also operate from a secondary movement wherein an extension of the connection is effected to a successive link the said disabling mechanism will become effective.
11. In an automatic switching system, a series of circuit links, a linking switch terminating the far end of each of said links, said switches having a directed primary movement to select a group and an automatic secondary movement to select an idle line of the group, operator control means for sending impulses from the calling station on the near end of a calling link to directively operate the successive switches in a primary direction to extend a connection to include a plurality of said links in tandem, impulse means in the switches controlled by the operative movement of the connective element of the respective switches to revert impulses to the calling station responsive to the movement of the respective switches, an indicator at the calling station responsive to the reverted impulses to indicate the primary operation of the respective switches responsive to the said operator control means and the said automatic secondary movement of the respective switches, a disabling mechanism associated with the operator's control means for disabling the latter said means against sending, and means whereby if the indicator at the calling station does not operate correspondingly to the said operator's sending control means and if the last switch directly operated fails to find an idle line upon effecting the secondary movement the said disabling mechanism will become effective.
12. In an automatic switching system, a series of impulse links, said impulse links comprising a single conductive path and being of a character enabling impulses to be simultaneously sent in opposite directions thereover without interference, a linking switch terminating the far end of each of said links, operator control means for sending impulses from a calling station on the near end of a calling link to directively operate the successive switches to extend an operating connection to include a plurality of said links in tandem, an impulse repeating mechanism between the connected impulse links so that impulses can be sent from the calling station and repeated from the calling link to the second and to each successive link of the connection successively and so that impulses can be sent from the remotest link in a connection and be repeated through the said repeating mechanism at each linking point to operate a receiving mechanism at the calling station, impulse means in the switches controlled by the operative movement of the switches respectively to revert impulses to operate said receiving mechanism, a disabling mechanism in the operator's control means controlled by the said receiving mechanism for disabling the operator's control means against sending impulses, and means whereby if the said receiving mechanism does not operate in correspondence with the operator's control means the said disabling mechanism will become effective.
13. In an automatic switching system, a series of impulse links and companion talking links, said impulse links comprising a single conductive path and being of a character enabling impulses to be simultaneously sent in opposite directions thereover without interference, a linking switch terminating the far end of each of said pair of links, operator control means for sending impulses from a calling station on the near end of a calling link to directively operate the successive switches to extend a talking connection to include a plurality of said pairs of links in tandem, an impulse repeating mechanism between the connected impulse links so that impulses can be sent from the calling station and repeated from the calling link to the second and to each successive link of the connection successively and so that impulses can be sent from the remotest link in a connection and be repeated through the said repeating mechanism at each linking point to operate a receiving mechanism at the calling station, impulse means in the switches controlled by the operative movement of the switches respectively to revert impulses to operate said receiving mechanism, a disabling mechanism in the operator's control means controlled by the said receiving mechanism for disabling the operator's control means against sending impulses, and means whereby if the said receiving mechanism does not operate in correspondence with the operator's control means the said disabling mechanism will become effective.
14. In an automatic telephone system, a plurality of circuit links each terminating in a switch, an operator controlled sending means at the calling station on a calling one of said links for directively extending a con-

nection to include a plurality of said links in a tandem connection, one of the said switches being of the group selecting type wherein upon it being operated into selective relation to a group of lines it will thereupon automatically self-function to select and seize an idle one of said lines of the group by way of extending the said connection to the first idle line of the group selected, a step-by-step indicator mechanism at the calling station operated by impulses sent back over the calling link after the connection to the said idle line is effected, means associated with the said group of lines which will operate to transmit impulses when all the lines of said group are busy, and means for applying the latter said impulses effective to the indicator mechanism.

15. In an automatic telephone system, a plurality of circuit links each terminating in a switch, an operator controlled sending means at the calling station on a calling one of said links for directly extending a connection to include a plurality of said links in a tandem connection, one of said switches being of the group selecting type wherein upon it being operated into selective relation to a group of lines it will thereupon automatically self-function to select and seize an idle one of said lines of the group by way of extending the said connection, the latter said switch being barred against operating in the said self-function manner to select if all the lines of the group are busy but will be disabled until a line of the selected group becomes idle whereupon it will selectively operate, a step-by-step indicator at the calling station of each said busy line operated by impulses sent back over each of the calling links, means associated with the said group of lines for transmitting impulses, and means for applying the latter said impulses effective to the indicators when a said switch is barred in a waiting condition with reference to the said line group.

16. In an automatic telephone system, a plurality of circuit links each terminating in a switch, an operator controlled sending means at a calling station on a calling one of said links for directly extending a connection to include a plurality of said links in a tandem connection, one of said connected links being one of a group of lines, and means associated with said group of lines which will operate to transmit a signal to the calling station when all the lines of the said group are busy.

17. In an automatic switching system, a plurality of circuit links each terminating in a switch, an operator controlled sending means at a calling station on a calling one of said links for directly extending a connection to include a plurality of said links in a tandem connection, one of said connected links being one of a group of lines, a switch

accessible to said group of lines, means to hold the switch in a waiting position barred from selecting if operated into selective relation to the group if all the lines of the group are busy, and means associated with the said group of lines which will operate to transmit a signal to the calling station consequent upon the switch becoming in waiting relation to the said line group.

18. In an automatic telephone system, a trunk line leading to a group-selecting switch, a group of lines accessible to said switch, a group busy-test contact, busy-test contacts individual to each said line, said busy-test contacts selectively accessible to the switch, means for setting said switch into testing relation with said group whereby the switch will thereafter first test the group busy-test contact and then successively test the said individual line busy-test contacts and seize the first idle line thereof if the group busy-test contact does not index a busy condition of all the lines of the group and which will assume a waiting condition by being barred from testing beyond the group busy-test contact if the group busy-test contact indexes a busy state of all the lines of the group, means whereby if the switch when selectively testing the individual lines of the group fails to find an idle line it will restore to its testing engagement with the group busy-test contact and become barred from testing or will retest for an idle line of the group depending upon if the lines of the group are then all busy or not all busy respectively, an operator's jack leading to a set of normally falsely busy line and busy-test terminals positioned to be tested after the lines of the group are tested, an operator's plug, and means whereby if the switch is in a said waiting condition and the said plug is introduced into the said jack the switch will forthwith selectively test over all the lines of the group regardless of the busy or idle condition when tested and test and seize the set of terminals corresponding to the said jack.

19. In an automatic telephone system, a trunk line leading to a group-selecting switch, a group of lines accessible to said switch, a group busy-test contact, busy-test contacts individual to each said line, said busy-test contacts selectively accessible to the switch, means operated over the trunk for directly setting said switch into testing relation with said group whereby the switch will thereafter first test the group busy-test contact and then successively test the said individual line busy-test contacts and seize the first idle line thereof if the group busy-test contact does not index a busy condition of all the lines of the group and which will assume a waiting condition by being barred from testing beyond the group busy-test contact if the group busy-test contact indexes a busy state of all the lines of the group, means whereby

if the switch when selectively testing the individual lines of the group fails to find an idle line it will restore to its testing engagement with the group busy-test contact and become barred from testing or will retest for an idle line of the group depending upon if the lines of the group are then all busy or not all busy respectively, an operator's jack leading to a set of normally falsely busy line and busy-test terminals positioned to be tested after the lines of the group are tested, an operator's switching cord and plug associated with an operator's telephone set, and means whereby if the switch is in a said waiting condition and the said plug is introduced into the said jack the switch will forthwith selectively test over all the lines of the group regardless of the busy or idle condition when tested and test and seize the set of terminals corresponding to the said jack whereby the operator's telephone set will be in talking relation with the trunk talking conductors.

20. In a circuit linking system, a calling station, a plurality of circuit links, a linking switch terminating the far end of each said link, a code switch companion to each of said switches, the said code switches operating coincidently with operating a succeeding terminating switch of a connection, the said code switches for altering the circuits associated with their companion said switch, a control device at the calling station for directly operating the linking switches successively to interlink a series of the circuit links and to also operate certain ones of the said code switches coincidently from the same control circuit path, and means whereby any one of the code switches of the connection can be effectively operated directly from the calling station without idly progressing the call beyond the last linking switch of the connection then existing.

21. In a circuit linking system, a calling station, a plurality of circuit links, a linking switch terminating the far end of each said link, a code switch companion to each of certain of said switches, the said code switches operating coincidently with operating a succeeding terminating switch of a connection, the said code switches for altering the circuits associated with their companion said switch, a control device at the calling station for directly operating the linking switches successively to interlink a series of the circuit links and to also operate certain ones of the said code switches coincidently from the same control circuit path, means whereby any one of the code switches of the connection can be effectively operated directly from the calling station without idly progressing the call beyond the last linking switch of the connection then existing, and means whereby the call can thereafter be effectively progressed from the said last linking switch to

further progress the call under directive control of the calling station.

22. In a circuit linking system, a calling station, a plurality of circuit links, a linking switch terminating the far end of each of said links, a pair of directive switches companion to each of certain of said linking switches, a first one of said pair of directive switches being normally non-operative, the second one of said pair of directive switches operating coincidently with a succeeding linking switch of a connection, the said second switch for effecting the operative connection of the said first switch with its companion link, the said first switch for altering the circuits associated with its companion linking switch, an impulse control device at the calling station for directly operating the linking switches successively to extend a connection including a plurality of said circuit links in tandem, and means whereby any desired said first code switch can also be operated under directive control of the said impulses of the said control device.

23. In a circuit linking system, a calling station, a plurality of circuit links, first and second code switches associated with each said link, a control device at the calling station for directly operating the switches, the first said switch being normally non-operative, the second said switch for connecting the first said switch into operative relation to the corresponding link, and means whereby operating the control device in a predetermined manner will effectively operate the second said switch whereby the first said switch will thereupon be responsive to the control device.

24. In a circuit linking system, a calling station, a circuit link, a linking switch for the link, first and second code switches companion to said link, a control device at the calling station for directly operating the switches, the first said code switch being normally non-operative, the second said code switch for connecting the first said code switch into operative relation to the corresponding link, means whereby operating the control device in a predetermined manner will effectively operate the second said code switch whereby the first said code switch will thereupon be responsive to the control device, and means for thereafter at will operating the first code device by the control device.

25. In an impulse circuit, a calling station; first and second code switches companion to the circuit, a linking switch for extending the impulse circuit, a control device at the calling station for directly operating the switches, the first said switch being normally non-operative, the second said code switch for connecting the first said switch into operative relation to the corresponding link, means whereby operating the control device in a predetermined manner will effectively

operate the second said code switch whereby the first said code switch will thereupon be responsive to the control device, and means for thereafter at will operating the first code device by the control device.

5 26. The combination of a line, a first and a second step-by-step switch associated with the remote end of the said line, a directive device on the near end of the line, the directive device for operating the first switch controlled over the line, the first switch responsive to each directive operation of the directive device and thereupon restoring to normal, the said second switch not being normally operatively connected to the line, a predetermined operation of the first switch which will effect the connection of the second switch into operative relation with the line subject to directive control of the directive device and cause the said first switch to restore to normal thereupon responsive to the directive device, and means whereby then operating the directive device will thereupon directly operate said second switch and the said first switch.

25 27. The combination of a line, a first and a second step-by-step switch associated with the remote end of the said line, a directive device on the near end of the line, the directive device for operating the first switch controlled over the line, the first switch responsive to each directive operation of the directive device and thereupon restoring to normal, the said second switch not being normally operatively connected to the line, a predetermined operation of the first switch which will effect the connection of the second switch into operative relation with the line subject to directive control of the directive device and cause the said first switch to restore to normal thereupon responsive to the directive device, means whereby then operating the directive device will thereupon directly operate said second switch and the said first switch, and means whereby thereafter directly operating the first switch in a predetermined manner controlled by the directive device will cause the said second switch to be disconnected from operative connection with the line.

50 28. The combination of a line, a first and a second step-by-step switch associated with the line, a directive device on the line for operating the first switch responsive to each directive operation of the directive device the said first switch restoring to normal thereafter, the said second switch not being normally operatively connected to the line, an indicating device at the station at which the directive device is located operated over the line from the said second switch in correspondence with its operative movement, a predetermined operation of the first switch which will effect the connection of the second switch into operative relation with the

line subject to directive control of the directive device and cause the said first switch to restore to normal thereupon responsive to the directive device, means whereby again operating the directive device will directly operate the said first switch and the said second switch, and means whereby the said indicating device will operate correspondingly responsive to the operation of the second switch.

75 29. The combination of a line, a first and a second step-by-step switch associated with the line, a directive device on the line for operating the first switch responsive to all directive operations of the directive device the said first switch restoring to normal thereafter, the said second switch not being normally operatively connected to the line, an indicating device at the station at which the directive device is located operated over the line from the said second switch in correspondence with its operative movement, a predetermined operation of the first switch which will effect the connection of the second switch into operative relation with the line subject to directive control of the directive device and thereafter cause the said first switch to restore to normal responsive to the directive device, and means whereby again operating the directive device, will directly operate the said second switch and the indicating device correspondingly.

80 30. In a telephone system, a group of two-direction switching lines, a switch bank at each end of the group into which the lines of the group terminate, respective switches accessible to the line group through a companion said bank for extending a connection over an idle line of the group to the respective opposite end, the lines of the group being tested successively and the first idle line thereof seized by the switch operated into selective relation to the group, and means for disposing of the lines of the group at the switch banks so that the lines of the group will have a predetermined order of preference depending upon which terminus of the group is the originating end.

85 31. In a telephone system, a calling station, a calling line leading from the said station, a selecting switch at the far end of the line from the calling station, a directive device at the calling station, a signal lamp at the calling station, a mechanism for closing an energizing circuit for the lamp controlled over the line from the switch, the switch operating the said mechanism in accordance with its operative movement in testing lines successively, a group of called lines accessible to the switch, means for operating the switch by the directive device to set the switch into selective relation with the called line group whereby it will forthwith successively test the individual lines of the group and seize the first idle line or successively test all the lines

- of the group and disengage from the last one thereof and rotate to a predetermined position, and means whereby if the switch tests all the lines of the group and finds them busy the said mechanism will energize the lamp.
32. In a telephone system, a calling station, a calling line leading from the station, a switch at the far end of the line from the calling station, a directive device at the calling station, a lamp at the calling station, a called line, means for operating the switch by the directive device to set the switch into selective relation with the called line whereby it will be seized if idle and not seized if busy, and means responsive to a plurality of impulses applied thereto to then cause the lamp to glow indicative that the line is busy.
33. In a telephone system, a calling station, a calling line leading from the station, a selecting switch at the far end of the line from the calling station, a directive device at the calling station, a lamp at the calling station, a group of called lines, means for operating the switch by the directive device to set the switch into selective relation with the called line group whereby it will forthwith selectively test the individual lines of the group and seize the first idle line thereof or successively test all the lines of the group and disengage from the last one thereof, and means responsive to a plurality of impulses applied thereto for causing the lamp to glow if all the lines of the group were found busy when tested.
34. In a telephone system, a calling station, a calling line leading from the calling station to a stepping switch, an impulse directive device at the calling station for step operating the switch responsive to each impulse of the directive device, an indicator at the calling station, a sending device in the switch for sending impulses effective to the indicator, the sending device operating in correspondence with the step movement of the switch, means whereby operating the directive device will correspondingly operate the indicator, and means to retain the indicator in its operated position.
35. In a telephone system, a calling station, a calling line leading from the calling station to a stepping switch, an impulse directive device at the calling station for step operating the switch responsive to each impulse of the directive device, an indicator at the calling station, a sending device in the switch for sending impulses effective to the indicator, the sending device operating in correspondence with the step movement of the switch, means whereby operating the directive device will correspondingly operate the indicator, and means to retain the indicator in its operated position.
36. In a telephone system, a calling station, a calling line leading from the calling station to a stepping switch, a directive device at the calling station which can be set for operating the switch, an indicator at the calling station, a sending device in the switch for sending impulses effective to the said indicator, the sending device operating in correspondence with the step movement of the switch, means whereby operating the directive device will correspondingly operate the indicator, means to retain the indicator in its operated position, and means controlled consequent to again setting the directive device whereby the operated condition of the indicator will be effaced.
37. In a telephone system, a calling station, a calling line leading from the calling station to a stepping switch, a directive device at the calling station for operating the switch directly to effect a primary movement after which the switch will automatically self-function in effecting a secondary movement whereby it will selectively seek an idle line of a group, a first and a second indicator at the calling station, sending devices in the switch for sending impulses effective to the first indicator and thereafter to the second indicator responsive to the primary step operation and the successive secondary operation of the switch, means for retaining the indicators in their operated positions, and means whereby operating the directive device to operate the switch in a primary movement and the second indicator to indicate what position the switch has taken in the secondary movement.
38. In a telephone system, a calling station, a calling line leading from the calling station to a stepping switch, a directive device at the calling station which can be set for operating the switch directly to effect a primary movement after which the switch will automatically self-function in effecting a secondary movement whereby it will selectively seek an idle line of a group, a first and a second indicator at the calling station, sending devices in the switch for sending impulses effective to the first indicator and thereafter to the second indicator responsive to the primary step operation and the successive secondary operation of the switch, means for retaining the indicators in their operated positions, means whereby operating the directive device to operate the switch in a primary movement will cause the first indicator to indicate the position taken by the switch in the primary movement and the second indicator to indicate what position the switch has taken in the secondary movement, and means to restore the indicators at will consequent to setting the directive device thereafter.
39. In a telephone system, a calling station, a calling line leading from the calling station, a selecting switch at the far end of the

- line from the calling station, a directive device at the calling station for operating the switch, a locking device at the calling station operative to disable the directive device, an impulse device in the switch operated in correspondence with the movement of the switch for controlling a mechanism at the calling station to render effective the locking device, and means whereby if the switch does not operate in correspondence with the operation of the directive device the directive device will thereupon become disabled. 40. In a telephone system, a calling station, a calling line leading from the calling station, a selective switch at the far end of the line from the calling station, the said switch being operative directly primarily and then automatically secondarily to select an idle line of a group, a directive device at the calling station for directively operating the switch, a locking device at the calling station operative to disable the directive device, an impulse device in the switch operated in correspondence with the movement of the switch for controlling a mechanism at the calling station to render effective the locking device, and means whereby if the switch does not correspondingly respond to the directive device and thereafter automatically select an idle line of the group the directive device will thereupon become locked against operation. 41. In a telephone system, a calling station, a line leading from the calling station to a switch, an operator's switching circuit at the calling station for connection to the line, an effectively disconnected tone source in the switch for application to the line, a directive device at the calling station for controlling the operation of the switch, and means in the switch operative consequent upon connecting the said circuit to the line for effecting the application of the tone source to the line audible in the said circuit. 42. In a telephone system, a calling station, a line leading from the calling station to a switch, an operator's circuit at the calling station for connection to the line, an effectively disconnected tone source in the switch for application to the line, a directive device at the calling station for controlling the operation of the switch, means in the switch operative consequent upon connecting the said circuit to the line for effecting the application of the tone source to the line audible in the said circuit, and means controlled by the directive device to disconnect the tone source. 43. In a circuit linking system, a balanced artificial line duplex control circuit, a switch at the remote end of the circuit, a permanently organized simultaneous two-way impulse-repeater at the near end of the line, the said repeater including one end of the said duplex circuit equipment as a portion thereof, 60 said repeater being normally disabled due to an energizing circuit thereof being open, and means operated consequent to seizing the line through the repeater for closing the said energizing circuit whereby impulses may be transmitted simultaneously in opposite directions through the junction effected by the seizure. 44. In a telephone system, a group of lines, a plurality of calling lines each extended to a switch having an attained order of access to the group depending upon the numerical order in which the switches were set into selective relation with the group, a predetermined number of switches being enabled to attain an order of access upon being respectively set in selective relation to the group, after which any switch set with relation to the group will be barred from thereafter connecting to a line of the group, and means for thereupon disabling the said barred switch from affecting the condition of the group regardless of the fact it may be left in its set condition as when it became barred. 45. In a telephone system, a group of lines, a plurality of calling lines each extended to a switch having an order of access to the group, a predetermined number of switches being enabled to attain an order of access upon being respectively set with relation to the group, after which any switch set with relation to the group will be barred from thereafter connecting to a line of the group, and means for thereupon disabling the said barred switch from affecting the condition of the group regardless of the fact it may be left in its set condition as when it became barred. 46. In a circuit linking system, a calling station, a plurality of line links each terminating in a linking switch at its far end, a directive device at the calling station for successively operating the switches to connect the line links in tandem, a code switch mechanism associated with each said linking switch and responsive to said directive device, a plurality of local circuits of each said code switch, means whereby any one of said plurality of local circuits can be directively operated by operating the directive device in a corresponding manner after the circuit links are connected in tandem, and means whereby again operating the directive device in a like predetermined manner will destroy the operated state of the corresponding local circuit. 47. In a circuit linking system, a calling station, a plurality of line links each terminating in a linking switch at its far end, a directive device at the calling station for successively operating the switches to connect the line links in tandem, a code switch mechanism associated with each said linking switch and responsive to said directive device, a plurality of local circuits of each said code switch, means whereby any one of said plurality of local circuits can be directly operated by operating the directive device in a corresponding manner after the 120 125 130

circuit links are connected in tandem, and means whereby again operating the directive device in a like predetermined manner will destroy the operated state of the corresponding local circuit regardless of other local circuits which may have been operated and maintained either before or after the initial operation of the said destroyed operated state.

48. In a telephone system, a calling station, a plurality of line links each terminating in a linking switch at its far end, a directive device at the calling station for successively operating the switches to connect the line links in tandem extending from the calling station, a code switch mechanism associated with each linking switch and responsive to the said directive device, a jack and a telephone set for connection to the jack at each linking point contiguous to the linking switch thereat for connection to the tandem line, a call signal device companion to the jack, and means whereby operating the directive mechanism in a predetermined manner with respect to any specific said jack will operate the companion call signal.

49. In a telephone system, a calling station, a plurality of line links each terminating in a linking switch at its far end, a directive device at the calling station for successively operating the switches to connect the line links in tandem extending from the calling station, a code switch mechanism associated with each linking switch and responsive to the said directive device, a jack and a telephone set for connection to the jack at each linking point contiguous to the linking switch thereat for connection to the tandem line, a call signal device companion to the jack, and means whereby operating the directive mechanism in a predetermined manner with respect to any specific said jack will operate the companion call signal without destroying the established connection.

50. In a telephone system, a calling station, a plurality of line links each terminating in a linking switch at its far end, a directive device at the calling station for successively operating the switches to connect the line links in tandem, a specific tone source associated with each switch, and means whereby operating the directive device in a predetermined manner causes the switch on the remotest link connected to apply the tone thereon audible to the calling station to identify the said last switch on the remotest link.

51. In a telephone system, a calling station, a first toll line link having access to a second toll line link and also having access to a local line link, a directive device at the calling station for operating the switch to extend a connection from the first toll line link to either the second toll line link or the local line link at will, means for sending a specific series of directive control impulses

over the said first toll line link after a said connection is established, means to disconnect the said switch from the said local line link, means to apply signaling current to the said second toll line link, and means depending upon whether the said first toll line link is connected to the said second toll line link or the said local line link to apply the signaling current to the said second toll line link or disconnect the said switch from the local line link respectively when the said specific series of control impulses is sent.

52. In a telephone system, a calling station, a plurality of line links each terminating in a linking switch at its far end, a directive device at the calling station for successively operating the switches to connect the line links in tandem, a code switch mechanism associated with each linking switch and responsive to the said directive device, a repeating coil and a speech amplifying repeater respectively associated with each linking switch and its associated code switch mechanism, means whereby after the directive device is operated to connect the line links in tandem the said directive device can then be operated in a predetermined manner to effectively operate any code switch mechanism of the connection to introduce either the repeating coil or the speech amplifier at any linking point at will, and means whereby the directive device can be thereafter operated to exclude the said introduced element without destroying the established connection.

53. In a telephone system, a calling station, a plurality of line links each terminating in a linking switch at its far end, a directive device at the calling station for successively operating the switches to connect the line links in tandem, a code switch mechanism associated with each linking switch and responsive to the said directive device, a repeating coil and a speech amplifying repeater respectively associated with each linking switch and its associated code switch mechanism, means whereby after the directive device is operated to connect any of the line links in tandem the said directive device can then be operated in a predetermined manner to effectively operate any code switch mechanism of the connection to introduce either the repeating coil or the speech amplifier at any linking point at will, and means whereby the directive device can be thereafter operated as before when introducing the said element to exclude the said introduced element without destroying the established connection.

54. In a telephone system, a calling station, a plurality of line links each terminating in a linking switch at its far end, a directive device at the calling station for successively operating the switches to connect the line links in tandem, a code switch mechanism associated with each linking switch and

responsive to the said directive device, a repeating coil and a speech amplifying repeater respectively associated with each linking switch and its associated code switch mechanism, means whereby after the directive device is operated to connect any of the line links in tandem the said directive device can then be operated in a predetermined manner to effectively operate any code switch mechanism of the connection to introduce either or both the repeating coil and speech amplifier at any linking point at will, and means including the directive device to exclude any specific introduced element without other exclusion.

55. In a telephone system, a calling station, a plurality of line links each terminating in a linking switch at its far end, a directive device at the calling station for successively operating the switches to connect the line links in tandem, a code switch mechanism associated with each linking switch and responsive to the said directive device, a plurality of circuits respectively associated with each linking switch and its associated code switch mechanism, means whereby after the directive device has been operated to connect any of the links in tandem the said directive device can then be operated in a predetermined manner to effectively operate any code switch mechanism of the connection to affect a directed one of the said plurality of circuits at any directed linking point at will, and means whereby the directive device can be thereafter operated as before when affecting the said circuit to restore the said affected circuit directly without otherwise affecting the connection.

56. In a telephone system, a calling station, a plurality of line links each terminating in a linking switch at its far end, a directive device at the calling station for sending a predetermined one type of impulses, said device for successively operating the switches to connect the line links in tandem, a code switch mechanism associated with each linking switch and responsive to the impulses of the directive device, a plurality of circuits respectively associated with each linking switch and its associated code switch mechanism, means whereby after the directive device has been operated to connect any of the links in tandem the said directive device can then be operated in a predetermined manner to effectively operate any code switch mechanism of the connection to affect a directed one of the said plurality of circuits at any directed linking point at will, and means whereby the directive device can be thereafter operated as before when affecting the said circuit to restore the said affected circuit directly without otherwise affecting the connection.

57. The combination of a line, a first and a second step-by-step switch associated with

the line, a directive device on the line for operating the first switch responsive to all directive operations of the directive device the said first switch restoring to normal thereafter, the said second switch not being normally operatively connected to the line, an indicating device at the station at which the directive device is located operated over the same conductor as the said first switch and in correspondence with the operative movement of the said second switch operated by the said second switch, a predetermined operation of the first switch which will effect the connection of the second switch into operative relation with the line subject to directive control of the directive device and thereafter cause the said first switch to restore to normal again responsive to the directive device, and means whereby again operating the directive device will directly operate the said second switch and the indicating device correspondingly.

58. The combination of a line, a first and a second step-by-step switch associated with the line, a directive device on the line for operating the first switch responsive to all directive operations of the directive device the said first switch restoring to normal thereafter, the said second switch not being normally operatively connected to the line, a predetermined operation of the first switch which will effect the connection of the second switch into operative relation with the line subject to directive control of the directive device, and means whereby again operating the directive device will directly operate the said second switch.

59. In an automatic telephone system, a trunk line leading to a group-selecting switch, a group of lines accessible to the switch, a group busy-test contact, busy-test contacts individual to each said line, said busy-test contacts being selectively accessible to the switch, means for setting said switch into testing relation with said group whereby the switch will thereafter first test the group busy-test contact and then successively test the said individual line busy-test contacts and seize the first idle line thereof if the group busy-test contact does not index a busy condition of all the lines of the group and which will assume a waiting condition by being barred from testing beyond the group busy-test contact if the group busy-test contact indexes a busy state of all the lines of the group, an operator's jack leading to a set of falsely busy line and busy-test terminals, an operator's plug, and means whereby if the switch is in a said waiting condition and the said plug is introduced into the said jack the switch will forthwith selectively test for and seize the set of terminals corresponding to the said jack.

60. In an automatic telephone system, a calling line leading to a linking switch, a busy

called line normally accessible from the switch but barred therefrom because of its busy condition, an operator's jack also accessible from the switch but normally barred therefrom, an operator's plug, and means whereby applying the plug into the jack will cause the switch to thereupon extend the calling line to the jack.

61. In an automatic telephone system, a trunk line leading to a group-selecting switch, a group of lines accessible to the switch, a group busy-test contact, busy-test contacts individual to each said line, said busy-test contacts being selectively accessible to the switch, means for setting said switch into testing relation with said group whereby the switch will thereafter first test the group busy-test contact and then successively test the said individual line busy-test contacts and seize the first idle line thereof if the group busy-test contact does not index a busy condition of all the lines of the group and which will assume a waiting condition by being barred from testing beyond the busy-test contact for the group if the group busy-test contact indexes a busy state of all the lines of the group, an operator's jack leading to a set of falsely busy line and busy-test terminals, an operator's plug and associated telephone, and means whereby if the switch is in a said waiting condition and the said plug is introduced into the said jack the switch will forthwith selectively test for and seize the set of terminals corresponding to the said jack whereupon the said telephone will be in talking relation to the said trunk line.

62. In an automatic telephone system, a calling line leading to a linking switch, a busy called line normally accessible from the switch but barred therefrom because of its busy condition, an operator's jack also accessible from the switch but normally barred therefrom, an operator's plug and telephone, and means whereby applying the plug into the jack will cause the switch to thereupon extend the calling line to the said telephone.

63. In a telegraph system, a plurality of circuit links, a linking switch at the remote end of each link operated from the near end thereof, a directive device at a calling station on one of the links for sending impulses over an impulse path for controlling the switches to interlink a plurality of said links in a tandem connection to a called station, an impulse device at the calling station for sending telegraph signals over the impulse path, a telegraph receiver at the called station associated with the impulse path and responsive to the said impulse device, and means whereby after a connection is interlinked to the called station the impulse device can be operated to correspondingly affect the said receiver.

64. In a telegraph system, a plurality of circuit links, a linking switch at the remote

end of each link operated from the near end thereof, a directive device at a calling station on one of said links for sending impulses over an impulse path for successively controlling the switches to interlink a plurality of said links in a tandem connection to a called station, an impulse device at each the calling and the called stations for sending telegraph signals, a telegraph receiver at each the calling and the called stations associated with the impulse path and responsive to the respective opposite said impulse device, and means whereby after a connection is interlinked to the called station either said impulse device can be operated to affect the opposite said receiver.

65. In an automatic telephone system, a plurality of circuit links each terminating in a switch, an operator controlled sending means at the calling station on a calling one of said links for directly extending a connection to include a plurality of said links in a tandem connection, one of said switches being of the group selecting type wherein upon it being operated into selective relation to a group of lines it will thereupon automatically self-function to select and seize an idle one of said lines of the group by way of extending the said connection to the first idle line of the group selected, a step-by-step indicator mechanism at the calling station operated by impulses sent back over the calling link after the connection to the said idle line is effected, an indicator companion to the indicator mechanism operated responsive to a predetermined step operation of the indicator, means associated with the said group of lines which will operate to transmit impulses when all the lines of said group are busy, and means for applying the latter said impulses effective to the indicator mechanism to thereby operate the indicator.

66. In a telephone system, a calling line, a plurality of accessible lines in a group, switch mechanism, means for operating the switch mechanism for extending a connection from the calling line to an idle line of the group, and a signal device controlled over the calling line for indicating when all the lines of the group become busy after said connection is effected.

67. In a telephone system, a calling line, a plurality of accessible lines in a group, switch mechanism, means for operating the switch mechanism for extending a connection from the calling line to an idle line of the group, a signal device on a random line of the group, and means controlled over said random line for operating said indicator responsive to said connection being effected to the only idle line of the group.

68. In a telephone system, a calling line, a plurality of accessible lines in a group, switch mechanism, means for operating the switch

mechanism for extending a connection from the calling line to the group, automatically applied means for selecting an idle line of the group and for extending the calling line thereto, means for barring the extending of said connection if no line of the group is idle, a signal device on a random line of the group, and means controlled over said random line for operating said indicator responsive to said connection being extended to the group and wherein the extending of the calling line to a line of the group is barred.

69. In a telephone system, a calling station, a stepping switch, an operating conductor leading from the calling station to the stepping switch, an impulse directive device at the calling station which can be set for step-operating the switch over said conductor responsive to each impulse of the directive device, a sending device in the switch for sending impulses over said conductor, the sending device operating in correspondence with the step movement of the switch, an indicator at the calling station responsive to each impulse of said sending device, means including said conductor and said switch whereby operating the directive device will correspondingly operate the indicator, means to retain the indicator in its operated position, and means controlled incident to again setting the directive device for effacing the operated condition of the indicator.

70. In a telephone system, a calling station, a stepping switch, an operating conductor leading from the calling station to the stepping switch, an impulse directive device at the calling station which can be set for step-operating the switch over said conductor responsive to each impulse of the directive device, a sending device in the switch for sending impulses over said conductor, the sending device operating in correspondence with the step movement of the switch, an indicator at the calling station responsive to each impulse of said sending device, means including said conductor and said switch whereby operating the directive device to send impulses will coincidentally operate the indicator by repeated said impulses, means to retain the indicator in its operated position, and means controlled incident to again setting the directive device for effacing the operated condition of the indicator.

71. In a telephone system, a calling station, a stepping switch, an operating conductor leading from the calling station to the stepping switch, an impulse directive device at the calling station which can be set for step-operating the switch over said conductor responsive to each impulse of the directive device, a sending device for sending impulses over said conductor, the sending device operating responsive to the step movement of the switch, an indicator at the calling station,

means including said switch whereby sending impulses over the operating conductor from the calling device in one direction will cause said impulses to be repeated over said conductor in the opposite direction to step-operate the indicator in correspondence with the impulses sent from the directive device, means to retain the indicator in its operated position, and means controlled incident to again setting the directive device for effacing the operated condition of the indicator.

72. In a telephone system, a calling station, a calling line leading from the calling station, a selecting switch at the far end of the line from the calling station, a directive device at the calling station for operating the switch, a locking device at the calling station operative to disable the directive device, and means whereby if the switch does not operate in correspondence with the operation of the directive device the directive device will thereupon become disabled.

73. In a telephone system, a calling station, a calling line leading from the calling station, a selecting switch at the far end of the line from the calling station, an impulse directive device at the calling station for operating the switch, a locking device at the calling station operative to disable the directive device, and means whereby if the switch does not operate in correspondence with the operation of the directive device the directive device will thereupon become disabled.

74. In a switching system, a calling station, a calling line leading from the calling station, a selecting switch at the far end of the line from the calling station, an impulse directive device at the calling station for operating the switch, a locking device at the calling station operative to disable the directive device, and means whereby if the switch does not operate in correspondence with the operation of the directive device the directive device will thereupon become disabled.

75. In a switching system, a calling station, a calling line leading from the calling station, a selective switch at the far end of the line from the calling station, the said switch being operative directly primarily and then automatically secondarily to select an idle line of a group, a directive device at the calling station for directly operating the switch, a locking device at the calling station operative to disable the directive device, and means whereby if the switch does not correspondingly respond to the directive device and thereafter automatically select an idle line of the group the locking device will thereupon become effective.

76. In a switching system, a calling station, a line leading from the calling station to a switch, a manually operated switch at the calling station for affecting the condition of the line, an effectively disconnected

tone source companion to first said switch, a directive device at the calling station for directively operating the first said switch over the line, means responsive to the operation of 5 said manually operated switch for connecting the tone source to said line, and means responsive to an off-normal movement of first said switch for disconnecting the tone source while maintaining second said switch operated.

77. In a telephone system, a calling line, a called line, a linking switch terminating the calling line, a directive device on the calling line for operating the switch over the 15 calling line to extend the calling line to the called line, a code switch mechanism companion to first said switch and responsive to the directive device, a repeating coil and speech amplifying repeater companion to the 20 code switch mechanism, and means whereby after the directive device is operated to connect the calling line to the called line the directive device can then be operated in a predetermined manner to effectively operate 25 the code switch mechanism to introduce either the repeating coil or the speech amplifying repeater at will.

78. In a telephone system, a calling line, a called line, a linking switch terminating the 30 calling line, a directive device on the calling line for operating the switch over the calling line to extend the calling line to the called line, a code switch mechanism companion to first said switch and responsive to the directive device, a repeating coil and speech 35 amplifying repeater companion to the code switch mechanism, means whereby after the directive device is operated to connect the calling line to the called line the directive 40 device can then be operated in a predetermined manner to effectively operate the code switch mechanism to introduce either the repeating coil or the speech amplifying repeater at will, and means whereby the directive 45 device can be thereafter operated to exclude the said introduced element without destroying the established connection between the calling and called lines.

79. In a telegraph system, a plurality of 50 line links, a directive device at a station on a calling one of said lines, mechanism operated over said calling line by said directive device for interlinking the calling line to a called one of said lines, an impulse device 55 at the calling station and also on the called line for sending telegraph signals, a telegraph receiver at each the calling station and on the called line, and means whereby after the 60 said connection is established said impulse devices can be operated independently of each other coincidently to effect only the corresponding opposite receiver and wherein both receivers are operated over the same intervening line conductor.

80. In a telephone system, a calling line, a called line, switching mechanism for extending a connection from the calling line to the called line, a source of signaling current, another source of current, operator directed means controlled over the calling line for operating the switching mechanism to extend a connection from the calling line to the called line, operator directed means for thereafter at will applying second said source 75 of current over the calling line effective to apply first said source of current to the called line, automatically applied means for maintaining the intermittent application of current to the called line, means controlled over the called line for disabling the said automatically applied means, and means for preventing the re-application of said first source regardless of any condition occurring upon the called line while the extended connection is maintained.

81. In a telephone system, a calling line, a called line, switching mechanism for extending a connection from the calling line to the called line, a source of signalling current, an impulse directive device for the calling line, means responsive to impulses sent from the directive device for operating the switch mechanism to extend a connection from the calling line to the called line, means thereafter responsive to a predetermined operation of the directive device at will to effect a predetermined series of impulses for applying said signaling current to the called line, and automatically applied 90 means for indefinitely sustaining the application of the signaling current to the called line after second said means restores from its operated state and said extended connection to the called line is maintained.

82. In a telephone system, a calling line, a called line, switching mechanism for extending a connection from the calling line to the called line, a source of signaling current, an impulse directive device for the calling line, means responsive to impulses sent from the directive device for operating the switch mechanism to extend a connection from the calling line to the called line, means thereafter responsive to a predetermined operation of the directive device at will to effect a predetermined series of impulses for applying said signaling current to the called line, automatically applied means for sustaining the application of the signaling current, means controlled over the called line for disabling said automatically applied means, and means for preventing the re-application of said first source regardless of any condition occurring upon the called line while the extended connection is maintained.

83. In a telephone system, a calling line, a called line, switching mechanism for extending a connection from the calling line to the called line, a source of signaling current, an 120

- impulse directive device for the calling line, means responsive to impulses sent from the directive device for operating the switch mechanism to extend a connection from the calling line to the called line, automatically applied means thereafter effective to apply said signaling current to the called line, automatically applied means for sustaining the application of signaling current to the calling line, means controlled over the called line for disabling the application of signaling current to the called line, means responsive to a predetermined operation of the directive device at will to effect a predetermined series of impulses for again applying said signaling current to the called line, and means for sustaining the application of last said application of signaling current by first said automatically applied means.
84. In a line linking system, a plurality of line links, first and second code switches companion to each said links, mechanism for uniting the links in a tandem connection, an impulse directive device for effectively operating said mechanism and also for step operating the code switches to effect circuit changes, means whereby sending a predetermined series of impulses by said device will effectively step operate only a corresponding one of said first code switches, and means whereby then operating said device will directly step operate a said second code switch companion to the operated said first code switch while other said second code switches remain disabled and said first code switch operated has restored.
85. In an electrical control system, a first and a second code switch, an impulse device for step directly operating said switches over an operating conductor to effect circuit changes by said second switch, means whereby sending a predetermined train of impulses by said device will effectively operate the first switch and then operate the second switch wherein said first switch will be restored before the step directive operation of the said second switch is completed responsive to said device.
86. In a telephone system, a telephone exchange, a subscriber's station, means including a line composed for simultaneous telephony and telegraphy and a plurality of automatic switches for interconnecting said exchange and said station, and means controlled over the composite leg of said line for setting said switches, and signaling said station, a direct current source and means for transmitting supervisory signals from said source to said exchange over the composite leg operative on the response of the subscriber's station.
87. In a telephone system, a telephone exchange, a subscriber's station, means including a line composed for simultaneous telephony and telegraphy and a plurality of au-
- tomatic switches for interconnecting said exchange and said station, a signal at said exchange, means controlled over the composite leg of said line for setting said switches and signaling said station, sources of battery of different potentials, and means controlled by said station including the transmission of current from one source of battery by way of the composite leg of said line for the actuation of the signal and the transmission of current from a second source of battery by way of the composite leg of said line for effecting the restoration of the signal to normal condition.
88. In a telephone system, a telephone exchange, supervisory apparatus thereat, a subscriber's station, means including a line composed for simultaneous telephony and telegraphy and a plurality of automatic switches for interconnecting said exchange and said station, and a path, including the composite leg of said line, for the transmission of dial impulses for setting said switches and signaling current for signaling said station and means including sources of battery and the composite leg for transmitting signaling current from said sources for controlling the supervisory apparatus at said exchange in different manners.
89. In a telephone system, two exchanges, a two-way line circuit extending between said exchanges, an automatic exchange, automatic switches thereat, means for establishing a connection between said first exchanges over said line, and means for controlling said switches at said automatic exchange over one side of said line comprising a source of battery, a dial and a relay responsive to impulses of current from said battery by the actuation of said dial, a second source of battery, contacts and a control relay included in said side of the line said contacts being controlled by said first relay to cause the actuation of the control relay in accordance with operations of the dial.
90. In a telephone system, a telephone exchange, a subscriber's station, means including a line composed for simultaneous telephony and telegraphy and a plurality of automatic switches for interconnecting said exchange and said station, a signal at said station, a signal at said exchange, means at said exchange for controlling said switches over the composite leg of said line, means at said exchange for controlling the signal at said station over the composite leg of said line, and means controlled over the composite leg of said line, from said station for actuating the signal at said exchange to indicate when the subscriber at said station answers, when he has completed conversation and when he recalls the exchange by the manipulation of the subscriber's switchhook.
91. In a telephone system, a telephone exchange, a subscriber's station, means includ-

- ing a line composed for simultaneous telephony and telegraphy and a plurality of automatic switches for interconnecting said exchange and said station, a signal at said 5 exchange, a signal at said station, means at said exchange for controlling said switches over the composite leg of said line, means at said exchange for controlling the signal at said station over the composite leg of said 10 line, and means responsive to switchhook actuations at said station for transmitting direct current impulses over the composite leg of said line to flash the signal at said exchange.
- 15 92. In a telephone system, a first exchange, a second exchange, a transmission line, subscriber stations, a signaling device at said first exchange, automatic switches at said second exchange, means at said first exchange 20 for controlling said switches over only one side of said transmission line to connect said first exchange with a subscriber's station, and means controlled over the same side of said line for complete control over the operation 25 of the signaling device at said first exchange during the establishing of a connection.

In witness whereof, I hereunto subscribe my name this 28th day of February A. D., 1923.

30 HERBERT M. FRIENDLY.
